UNITED STATES PATENT OFFICE.

WARREN WESLEY CARPENTER, OF QUEENS VILLAGE, NEW YORK, ASSIGNOR TO
WESTERN ELECTRIC COMPANY, INCORPORATED, OF NEW YORK, N. Y., A CORPOR-
ATION OF NEW YORK.

TELEPHONE-EXCHANGE SYSTEM.

Application filed July 14, 1925. Serial No. 43,478.

This invention relates to telephone exchange systems, and more particularly to systems of the class wherein automatic switching apparatus is employed either entirely or in part for the establishment of conversational connections.

In telephone systems of the class in which the automatic selective switches are under the control of common register controlling apparatus located at the central office, it is necessary to associate the recording or registering apparatus with the successive switches in the train which it is to control. It is also usually true that the majority of the various operations involved in establishing a connection take place either in or under the control or influence of the central office register controlling apparatus. It follows, accordingly, that whenever trouble is encountered in the process of establishing a telephone connection, the probability is that the source of such trouble is either within the controlling mechanism or in apparatus over which the controlling mechanism is at the time exercising control. In order that every instance of trouble may not be permitted to thwart the successful establishment of the connection, it is proposed to discharge the controlling mechanism being employed at the time the trouble occurs and to again seize either the same or a new controlling mechanism in a new attempt to accomplish the operations necessary to the completion of the desired connection.

Again, where the register controlling mechanism is provided in common to a plurality of selective switches, any one of which it may govern, it is convenient to employ suitable connectors to connect said mechanism to a desired switch during the time the control is taking place. Frequently, the controlling mechanism will be unable to successfully complete the desired connection owing to a failure in some one of the various control circuits leading to and through said connectors. From this it will be seen that were it possible to make use of a different connector for associating the control mechanism with the selective switch, the difficulty might be circumvented.

An object of the invention, therefore, is to

enable the discontinuance of a first attempt to complete a telephone connection, without releasing such portion of the connection as may already have been established, and to make a new attempt to complete the connection employing new apparatus for associating the controlling mechanism with the selective switches.

A feature of the invention relates to a system having a plurality of switch controlling mechanisms or markers and a plurality of connectors each available for connecting any marker to a given switch or group of trunks together with means for discharging a marker and the connectors it is using, without releasing the partly established connection, and for seizing a new marker and new connectors in a further attempt to complete the connection.

Another feature of the invention relates to an arrangement in which the markers are divided in two groups, the markers of each group normally preferring certain connectors for gaining access to the switches and trunks together with means whereby when any marker encounters difficulty it is discharged and another marker seized for a second trial, the new marker in every case employing connectors other than those employed by the first marker.

Another feature relates to a system having register senders and switch controlling markers with means for recording in the sender the character of the connectors used by the first marker and for thereupon discharging the first marker and seizing a new one, the record in the sender now serving to determine that the new marker will employ other connectors.

Another feature relates to the provision of a plurality of translators for each of several groups of lines or switches, certain markers normally preferring to use a certain translator of each group for controlling the selective operation of the associated switches, together with means whereby a second trial marker will make use of a translator other than the one used in the first trial.

A further feature relates to the provision of a trouble indicating device common to a number of markers arranged to be connected

to a given marker at the end of a measured interval together with means responsive to certain conditions for connecting said device to the marker immediately.

5 Another object of the invention is an improved method of assigning trunk groups of varying sizes to different portions of the selector switch with means for confining the testing operation to the particular 10 trunks in the desired group.

Another object of the invention is to make a test of the partially established connection before proceeding to complete the same.

According to this latter object, a polarized 15 relay is installed in the marker and is included in a circuit including the talking circuit which has been extended through a switch to a succeeding switch to insure that such talking circuit is in proper condition.

20 Another object is to secure an improved arrangement of locating and testing the trunks of a private branch exchange group.

The drawing, which is partly diagrammatic and partly in detail, illustrates the 25 circuits and apparatus of a local telephone office. The equipment shown is capable of receiving calls from subscribers' lines which terminate as calling lines in the local office, and of completing these calls to any of the 30 subscribers' lines which terminate as called lines in the same office. Moreover, it is designed to extend calls to the various types of the operators' positions as customarily employed in commercial exchanges. Furthermore, the equipment shown in this disclosure is designed to extend calls from the local office over outgoing trunks to the various types of outlying offices with which connection may be desired. Again, calls may 40 be received incoming from outlying offices for local subscribers' lines. For the purpose of this case, however, it has been considered sufficient to confine the description to local office operation and to point out only 45 in a general way the manner in which interoffice connections are effected.

In referring to the drawing, Figs. 1 to 50 68 inclusive when taken in the order illustrated in Fig. 73 disclose circuits and apparatus employed in the establishment of connections between calling and called lines.

Fig. 1 shows two calling subscribers' lines together with a portion of the control circuits of the line switch.

55 Fig. 2 illustrates diagrammatically a coordinate line switch in which the calling lines appear.

Fig. 3 shows one of the trunk circuits leading from the line switch.

60 Fig. 4 illustrates a portion of a coordinate district selector switch in which terminate the trunks leading from the line switches.

Fig. 5 shows two of the trunk circuits outgoing from the district selector switch,

Fig. 6 shows one of the coordinate office 65 selector switches in which terminate trunks leading from the district selector switches.

Fig. 7 shows control circuits associated with one of the trunks leading from the 70 district selector switch.

Fig. 8 illustrates a portion of a coordinate incoming selector switch in which terminate trunks from the distant switches.

Fig. 9 illustrates a number of trunks leading from the incoming selector switches to 75 the final connectors.

Figs. 10 and 11 taken together illustrate a portion of one of the final connector switches which have access to the called subscribers' lines and to private branch exchange trunks.

Figs. 12 and 13 illustrate a coordinate sender selector switch for associating the trunks with the register senders.

Figs. 14 to 24 inclusive illustrate one of a 85 plurality of register senders.

Figs. 14 and 15 illustrate a portion of the control circuits of the sender.

Fig. 16 illustrates the counting relay set.

Fig. 17 shows a portion of the class relays 90 for recording class indications.

Figs. 18 and 19 show control circuits.

Fig. 20 shows a portion of a relay sequence switch for associating the impulse circuit with the registers.

Fig. 21 shows the office code registers.

Fig. 22 shows the code impulse sending sequence switch.

Fig. 23 shows the remainder of the relay sequence switch.

Fig. 24 illustrates the numerical and stations registers.

Figs. 25 and 26 show a portion of the sender connector for connecting the senders to the outgoing markers.

Figs. 27 to 35 inclusive illustrate one of a plurality of outgoing markers.

Fig. 27 shows a portion of the controlling apparatus.

Fig. 28 shows a part of the testing relay 110 equipment.

Fig. 29 shows the full registers in the marker.

Figs. 30, 31 and 32 show controlling relays and circuits.

Fig. 33 shows a portion of the translator.

Fig. 34 shows cross-connecting frames and controlling relays.

Fig. 35 illustrates a few of the code relays and also shows controlling equipment.

Fig. 36 illustrates two of the district frame connectors.

Fig. 37 illustrates two of the trunk connectors.

Fig. 38 illustrates two of the office frame 125 connectors.

Fig. 39 illustrates a portion of the marker alarm and trouble indicator equipment.

Fig. 40 illustrates a connector for associating a trouble indicator with the outgoing markers.

Figs. 41, 42 and 43 show the remainder of 5 the trouble indicating equipment.

Figs. 41 and 42 show relays and lamps for indicating the progress of the marker when trouble is encountered.

Fig. 43 shows two time measure circuits.

19 Figs. 44 and 45 illustrate a sender selector switch for associating the incoming senders with the trunks incoming to the incoming selector switches.

15 Figs. 46, 47 and 48 illustrate one of a number of incoming senders.

Fig. 46 shows the impulse receiving and control circuit of the sender.

Fig. 47 shows the numerical registers.

20 Fig. 48 shows a time measure mechanism. Figs. 49 and 50 show a portion of the incoming sender connector for connecting the incoming senders with the incoming markers.

25 Figs. 51, 52, 53, 54, 55 and 56 illustrate one of the incoming markers.

Fig. 51 shows control relays and circuits.

Fig. 52 shows a portion of the testing equipment.

Fig. 53 shows the marker registers.

30 Fig. 54 shows a portion of the translator in the incoming marker.

Fig. 55 shows control equipment.

Fig. 56 illustrates the controlling equipment for PBX operation.

35 Figs. 57 and 58 show a portion of the final translator connector for connecting the incoming markers to the final translators.

40 Fig. 59 shows one of the final translators for controlling the operation of the final switches in a particular group.

Fig. 60 shows a portion of an ultimate final translator for controlling the same group of switches.

45 Fig. 61 shows two incoming frame connectors.

Fig. 62 shows two trunk connectors.

Fig. 63 shows a pair of final frame connectors.

50 Fig. 64 shows a portion of the incoming marker alarm and trouble indicator circuit.

Fig. 65 shows two time measure devices constituting a part of the trouble indicator equipment.

55 Fig. 66 shows a connector for connecting the trouble indicator to the incoming markers.

Figs. 67 and 68 show relays and lamps in the trouble indicator for indicating the progress of the marker which has encountered trouble.

60 Figs. 69 and 70 constitute a diagram of the system.

65 Figs. 71 and 72 are diagrams illustrating the manner in which trunks are assigned to space in the selector switches and the man-

ner in which the testing equipment of the outgoing markers functions.

Fig. 73 is a diagram showing the manner in which the several sheets of the drawing should be arranged. 70

General description of the system and apparatus.

A description will first be given of the general plan of the system in connection 75 with the diagram of Figs. 69 and 70. The lines such as 6900 and 6901 enter the office and terminate in a suitable number of line switches such as the switches 6902 and 6903. Outgoing from these switches are a number 80 of trunks which extend to district selectors. For reasons which will appear later, the district selectors are divided into a number of groups, two of which groups 6906 and 6907 are illustrated. The group 6906 comprises 85 a number of district selector frames of which two, 6908 and 6909, are shown, and trunks such as trunks 6905 and 6939 leading from the line switches are distributed among these district selectors. In like manner 90 other trunks 6904, etc., extend to the district selectors 6910 and 6911 of the second group 6907. Still other groups of district selectors may be provided.

The trunks outgoing from the district selector switches lead in different directions. For example, some of the trunks such as 95 6914 and 6915 extend to office selector switches. The office selectors may be arranged in groups similar to the district switches, the selectors 6916 and 6917 constituting one group. Other groups may be provided in a manner similar to that illustrated for the district selector switches. The trunks 6918 leading from the office selectors 100 extend to distant offices to take care of inter-office traffic. 105

Other trunks leading from the district selector switches, such as the trunks 6912 and 6913, extend to incoming switches located in the same central office. These incoming switches may be divided into two groups, one of which is represented by the frames 7000 and the other by the frames 7001. The trunks outgoing from the incoming switches, such as trunks 7028 and 7029, lead to the various connector switches of the several groups or choices. Two groups of connector switches, 7002 and 7003, are illustrated in the drawing. The first group 115 includes final switches 7004 and 7005 and the second group includes final switches 7006 and 7007. These final switches have access to numerically designated called lines, such as the lines 7008 and 7009. 120

The trunks which lead from the line switch to district selectors also appear in sender selector switches 6919 which operate to extend these trunks to the register senders. Two of these senders, 6920 and 6921, 130

are shown. The sender connector 6922, which actually comprises a plurality of sections, serves to connect the senders to the outgoing markers 6923, 6924, 6925 and 6926.

5 In order to connect the outgoing markers to the district selector switches, there are provided a number of district frame connectors. The markers are all divided into two groups, which will be designated the 10 even and the odd groups. For instance, it may be considered that the markers 6923 and 6924 belong to the even group and that the markers 6925 and 6926 belong to the odd group. Similarly, all of the district frame 15 connectors are divided into two corresponding groups, an even group 6927 and an odd group 6928. Normally the even markers prefer to use the even frame connectors in making connection with any district frame, 20 and the odd markers prefer to employ odd frame connectors. For instance, if one of the markers of the even group is to be connected to a district selector in the group 6906, the frame connector 6929 which is located 25 in the even group 6927 and which relates to the group of district switches 6906 will preferably be employed. If one of the even markers is to be connected to a district 30 in the group 6907, then the frame connector 6930 also in the even group 6927 will be used preferably. In like manner, the odd markers will prefer to use a connector such as connector 6931 for making connection to district switches in the group 6907, and a 35 connector such as 6932 for making connection with the district switches 6906.

In order that the outgoing markers may 40 perform a test of the trunks in the desired group outgoing from the district selectors, there are provided a number of trunk connectors 6933, 6934, etc. These trunk connectors are also arranged in an even and 45 an odd group. The connector 6933, for instance, may be located in the even group and will be used preferably by the markers of 50 the even group for making connections with the trunks outgoing from any of the district selectors. The connector 6934, on the other hand, may be located in the odd group and 55 will preferably be employed by the odd markers for making connection with any of said trunks.

On a first attempt to establish a connection through one of the district selector 60 switches, the sender may be connected to any marker depending upon the busy or idle condition of the markers. The sender in selecting an idle marker pays no attention to 65 whether or not such marker is in the even or odd group. Its only concern is to seize the first idle one. If the marker chances to be even, then, as above pointed out, a frame connector in the even group 6927 will be employed and an even trunk connector will 70 be used. Should trouble be encountered, or

should it be desired for any other reason to discontinue the first attempt to establish a connection through the district switches, the marker will be discharged without releasing so much of the connection as has already 70 been established. Immediately upon the discharge of the first marker, the sender will seize another marker regardless of whether the second marker is odd or even and depending only upon its idle condition. Therefore, the sender may secure an even marker on the second trial, or it may seize an odd marker. Regardless of whether the second marker is even or odd, the system is so arranged that this marker will employ an odd 75 frame connector and an odd trunk connector. The reason for this is to enable the marker on a second trial to employ different connecting equipment from that used by the first marker to eliminate the possibility of 80 encountering the source of trouble which thwarted the first attempt. In a similar manner, should the marker used on the first trial be odd, then the second marker regardless of whether it be even or odd would employ even frame connectors and trunk connectors. 85

If an interoffice connection is being established, the office selectors will be used as well as the district switches, and for this 90 purpose the markers will be connected to the office selectors through the frame connectors 6935 and 6936, and the outgoing trunk groups through the trunk connectors 6937 and 6938. These office frame and trunk connectors are employed in the same manner as the district connectors. A second trial 95 marker will therefore seize a frame connector and a trunk connector of the opposite character from those employed by the first 100 trial marker.

On a local call, the connection is extended through the district switches over trunks such as 6912 and 6913 to one of the incoming 105 selector frames 7000 or 7001. Immediately upon the extension of the connection to an incoming frame, an incoming sender selector 7010 is also operated to extend such connection to an idle one of the incoming senders, 7011, 7012, etc. Following the seizure of the 110 incoming sender, the numerical record identifying the called subscriber's line is transmitted from the subscriber's sender through the sender selector 6919, through the district selector switch over the trunk through the 115 sender selector 7010 and recorded in the incoming sender 7011, for instance.

Like the outgoing markers, the incoming markers are also divided into two groups, 120 an even group and an odd group. The marker 7014 may be considered as located in the even group and the marker 7015 in the odd group. Also, the incoming frame connectors are arranged in corresponding 125 groups, the connector 7030 belonging to 130

the even group and the connector 7031 belonging to the odd group. These two connectors, it will be noted, serve to connect the marker to the group of incoming selectors including the frames 7000 and 7001. Other pairs of incoming frame connectors will serve to connect the markers to other groups of incoming frames in a manner similar to that shown in connection with the 10 district selectors.

For the purpose of enabling the incoming marker to control the proper final selectors, the called subscriber's lines are arbitrarily divided into a number of groups together 15 with the final selector switches. It may be assumed, for instance, that there are five final groups or choices each containing 2000 lines in a 10,000 line office. Serving each of these five groups of lines are a plurality of 20 final selector switches and a pair of final translators. For instance, the first group or choice 7002 contains a plurality of final switches 7004 and 7005, etc., which are controlled by the incoming markers through the 25 medium of the final translators 7020 and 7021. A second group 7003 is illustrated containing the final frames 7006 and 7007 and the final translators 7024 and 7025. The incoming markers are connected to the final translators through translator connectors 30 7016 and 7017. One of these translator connectors is preferred by the even markers and the other is preferred by the odd markers. In a similar manner, the final translators 35 are of a first and second choice character; that is, the translator 7021 will be used on all first attempts to make a connection through the final switches of the choice 7002. If a second trial is made, then the other translator 7020 will be used. The same holds 40 true for the translators of the remaining groups.

Should it be desired to associate the even marker 7014 with the final group 7002 on a 45 first trial, the translator connector 7016, which the marker 7014 prefers, will be employed for connecting said marker to the first choice translator 7021. The final translator 7021 governs the proper final selector 50 switch to make connection with the called line. However, on a second trial if the first trial marker was even the second marker will be connected through the selector 7017 to the second choice translator 7020 which serves to 55 control the same final selector switches.

For enabling a test of the trunks interconnecting the incoming switches and final switches, each final group is provided with a pair of trunk connectors. The trunk connectors 7018 and 7019 serve to associate the 60 testing equipment with the trunks leading to the final switches of the first group 7002. Similarly, the trunk connectors 7022 and 7023 serve to connect the testing equipment 65 with the trunks leading to the second group

7003. The connector 7019 of the first group, for instance, is a first choice connector for even markers and is employed whenever the final translator 7021 is used. Likewise, the connector 7018 is a first choice connector for 70 all of the odd markers and is employed whenever the final translator 7020 is taken into use.

Trouble indicators and alarm circuits are also provided for calling attention to the 75 fact that trouble has been encountered and for taking a record of the equipment employed and the location and cause of such trouble. Common to all of the outgoing markers there is a trouble indicator 6940 80 which may be connected through a connector 6949 to any one of the markers. This indicator is summoned in response to various conditions and connected to a marker which has encountered trouble for the purpose of 85 taking a record of the operations.

Similarly, a trouble indicator 7026 is provided for the incoming markers and may be associated to any one thereof through a connecting device 7027. 90

Referring to Figs. 1 to 68, a more detailed explanation will now be given of the arrangement of the switches and the controlling mechanism. First, with respect to the construction of the line switch, selector and 95 connector switches, and the sender selectors, these may be of the same general construction and operation as the switch shown and described in detail in the patent to S. B. Williams, Jr., No. 1,517,331, issued December 2, 1924. 100

The subscribers' lines appear in the line switches as shown in Fig. 2, there being a plurality of lines assigned to each vertical row. For instance, the lines 100 and 101 appear in the vertical row 201 of the line switch 200. The line 100 is capable of connection to relays with a plurality of link circuits, or horizontal links as they will be called hereinafter. Two of these horizontal 110 links 205 and 206 are shown. The line 101 in the same vertical row has access to the horizontal links 207, 208, etc., of a different horizontal group. In like manner, other lines of the same vertical row have access to 115 other horizontal groups not shown in the drawing. There may be any desired number of vertical rows of groups of lines, one vertical group 202 being shown. The outgoing trunks, two of which trunks 219 and 220 are 120 illustrated, occupy each a complete vertical row of contacts such as 204 and 203 respectively in the line switch 200, thus intersecting all horizontal links. 125

The contact controlling bars assigned to the vertical rows are operated by the respective vertical magnets 209, 210, 211 and 212, while the horizontal operating bars are actuated by the individual magnets such as the magnet 216. 130

Trunks outgoing from the line switches lead to the district selector switches 400 and appear in vertical rows of contacts 401, 402, etc. These trunks may be disposed in any 5 convenient manner among the different district selectors of the different groups.

The trunks extending between the line switches and the district selectors also appear in sender selector switches such as the 10 switch 1300. These trunks appear in the sender selector switches in substantially the same manner as the subscribers' lines appear in the line switches. For instance, the trunk 219 together with trunk 221 and others appear in the vertical row 1301. Still other trunks occupy another vertical row 1302. The different groups of trunks are served by the different groups of horizontal links including links 1305, 1306, 1307 and 1308. 15

20 The outgoing trunks from the sender selector switches lead to the separate register sending mechanisms, and each such circuit occupies a full vertical row of contacts. The circuit 1309 shown in full occupies the vertical row 1304 and leads to the particular sender shown in the drawing. The circuit occupying the vertical row 1303 leads to a different register sender.

The purpose of the register sender shown 30 in Figs. 14 to 24 inclusive is to receive and record the designation of desired lines for the purpose of controlling the selective operation of the switches. The receiving portion of the sender shown in Fig. 16 consists 35 of the impulse relays which receive the impulses and in turn operate a series of counting relays 1600. The first three registers 2100, 2101 and 2102, each comprising a plurality of relays, are for the purpose of recording the three digits which constitute the code designation of the office in which the call is to be completed. The remaining registers shown in Fig. 24 serve to receive and record the numerical and stations portion 40 of the called line designation.

The relays shown in Fig. 17 are principally for storing class information whereby the sender may properly govern the remaining apparatus in the system to establish 50 the connection involved. This class information is received from the outgoing marker during the time the sender is connected thereto to be used by the sender after the marker has completed its function and has 55 been disconnected from the sender.

The relay series 2000 and 2300 constitute a switching device by means of which the impulse circuit is associated with registers and functions as the digits are received over 60 the calling line. The switch 1900 is a switch of the sequence type, driven from position to position by a power-operated shaft and serves to control the sequence of operations of the sender. This switch has several contacts which are shown at different places in

Fig. 19. The sequence switch 2200, also of the same type, has a number of contacts shown in Fig. 22 and its purpose is to transfer the record stored in the sender by means of code impulses either to the incoming 70 sender in the same office or to an incoming sender at the distant office. These switches may be of the construction shown in the patent to Reynolds and Baldwin, No. 1,127,808, granted February 9, 1915.

Since there are a number of outgoing markers available for all of the district selectors, and since the district selectors are divided into groups each group having a separate frame connector, it is possible to 75 have two or more outgoing markers function simultaneously in the control of the district selector switches, provided the sender connector is so arranged that a plurality of markers may be simultaneously connected 80 to respective senders. To this end the sender connector has a number of separate connector sections 2500 and 2600. The section 2500 is made up of a plurality of multi-contact relays 2501, 2502, etc., each such relay 90 being individual to a different one of the recording senders. Furthermore, this section 2500 includes a number of multi-contact relays 2503, 2504, etc., each individual to a different one of the outgoing markers. In 95 a similar fashion, section 2600 of the sender connector is made up of multi-contact relays 2601 and 2602 each individual to a separate sender, and relays 2603, 2604, etc., each individual to one of the outgoing markers. All 100 of the senders appearing in the section 2500 may be considered as a group of senders, while senders appearing in section 2600 comprise a second group. It will be noted that no one sender appears in more than one of these groups, the particular sender illustrated in full in the drawing appearing in the first mentioned group and in contacts of 105 the relay 2501.

Each of the outgoing markers has an appearance in each of the different sections 110 2500 and 2600 of the sender connector. For example, the marker shown in the drawing appears in contacts of relay 2504 in the section 2500 and also in corresponding relay 2604 in section 2600. A second marker will similarly appear in the contacts of relays 2503 and 2603 of the respective sections. The circuits are arranged to prevent interference so that whenever a marker is connected to a sender through one section of the sender connector, it is rendered non-selectable to any other sender either through the same or through another section.

As soon as the sender which has received 115 the record from the calling line has been connected through the sender connector to an idle outgoing marker, the office or code part of the designation is transferred from the registers 2100, 2101 and 2102 through the 120

5 sender connector to corresponding registers 2900, 2901 and 2902 in the marker. The register 2900 determines the operation of one of the 10 number of multi-contact relays 3301, 3302, 3303, etc., of the translator 3300. The 15 register 2902 determines the operation of one or more of the relays 3304, 3305, etc. With these relays operated, the register 2901 applies ground potential to one or more of the 20 conductors 3306 which lead through the translator 3300 to the distributing frame 3503, causing the operation of one of the routing or code relays 3500, 3501 and 3502. The purpose of these code relays is to determine the routing of the connection through 25 the district and office selector switches 400 and 600.

As hereinbefore noted, there are a number of frame connecting devices for connecting the outgoing markers to the district and office frames. There is at least one of these 20 district frame connectors for each of the different groups of district frames, the purpose being to enable a number of different markers to be simultaneously connected to district 25 switches in the different groups. The district frame connector 3600 is individual to the particular group of district frames which contains the district switch 400. The connector 3600 consists of a number of multi-contact relays 3604, 3606, etc., each individual to a different one of the outgoing markers. Moreover, it includes a number of 30 multi-contact relays 3605, 3607, etc., each of which is individual to a different district 35 selector in the group. The relay 3604 is seen to be individual to the particular marker shown in the drawing, which marker prefers the frame connector 3600 on all first trials. The relay 3606, for example, may be individual to some other marker which only employs the frame connector 3600 on second 40 trials.

The frame connector 3601 also serves the 45 same group of districts including the district switch 400. This frame connector is employed by the marker shown and all other markers of the same group as a second choice connector. The connector 3601 would 50 also be used by the other group of markers as a first choice connector on all first trials. There will be other pairs of frame connectors 55 similar to the pair shown for other groups of district selectors, each connector of each pair serving as first choice to one group of markers and second choice to the other group.

A description will now be given of the 60 manner in which a marker is enabled to determine the group of districts and also the particular district in the group to which it should make connection. All of the trunks leading from the line switches to a given 65 group of district selectors may be segregated to appear in one or more sender selectors

1300. These sender selectors have access to a given group of senders. This group of senders, in turn, will have access to the markers through a given section 2500 of the 70 sender connector. Hence, whenever a call is extended to a given group of districts, the 75 marker seized will be able to distinguish this group from other groups by reason of the fact that it was seized through the section 2500 of the sender connector instead of some other section. To this end, a group 80 of frame test relays 2700 in the marker is provided for each group of districts. While only one set of relays 2700 is shown, it will be obvious that other sets may be employed. Whenever a marker is seized, the relay 2701 is operated in a circuit completed through the section 2500 to determine the particular 85 group of districts concerned. Should the call be extended to some other group of districts, then a different group of senders will be employed and the marker will be seized through another section of the sender connector 2600, and accordingly a different relay 2701 will be operated in the marker to 90 identify this other group of district switches. Each group of district switches may contain a plurality of frames, four for example. In order that the marker may determine the 95 particular one of the four frames in the group, a test is performed by means of the frame test relays 2700 which are included in a test circuit leading to the resistance connections 300 in the district trunk. All of the trunks leading to a given district in a 100 group will have the same type of connection 300. Similarly, all of the trunks leading to each of the other three districts of the same group will have a uniform connection, but all four groups of trunks will differ each 105 from the other. By this means whenever a connection is extended over any trunk into any one of the four district switches, the test relays 2700 will operate in a variable manner to identify this particular district 110 frame. This test is used for the purpose of selecting and operating the frame connectors 3600, 3601, etc.

The trunk connectors 3700 and 3701 are 115 employed for connecting the markers to the trunks outgoing from the district and office switches. While the diagram of Fig. 69 shows separate trunk connectors for the district and office trunks, these may be combined if desired as shown in Fig. 37. The 120 trunk connector 3700 serves as first choice to one group of markers, which includes the marker shown in the drawing, and as second choice to the other group for second trials. Similarly, the other connector 3701 125 serves as second choice for the first group of markers and first choice for the second group. As many other trunk connectors may be provided as are necessary. These 130 trunk connectors are selected and operated

by the trunk group relays 3000, 3001, 3100, 3101, etc.

The office frame connectors 3800, 3801 are similar to the district frame connectors and are controlled in like manner. There may be as many pairs of these frame connectors as there are groups of office frames. The office frame connectors, as will be explained in detail hereinafter, are selected by the office frame relays 3200.

Each of the outgoing markers is equipped with a series of testing relays 2800 for testing the horizontal links and the outgoing trunks on any of the district or office switches. Each relay has two windings, one for testing the condition of the corresponding link on any switch frame and a second winding for testing the trunk to which such link has access. There are, therefore, as many testing relays in the series as there are links and trunks in any vertical row in the switch frames. For convenience in description, it may be assumed that the switch frames have a capacity for 70 horizontal links and consequently 70 trunks in each vertical row as a maximum. According to the character of the traffic served, a trunk group may comprise the full 70 trunks in a vertical row of the switch. If small groups are required, a vertical row of contacts may be divided into several groups. For example, a single vertical row may contain one group of 40 trunks, a second group of 20, and a third group of 10 trunks, each of these trunks being separate and distinct from the others and going in different directions. Again, a vertical row may be made up of three groups of 20 and a single group of 10 trunks. In other cases it may be desired to employ groups of trunks containing more than 70. In this case it becomes necessary to place 70 trunks on a corresponding vertical row of a number of district selectors and to place the remaining trunks on corresponding rows of other and separate district selectors. For instance, if it is necessary to have a group of 140 trunks, 70 of these may be multiplied to half of the district selectors occupying a full vertical row on each of these, and the other 70 trunks may be similarly multiplied to the other half of the district selectors. In fact, this gives two full groups of trunks going to the same destination.

For the sake of convenience merely, it will be considered that the smallest group of trunks contains 10 trunks and that all groups contain a number of trunks which is some multiple of 10. In order that these variably sized groups of trunks may occupy any portion of a vertical row of 70 contacts in the switch frame, it is necessary to provide some means whereby the corresponding number of test relays in the marker, and these only, will be employed for making

the test for an idle trunk. Referring to Figs. 71 and 72, there is shown a portion of the testing and space assignment equipment of one of the outgoing markers. The series 7100 represents the 70 double wound relays in the marker. There is shown the first and last relay of each sub-group of 10. A number of space assignment relays 7101, 7102, 7103 and 7104 are illustrated. There will be one of these relays for each group of trunks. Each of the space assignment relays causes the operation of one of the relays 7105, 7106, 7107, 7108, etc., to determine the point at which the test is started in the chain of test relays 7100. In other words, these relays 7105, 7106, etc., determine whether the test starts at the beginning of the trunk group or at some point intermediate the beginning and end of the trunk group. In any case, the starting point in a trunk group will be with the beginning of some sub-group of 10 trunks. The space assignment relays also cause the operation of one or more of the relays 7109, 7110, 7111, 7112, etc., to determine the beginning of the trunk group in the vertical row of contacts or in the testing relay chain and to determine the end of such group.

To consider a specific example, assume that the group of trunks to be tested contains only 10 trunks and that this group is located at the bottom or occupying the first 10 sets of contacts in a vertical row on the selector switch. Accordingly, the space assignment relay 7101 is operated, causing the operation of relays 7105, 7109 and 7113. The test relays 7100 are operated or not according to whether the corresponding trunks are busy and a start circuit may be traced from ground through the right armature of relay 7105, thence through the front contacts of all operated test relays, through the back contact of the first non-operated test relay, to an operative relay such as the last relay in the group 7114. As will be explained hereinafter, the relay 7114 causes the operation of the horizontal magnet on the switch frame. Had all of the 10 trunks been busy, then the circuit above traced would have extended over the front contacts of relay 7115, front contact of relay 7109, lower front contact of relay 7113, to the pairs busy and overflow conductors 7116 and 7117.

Assuming another example in which a group contains 30 trunks which are located on the bottom of the switch frame, the space assignment relay 7102 in this case will be operated. Relay 7102 causes the operation of relays 7106, 7118 and 7111. It will be noted that since relay 7106 is operated instead of relay 7105, the testing operation will begin with the 11th trunk instead of the first trunk in the group of 30.

Accordingly, a test circuit may be traced from ground through the right contact of relay 7106, thence through front contacts of the operated test relays 7119 to 7120 provided the second 10 trunks are all busy, through the back contact of relay 7110, lower back contact of relay 7122, thence through front contacts of the third group of 10 test relays, and, if all of these are busy, through the front contact of relay 7123, front contact of relay 7111, right back contact of relay 7124, back contact of relay 7121, lower back contact of relay 7113, thence through the front contacts of the operated test relays in the first sub-group of 10, and if no idle trunks are found herein, through the front contact of relay 7115, back contact of relay 7109, front contacts of relay 7118, to the overflow and pairs busy conductors. In this instance, it will be noted that the group contained 30 trunks and the testing operation instead of beginning with the first trunk in the group commenced with the 11th trunk. In a similar manner, the starting point of the test may enter at the beginning of any sub-group of 10 trunks in any trunk group, dependent upon the connections of the space assignment relay. Thus the distribution of the load on the trunks of a group may be evenly distributed by causing the testing operation to begin at different points in the group in accordance with different conditions, as for example the particular marker that is being used. Whenever a certain marker is employed, the testing operation may begin at one point in a particular trunk group, whereas if another marker is used, the testing operation will begin at a different point in the same trunk group.

Considering the third example, assume that the group of trunks contains 30 trunks and that they comprise the 21st to the 50th set of terminals in the selector frame. In other words, they correspond to the third, fourth and fifth sub-groups of 10. For this purpose, the space assignment relay 7103 is energized and causes the operation of relays 7125, 7126, 7124 and 7127. The test now begins with the last group of 10 and the circuit may be traced from ground through the right contact of relay 7125, thence through the front contacts of test relays 7128 to 7129, inclusive, thence through the front contact of relay 7127, back contacts of relays 7130 and 7131, front contact of relay 7124, lower back contact of relay 7122, thence through the front contacts of the operated test relays 7132 to 7123 if all of these are busy, back contacts of relays 7111, back contact of relay 7133, through the front contacts of the operated test relays 7134 to 7135 in the event these are all busy, back contact of relay 7112, thence through front contacts of relay 7126, to the busy conductors 7116 and 7117. The conductors 7116 and 7117 may be extended to suitable recording devices to indicate that the group of trunks is found busy and to operate such other mechanism as may be desired.

Inasmuch as the present case is devoted to the establishment of a local connection, the routing of calls to the office selector switches 600 will only be taken up in a general way. It will be noted that the trunks which extend to the office selectors appear in the district frame multiples. These trunks, which occupy the full vertical rows 601, 602, etc., of the office selector switches, 80 may be accessible to all horizontal links 605, 606, 607, 608, etc. The trunks occupying the vertical rows 603, 604, etc., comprise groups which extend to the distant offices for interoffice traffic. 85

The trunks leading from the district selector such as trunk 417 terminate in incoming selector switches 800. These trunks occupy the vertical rows of contacts 803, 804, etc., there being two trunks per vertical row of contacts. For example, the trunk 417 appears in the row 803 and has access to 35 horizontal links in the upper section 801, while the trunk 807 appears in the same vertical row having access to 35 95 horizontal links in the lower section 802 of the switch. In a similar manner, other incoming trunks occupy other vertical rows of contacts. 90

A number of groups of trunks leading from the incoming switches extend and appear in the vertical rows of the final or connector switches 1000. The connector switches may be arranged in five groups as previously explained, each group having access to the corresponding group of 2000 called subscribers' lines. In order to reach any desired group of connectors, it is only necessary to select at the incoming switch a group of trunks extending from the incoming switches to the proper group of connectors. These groups of trunks are multiplied so as to have an appearance in each of the horizontal sections 801 and 802 of the incoming switches. In other words, a given 100 group of trunks outgoing from the incoming switches contains 35 trunks, each of which may be reached through a single horizontal link in each of the two sections of the incoming switch. More specifically, the group 110 of trunks 808 appears in the vertical row of contacts 806 of the incoming frame 800, and is also multiplied to appear correspondingly in other incoming frames. The trunks of this group extend to a given final 120 group or choice and appear in vertical rows 1001, 1002, etc., of the connector switch 1000, and are also multiplied to appear correspondingly in other connector switches in the same connector group. 125 130

Furthermore, it will be noted that the connector switches are divided into a number of horizontal sections. In this case there are five horizontal sections each comprising 5 fourteen horizontal connecting links. Two of these sections 1003 and 1004 are illustrated. As in the case of the incoming switches, each of the trunks of a group has a single appearance in each of the five sections 10 of the connector switches.

A second group of 35 trunks 809 extending from the incoming switches may lead to the connector switches of a second connector group. Similarly, there are provided as 15 many groups of trunks extending from the incoming switches as there are groups of connector switches in the office.

It will be observed that while a group of 20 35 trunks may be contained in a single vertical row of contacts on the incoming switches 800, it is not practical to confine these trunks all to a single vertical row on the final switches. Accordingly, a group of 25 35 trunks is distributed among as many vertical rows as is necessary at the connector switches, and the testing relays in the marker are arranged so as to test for an idle path through the incoming and connector switches.

30 The called subscriber's lines appear in the connector switches in vertical rows 1102, 1103, 1104, 1105, etc., each vertical row accommodating five subscribers' lines. The line 1100 therefore appears in the row 1102 35 and has access to all of the horizontal links in the section 1003. A second line 1106 appears in the same vertical row having access to the horizontal links in the section 1004. A decimal group of ten subscribers' 40 lines therefore occupies two vertical rows in the connector switch, five on each row.

45 After the connection has been extended through the district selector switch over a trunk to the incoming selector 800, the incoming sender is connected to the extended trunk and the record is transferred from the first sender to the second sender. The incoming sender is thereupon connected to an idle incoming marker through the sender 50 connector 4900, 5000. The incoming marker comprises a number of numerical registers 5300, 5301, 5302, and 5303 which receive the numerical designation from the sender. Also the marker includes a translator device 5400 which is set in accordance with the 55 operation of the numerical registers. The translator device 5400 comprises a number of multi-contact relays 5401, 5402, 5403, etc., which are operated by the thousands register 5300. It also includes a number of relays 5404, 5405, 5406, etc., operated in accordance with the setting of the hundreds register 5301. The translator 5400 when thus positioned serves to select one of the 60 five translator connectors 5700 for the pur- 65

pose of associating the incoming marker with the final translator having access to the desired group of 2000 called lines.

70 For the particular group of 2000 lines illustrated in the disclosure, there are provided a pair of final translators 5900 and 6000. The translator 5900 is preferred for certain markers and is always taken instead of the other translator when the translator connector 5700 is employed instead of the translator connector 5800. On a second trial for the particular incoming marker shown, or on first trials for markers of the opposite kind, the translator connector 5800 is employed and accordingly the final translator 6000, instead of the final translator 5900. The final translator 5900 consists of a plurality of multi-contact relays 5901, 5902, 5903, etc., and a plurality of relays 5905, 5906, 5907, etc. Relays 5901 and 5902 75 are operated after the translator has been seized in accordance with the setting of the translator 5400, or in accordance with the hundreds digit of the wanted line. The relays 5905, 5906 and 5907 are operated in accordance with the setting of the tens register 5302 in the incoming marker. With the translator 5900 positioned, a circuit is completed through the units register 5303, 80 thence through the connector 5700 and the translator 5900 to operate the particular vertical magnet 1107, 1108 or 1109 on one of the connector switches which controls the row of contacts including the called line. Thus a group of five lines containing the 85 called line has been selected by the final translator. As will be seen hereinafter, the device 6300 which constitutes a part of the final translator 5900 determines the particular one of the five lines wanted.

90 The incoming marker is also associated with the incoming selector switch 800 by means of the incoming frame connectors 6100 and 6101. Furthermore, the testing equipment in the incoming marker is associated with the trunks leading from the incoming selector to the final switches through the final trunk connectors 6200 and 6201.

95 Both the outgoing and incoming markers are equipped with alarm and trouble indicator circuits which are common to all markers of a kind and may be associated with any particular marker for detecting and recording a case of trouble. The outgoing markers are equipped with the trouble indicator shown in Figs. 41 and 42 which is arranged to be connected to any marker by means of connecting device 4000. This indicator consists of a number of relays and lamps which record and indicate the condition of a marker together with other parts of the system after a source of trouble has been encountered. As soon as a marker is seized a time measuring device 4301 is set 100 in operation which, if the marker does not 105

progress normally and release in the regular manner, will count an interval of time and then cause the association of the indicator with the marker.

5 For certain classes of trouble in the marker, a series of relays 3901 are employed which cause the sounding of an alarm 3903 and the association of the indicator with the marker immediately without waiting for 10 any time interval.

For still other types of trouble in the markers, a series of relays 3900 are provided. Any one of these relays when actuated starts a time measure mechanism 4300 15 in operation, which causes the sounding of an alarm 3902 but does not summon the trouble indicator.

In a similar manner, the incoming markers are provided with a trouble indicator shown in Figs. 67 and 68 together with 20 the controlling relays 6400 and 6401 and time measure devices 6500 and 6501.

Detailed description of the operation.

25 *Establishment of a local connection.*—Assume that the subscriber of line 100 desires to hold conversation with the subscriber of line 1100 located in the same office. Consider that the code or office designation of 30 the local office is represented by the abbreviation T. O. K., which in terms of dial impulses is represented by three digits 8, 6 and 5. Assume further that the numerical designation of the line 1100 is 2, 3, 4, 5.

35 *Operation of the line switch.*—The calling subscriber on removing his receiver from the switchhook, closes an obvious circuit for the line relay 103. Relay 103 closes a circuit at its outer right contact for the operation of the relay 111. Relay 111 closes a circuit for relay 112 traceable from battery, through the winding of the latter relay, middle contact of relay 104, to ground at the outer contact of relay 111. Relay 111 40 also causes the operation of the horizontal group relay 105 which relates to the group of horizontal links containing the links 205 and 206. This circuit may be traced from battery, through the left contact of relay 113, left contact of relay 109, left contact of relay 107, outer contact of relay 104, left winding of relay 105, inner right contact of relay 111, to ground at the left contact of relay 114. Relay 105 locks in a circuit from 45 battery, through the left contact of relay 115, winding of relay 107, contact of relay 116, and other intervening horizontal group relays provided none of these relays is energized, through the inner right contact and right winding of relay 105, to ground as above traced. Relay 107 also operates in this circuit and closes an obvious circuit for relay 108. Relay 107 at its left contact 50 opens the operating circuit for other horizontal group relays 116, etc.

The vertical group relay 213 is now energized in a circuit from battery, through the left back contact of relay 110, upper winding of relay 213, conductor 222, inner contact of relay 105, middle contact of relay 108, conductor 118, to ground at the inner contact of relay 108. Relay 213 locks in a circuit from battery, through the winding of relay 110, lower contact and winding of relay 213, thence to ground as above traced over conductor 222. Relay 110 in operating opens the operating circuit for all other vertical group relays to prevent another one from operating at this time. Relay 110 at its right contact closes an obvious circuit for relay 115. Relay 115 at its left contact opens the original holding circuit for relays 107 and 105 but these relays are now held in a substitute circuit provided to the left front contact of relay 110. 55

The vertical magnet 209 is now operated to rotate vertical bar 218 to prepare the contacts in the vertical row 201. The circuit for this magnet may be traced from battery, through the winding thereof, upper contacts of relay 213, conductor 223, to ground at the middle right contact of relay 115. Next a trunk vertical magnet is operated depending upon the first one of the outgoing trunks which is idle at this time. The circuit for this purpose may be traced from ground, over conductor 223, upper contacts of relay 213, conductor 224, thence through the lower front contact of relay 225 assuming the trunk 220 to be busy, lower back contact of relay 214 assuming the trunk 219 to be idle, winding of the vertical magnet 212, to battery. The magnet 212 rotates the bar 226 to prepare the contacts of the vertical row 204. 100

105 When the magnet 209 operates, it closes a circuit as follows for operating the relay 109: battery, through the winding of said relay, to ground through the lower contact of magnet 209. Similarly, the magnet 212 closes a circuit for relay 113 traceable from battery, through the winding of said relay, to ground at the lower contact of magnet 212. A horizontal magnet is now operated to complete the connection from the calling line through an idle horizontal link to the selected outgoing trunk 219. This circuit may be traced from ground, through the right contact of relay 113, right front contact of relay 109, conductor 120, outer right contact of relay 105, conductor 121, inner back contact of relay 215 provided the link 206 is idle, left winding of the horizontal magnet 216, to battery. The magnet 216 rotates the horizontal bar 217 and operates the prepared contacts in the vertical rows 201 and 204. The magnet 216 closes a circuit for the left hand winding of relay 215 but this relay being shunted by ground potential on the conductor 121 does not operate at this time. 115 120 125 130

The relay 104 is also energized in a circuit from ground, over conductor 120 as above explained, through the outer right contact of relay 105, left back contact of relay 106, left winding of relay 104, to battery. Relay 104 operates and opens the circuit for relay 112. Relay 112, however, remains energized provided some other horizontal group contains a calling line at this time. 10 Relay 112 by remaining energized, completes a locking circuit through the right winding of relay 104. This prevents relay 104 from releasing to permit the corresponding horizontal group to make another call until such 15 other horizontal groups as contain calling lines have succeeded in completing their calls through the line switch.

The operation of the line switch is timed by an interrupter 122. As soon following 20 the operation of relays 110 and 115 as the interrupter 122 closes its contact, a circuit is closed from battery, through the contact of the interrupter, back contact of relay 123, winding of relay 124, inner left contact of 25 relay 115, to ground at the contact of relay 110. Relay 124 operates and completes a circuit from battery, through its contact, windings of relays 123 and 124, to ground as above traced. When the interrupter 30 opens, the relay 123 operates in series with relay 124. As soon as the interrupter again closes, certain operations are carried out whereby the line switch and the vertical magnets are released. In the meantime, 35 however, the sender selector switch 1300 is operating, a description of which operation will now be given.

At the time the vertical magnet 212 operates, a circuit is completed from ground, 40 through its inner contact, conductor 227, outer left contact of relay 1204, conductor 228, right contact of relay 301, inner upper back contact of relay 302, conductor 303, middle winding of the relay 1200, to battery. Relay 1200, which is individual to the 45 trunk 219, operates and starts the operation of the sender selector switch 1300. Relay 1200 completes a circuit from ground, through its outer left contact, conductor 1205, winding of relay 304, to battery. Relay 1200 is locked in a circuit from battery, 50 through its outer left winding and inner left contact, conductor 1206, normal upper contact of relay 305, to ground over conductor 1205 as traced. Relay 304 extends the tip and ring conductors of the calling subscriber's line through to the sender selector circuit. The holding relay 302 is also operated in a circuit from battery, through 55 its winding, conductor 306, right normal contact of relay 307, conductor 308, to ground through the inner lower front contact of relay 304. Relay 302 opens the operating circuit of relay 1200 and locks itself 60 in a circuit from battery, through its wind- 65

ing and inner upper front contact, right contact of relay 301, to ground at the inner lower contact of relay 302. Relay 302 supplies the holding ground for the line switch, horizontal magnet, and for operating the 70 line cut-off relay 102. The holding circuit of the magnet 216 may be traced from battery, through both windings of said magnet, thence through contacts of the switch 200, holding conductor 229, left back contact of 75 relay 301, conductor 309, to ground at the inner lower contact of relay 302. The circuit for cut-off relay 102 may be traced from battery, through its winding, thence through contacts of the switch 200, to the grounded 80 conductor 229.

Relay 102 opens the circuit of the line relay 103, which thereupon releases and causes the release of the start relay 111. Relay 103 also opens the holding circuit of 85 relays 213 and 110. Relay 111 causes the release of relays 105 and 107 and the latter causes the release of relay 108. Relay 110 in releasing opens the circuit of relay 115. Relay 115 at its middle right contact opens 90 the holding circuit of the vertical magnet 209, which in turn causes the release of the vertical bar 218 and also opens the circuit of relay 109. The circuit of the vertical magnet 212 is also opened and this magnet 95 restores the vertical bar 266 and also opens the circuit of relay 113. With ground removed from conductor 121, the shunt around the left winding of relay 215 is opened and this relay operates to extend the 100 start circuit 121 through to the next horizontal link.

If for any reason the line switch does not proceed in its regular operation, the interrupter 122 will close its contact a second 105 time and a circuit is completed from battery, through the contact of said interrupter, front contact of relay 123, winding of relay 125, to ground. Relay 125 operates the relay 106 in a circuit from battery, 110 through the right winding of the latter relay, right contact of relay 125, through contacts of relay 105, to the grounded conductor 118. Relay 106 operates and locks to the outer right contact of relay 111. Relay 106 115 operates the relay 104 to indicate that the horizontal group of links is busy. Relay 106 also closes an operating circuit for relay 114 traceable from battery, through the right winding of the latter relay, right contact of relay 106, and thence to ground as above traced. Relay 114 opens the holding circuit of the group relay 105, which releases and brings about a release of the remaining control relays of the line switch 120 which have been operated thus far. When the calling subscriber hangs up his receiver, the line relay 103 releases, causing in turn the deenergization of relays 111, 106 and 104. 125 130

Returning to the sender selector switch 1300, the relay 1200 in operating operates the start relay 1317 in a circuit from battery, through the winding of the latter relay, conductor 1325, right contacts of relay 1200, to ground at the back contact of relay 1202. Relay 1317 operates the relay 1208. The circuit for this purpose may be traced from battery, through the left winding of relay 1208, lower back contact of relay 1316, to ground at the contact of relay 1317. Relay 1317 also completes a circuit as follows for operating the vertical group magnet 1315: battery, through the left contact of relay 1209, outer left contact of relay 1210, right contact of relay 1211, upper back contact of relay 1316, upper winding of relay 1315, upper contact of relay 1317, conductor 1326, to ground at the left contact of relay 1212. Relay 1315 operates and locks in a circuit from battery, through the right contact of relay 1213, winding of relay 1211, lower contact and left winding of relay 1315, and thence to ground as above traced. Relay 1211 operates in this circuit and opens the original energizing circuit of relay 1315 whereby no other vertical group relay can be operated at this time. Relay 1211 at its left contact closes obvious circuits for relays 1214 and 1215. Relay 1214 operates immediately but relay 1215 being slow to energize requires a brief interval to attract its armatures. Relay 1211 closes a circuit for relay 1316 traceable from battery, through the upper winding of the latter relay, contact 1315, conductor 1216, to ground at the left contact of relay 1211. Relay 1316 locks through its lower winding, to ground at the right contact of relay 1208. Relay 1211 also closes a locking circuit for relay 1208. Relay 1211 further causes the operation of relay 1318. The circuit for this relay may be traced from battery, through its winding, inner upper contact of relay 1316, lowermost contact of relay 1315, conductor 1216, to ground at the contact of relay 1211.

The vertical magnet 1310 controlling the contacts in the vertical row 1301 is operated as soon as relay 1214 becomes energized. The circuit may be traced from battery, through the winding of said magnet, upper contact of relay 1315, inner right contact of relay 1214, to ground through the winding of relay 1217. Magnet 1310 rotates the bar 1314 to prepare the contacts. Relay 1217 is also operated in the circuit traced. As soon as relay 1215 operates, a circuit is closed for operating the first vertical magnet 1312, 1313 relating to an idle sender. This circuit may be traced from ground, through the winding of relay 1218, right contact of relay 1215, lower middle contact of relay 1315, conductor 1327, upper back contact of relay 1321, to the winding of the

magnet 1313. The magnet 1313 rotates the vertical rod 1328 to prepare the contacts in the row 1304. Relay 1218 also operates in the above traced circuit. Magnets 1310 and 1313 lock temporarily to ground at the inner contact of relay 1215. The magnet 1313 causes the operation of relay 1319 in a circuit from battery, through the winding of said relay, lower contact of magnet 1313, conductor 1329, to ground at the outer right contact of relay 1214.

At the time the magnet 1310 operates, relay 1219 is energized in a circuit from battery, through the left winding of said relay, thence through the right non-inductive winding thereof, to ground at the contact of magnet 1310. Subsequently, when relays 1217 and 1218 are operated, battery potential is connected to the non-inductive winding of relay 1219 in shunt of the inductive winding thereof. These windings are so proportioned, however, that the relay does not release at this time. When relay 1219 operates, it closes an obvious circuit for the slow release relay 1210. Relay 1210 closes an operating circuit for relay 1220 as follows: ground, through the left winding of relay 1220, outer right contact of relay 1210, conductor 1221, lower front contact of relay 1319, conductor 1330, through the winding of relay 1400, to battery. Relay 1400 operates in this circuit and locks in a circuit from battery, through its winding and left contact, conductor 1401, to ground at the left normal contact of relay 1402. Ground on conductor 1401 is also extended to conductor 1330 and thence to conductor 1221, whereby relay 1220 will lock through its right winding. Furthermore, relay 1209 is operated in a circuit from battery, through its winding, contacts of relay 1220, to the grounded conductor 1221.

The horizontal group relay 1201, relating to the horizontal group containing the links 1305 and 1306, is now operated in a circuit from battery, through the right contact of relay 1222, outer contact of relay 1202, right winding of relay 1201, conductor 1223, inner contact of relay 1318, conductor 1332, right contact of relay 1200, to ground at the inner contact of relay 1202. Relay 1201 operates and locks in a circuit from battery, through the winding of relay 1222, left back contact of horizontal group relay 1224, and other intervening group relays providing the same are not operating, front contact and left winding of relay 1201, and thence to ground over conductor 1223. Relay 1222 is also operated in this circuit to prevent the operation of other horizontal group relays. Relay 1222 operates the relay 1213 in a circuit from battery, through the winding of the latter relay, contact of relay 1222, to ground at the left contact of relay 1208. Relay 1203 is now operated in a circuit from battery, 130

through its winding, contacts of relay 1201 and 1222, to ground at the contact of relay 1208. It will be noted that the relay 1213 at its outer contact opens the holding circuit 5 of relay 1211 and relay 1315. A new holding circuit was previously closed, however, at the right front contact of relay 1222 to prevent the release of said relays.

A circuit is now completed for operating 10 a horizontal magnet, such as the magnet 1322. This circuit may be traced from ground, through the right contact of relay 1209, winding of relay 1226, inner right contact of relay 1210, contact of magnet 1310, conductor 1333, through the contact of relay 1203, conductor 1227, left back contact of relay 1324, left winding of the magnet 1322. Magnet 1322 rotates the horizontal bar 1323 and the connection through the 15 sender selector is completed. Magnet 1322 also closes a circuit from ground, through its left hand contact, left winding of relay 1324, to battery. Due to the presence of ground potential on conductor 1227, however, the relay 1324 does not operate until 20 such ground potential is removed. The relay 1226 operates in the above traced circuit of the horizontal magnet and in so doing connects battery potential to the mid-point 25 between the windings of relay 1219. With relays 1217, 1218 and 1226 or all three of them operated, the current flow through the left winding of relay 1219 is sufficiently reduced to permit said relay to release. Relay 30 1219 opens the circuit of relay 1210, which releases after an interval. Relay 1210 opens the original circuit of relays 1220 and 1209 but these relays remain operated temporarily 35 in circuits traceable from battery, through 40 their windings, thence through the right contacts of relay 1220, conductor 1228, to ground at the inner lower contact of relay 1319. Relay 1210 opens the original energizing circuit of the horizontal magnet 45 whereby the relay 1324 operates in a circuit above traced and extends the start circuit through to the next horizontal link.

As soon as the connection is extended through the sender selector switch 1300, the 50 grounded conductor 1330 is extended through the horizontal link 1306 to the conductor 1334, winding of the relay 305, to battery. Relay 305 operates and releases the relay 1200. The relay 305 opens the former holding 55 circuit of relay 304 and closes a new circuit therefor from battery, through the winding of the latter relay, conductor 1205, front contact of relay 305, to the grounded conductor 1334. Thus the relay 304 is placed 60 under the control of the sender.

The connection through the sender selector switch is also placed under the control of the sender by means of the following holding circuit of the horizontal magnet 1322: battery, through both windings of said magnet, 65

thence through contacts of the switch, to the grounded holding conductor 1330.

When relay 1200 releases, it releases the start relay 1317, which in turn causes the release of the group relay 1315 and relay 1211. 70 Relay 1211 causes the release of relays 1215, 1214 and 1208. The remaining energized relays of the sender selector also release in an obvious manner.

Upon the release of the vertical magnet 75 1313, relay 1319 deenergizes. Relay 1320 is now operated in a circuit from battery, through its upper winding, lower back contact of relay 1319, conductor 1330, to ground as above traced. Relay 1320 also closes an 80 operating circuit for relay 1321 whereby the start wire is extended to the next sender.

During the time that relay 1319 is operated, the relay 1500 in the sender is energized by means of a circuit from battery, 85 through the upper contact of relay 1319, conductor 1335, left back contact of relay 1501, middle right contact of relay 1400, winding of relay 1500, to ground. Relay 1500 operates the relay 1603 in a circuit from battery, 90 through the winding of the latter relay, conductor 1606, outer right front contact of relay 1500, conductor 1403, to ground at the outer right contact of relay 1400. Relay 1603 closes an obvious circuit for relay 1605, 95 which in turn operates relay 1604. Relay 1605 also closes an obvious circuit for relay 1502. Relay 1502 causes the operation of relay 1404 in a circuit from battery, through the right winding of the latter relay, left 100 contact of relay 1502, to the grounded conductor 1403.

After the sender selector switch has been fully operated and relay 1319 deenergizes, 105 relay 1500 releases. The subscriber's line is now included in an impulse circuit with the impulse relay 1601. This circuit may be traced from battery, through the right winding of relay 1601, outer left contact of relay 1604, conductor 1607, outer left back contact of relay 1800, outer right back contact of relay 1801, conductor 1802, right back contact of relay 1503, thence over conductor 1504, through the sender selector switch 1300, conductor 1336, lower contact of relay 304, 115 thence through the line switch 200 and over the ring conductor on the calling line, returning over the tip conductor through the line switch, upper contact of relay 304, conductor 1337, through the sender selector switch 1300, conductor 1505, inner right back contact of relay 1506, conductor 1507, outer left back contact of relay 1801, inner right back contact of relay 1800, to ground. 120

Recording the called number in the sender.—A circuit is now closed from dial tone source 1609 traceable through the left winding of relay 1601, conductor 1610, outer left contact of relay 2001, conductor 2002, outer right back contact of relay 1611, normal con- 125

acts of relay 1612, outer right contact of relay 1604, conductor 1613, outer right back contact of relay 1500, to the grounded conductor 1403. Current flowing through the 5 left winding of relay 1609 induces a current through the right winding of said relay which flows over the calling subscriber's line and produces a characteristic sound in the calling subscriber's receiver.

10 On hearing the dial tone, the subscriber manipulates his dial first to send three series of impulses representing the office designation, and then four series of impulses representing the line designation.

15 When relay 1500 releases as above described, it opens the circuit of relay 1603. Relay 1603, however, remains energized in a circuit from battery, through its winding, front contact of relay 1601, conductor 1608, 20 to ground at the contact of relay 1405.

25 The first manipulation of the subscriber's dial causes the interruption of the line to send a series of eight impulses. On the first opening of the line, relay 1601 releases and causes the momentary release of relay 1603. Relay 1605 being slow does not release during the momentary release of relay 1603. Relay 1603 operates the relay 1612 in a circuit from battery, through the winding 30 of the latter relay, outer left contact of relay 1603, outer right contact of relay 1604, conductor 1613, outer right back contact of relay 1500, to the grounded conductor 1403. The relay 2003 is operated for associating the 35 counting relays 1600 with the first office register 2100. The circuit for this purpose may be traced from battery, through the winding of relay 2003, inner left contact of relay 2001, conductor 2005, inner left contact 40 of relay 1604, to the grounded conductor 1613. Upon the operation of relay 1612, a circuit is closed for relay 1611 as follows: battery, right winding of relay 1614, winding of relay 1611, through the back contact 45 of relay 1614, left front contact of relay 1612, outer right contact of relay 1604, to the grounded conductor 1613. Relay 1611, however, does not operate since it is shunted by a circuit from battery, through the inner 50 right contact of relay 1611, conductor 1615, outer right contact of relay 2003, conductor 2006, to ground at the inner right back contact of counting relay 1623.

55 Upon the first release of relay 1601, a circuit is completed for operating the counting relay 1616 traceable from ground, over conductor 1608, back contact of relay 1601, inner left contact of relay 1604, inner right contact of relay 1500, conductor 1618, inner 60 right back contact of relay 1629, thence through the left back contacts of relays 1627, 1625, 1623 and 1617 in series, winding of relay 1616, to battery. Relay 1616 operates and closes a circuit from battery, through 65 its winding and the winding of relay 1617,

contact of relay 1616, outer right contact of relay 1623, right contact of relay 1612, conductor 1630, contact of relay 1604, to the grounded conductor 1613. At the end of the first interruption, the impulse relay operates 70 and, removing the shunt around relay 1617, permits this relay to operate in series with relay 1616. Relay 1603 also reoperates momentarily and opens the circuit of relay 1612. The latter relay being slow, however, 75 does not release due to momentary openings of its circuit. Upon the second interruption, the impulse circuit is extended over the left front contact of relay 1617, through the winding of relay 1619, to battery. Relay 80 85 89 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910

When relay 1623 operated the first time, it removed the above traced shunt around the winding of relay 1611. Relay 1611 there-

upon operates and a holding circuit is closed from battery, through the right winding of relay 1614, winding of relay 1611, left winding of relay 1614, left contact of relay 1611, to the grounded conductor 2005. Relay 1614 does not operate at this time since its left winding is shunted by a direct path through the back contact of relay 1614 and left contact of relay 1612 to the grounded conductor 1630. After an interval has elapsed following the impulse series, the slow relay 1612 releases and removing the shunt permits relay 1614 to operate in series with relay 1611. Before relay 1612 releases, however, the digit is recorded on the office register 2100. The register relay 2103 is operated in a circuit from battery, through its left winding, contact of relay 2003, conductor 2007, to ground at the right contact of relay 1625. Relay 2104 is operated in a circuit from battery, through its left winding, contact of relay 2003, conductor 2008, to ground at the right front contact of relay 1623. Also relay 2106 is operated in a circuit from battery, through its left winding, contact of relay 2003, conductor 2009, left front contact of relay 1633, left back contact of relay 1629, to ground. As soon as the slow relay 1612 releases, a temporary locking circuit is completed for the register relays. The relays 2103, 2104 and 2106 lock in circuits through their right windings and contacts, thence over conductor 2107, outer left back contact of relay 2010, conductor 2011, outer right front contact of relay 1611, normal contacts of relay 1612, to the grounded conductor 1630. Relay 1612 in releasing also operates the relay 2001 in a circuit from battery, through the winding of the latter relay, outer left contact of relay 2010, conductor 2011, outer right front contact of relay 1611, back contacts of relay 1612, to the grounded conductor 1630. Relay 2001 operates the connecting relay 2012 in a circuit from battery, through the winding of the latter relay, right back contact of relay 2010, to ground at the contact of relay 2001. Relay 2001 releases relay 2003, dissociating the counting relays from the first register 2100. Relay 2012 associates the common relays 1600 with the second office register 2101. The operated relays of the register 2100 are now locked in a circuit from battery, through their right windings and contacts, conductor 2107, thence through the inner inner left front contact of relay 2001, to the grounded conductor 2005. Relay 2001 also locks in this circuit which is seen to be independent of the relay 1612. Relay 1612 in releasing opens the circuit of the energized counting relays, permitting these relays to release in readiness for the next digit.

For the second digit 6 representing the letter O, the subscriber transmits a series of

six impulses, causing the operation of the counting relay 1600 in the manner already described. At the end of the sixth impulse, relays 1616, 1617, 1628, 1629 and 1632 are operated. At the first interruption in the second series of impulses, relay 1612 operates and a circuit is closed from battery, through the right winding and right front contact of relay 1614, front contacts of relay 1612, to the grounded conductor 1630. This circuit shunts the relay 1611, which thereupon releases. At the end of the second series of impulses, and before relay 1612 has had time to release, the register relays 2108 and 2111 are operated. The circuit for relay 2108 may be traced from battery, through the left winding thereof, contact of relay 2012, conductor 2007, to ground at the right contact of relay 1617. The circuit for relay 2111 leads through the left winding of said relay, contact of relay 2012, conductor 2009, back contact of relay 1633, to ground at the left front contact of relay 1629. As soon as relay 1612 releases at the end of the interval, the relays 2108 and 2111 are temporarily locked in circuits through their right windings and contacts, thence over conductor 2112, outer left back contact of relay 2013, outer left front contact of relay 2001, conductor 2002, outer right back contact of relay 1611, normal contacts of relay 1612, to the grounded conductor 1600. Relay 1612 operates the relay 2010 in a circuit from battery, through the winding of the latter relay, outer left back contact of relay 2013, outer left front contact of relay 2001, conductor 2002, outer right back contact of relay 1611, normal contacts of relay 1612, to the grounded conductor 1630. Relay 2010 releases the relay 2012 and locks itself to the contact of relay 2001. The register relays 2108 and 2111 are now locked in a circuit traceable over conductor 2112, right front contact of relay 2010, to ground at the contact of relay 2001. Relay 1612 in releasing also opens the holding circuit of the energized counting relays, whereby these relays become deenergized.

For the third digit 5, a series of five impulses are transmitted, at the end of which the counting relays 1628 and 1629 alone are operated. At the time relay 1612 released on the preceding series, the circuit of relay 1614 is opened and this relay becomes deenergized. Furthermore, the connecting relay 2014 is energized in a circuit from battery, through its winding, inner left back contact of relay 2013, to ground at the inner left contact of relay 2010. Upon the energization of the slow relay 1612 at the beginning of the third series of impulses, relay 1611 is operated in the manner above described. At the end of the third series of impulses, and before relay 1612 releases, relay 2116 is energized in a circuit from battery, through

its left winding, contact of relay 2014, conductor 2009, left back contact of relay 1633, to ground at the left front contact of relay 1629. Relay 2116 locks temporarily in a circuit from battery, through its right winding and contact, conductor 2015, left back contact of relay 2301, outer left front contact of relay 2010, conductor 2011, outer right front contact of relay 1611, normal contacts of relay 1612, as soon as relay 1612 has released, to the grounded conductor 1630. The relay 2013 also operates in the circuit above traced upon the release of relay 1612, releases the relay 2014, and locks to the inner left contact of relay 2010. Relay 2116 is now locked in a circuit traceable through the inner left front contact of relay 2013, to ground at the contact of relay 2010. As soon as relay 1612 releases, the relay 1614 operates as above described. Relay 2013 operates the relay 2302 in a circuit traceable through the inner right back contact of relay 2301.

Next the subscriber transmits a series of two impulses representing the first digit in the numerical portion of the designation. At the end of this series, relays 1619 and 1623 are energized. Relay 1612 in operating at the beginning of the series releases relay 1611 as explained. After this series has been received by the counting relays, the register relay 2406 is energized in a circuit from battery, through its left winding, contact of relay 2302, conductor 2008, to ground at the right front contact of relay 1623. Relay 2406 temporarily locks through its right winding and contact, left back contact of relay 2303, outer left front contact of relay 2013, outer left front contact of relay 2001, conductor 2002, back contact of relay 1611, normal contacts of relay 1612, as soon as this relay has released, to the grounded conductor 1630. Relay 1612 in releasing releases relay 1614 and operates the relay 2301 in the following circuit: battery, through the winding of relay 2301, left back contact of relay 2303, thence over the above traced circuit to the grounded conductor 1630. Relay 2301 releases relay 2302 and operates the relay 2304. The register relay 2406 is locked in a circuit when the counting relays 1619 and 1623 are released.

In a similar manner, it will be clear from inspection of the circuits that the remaining three digits, 3, 4 and 5, are recorded on the registers 2401, 2402 and 2403, causing the operation of relays 2410, 2411, 2416 and 2421.

Connection of the sender to an idle outgoing marker and transfer of the office record to the marker.—As soon as the first three digits have been recorded, the sender is attached to an idle marker through a sender connector found in Figs. 25 and 26,

and the office record stored on the registers 2100, 2101 and 2102 is transferred to corresponding registers 2900, 2901 and 2902 of the marker. After the third series of impulses have been registered, relay 2013 operates and a circuit is closed for relay 1407 traceable from battery, through the winding of the latter relay, normal contacts of relay 1408, normal contacts of relay 1409, conductor 1410, to ground at the inner right contact of relay 2013. Relay 1407 causes the operation of relay 2506, which is individual to the sender at the sender connector 2500. The circuit may be traced from battery, through resistance 1411, inner right back contacts of relays 1414 and 1415, left front contact of relay 1407, conductor 1416, upper winding of relay 2506, to ground at the back contact of relay 2507. Relay 2506 operates and locks in a circuit from ground, through the winding of relay 2507, back contacts of other relays similar to relay 2506, provided the same are deenergized, front contact and lower winding of relay 2506, and thence to battery as traced over the conductor 1416. Relay 2507 operates in this circuit and operates the multi-contact relay 2501. The circuit for the latter relay may be traced from battery, through its winding, upper contact of relay 2506, to ground at the front contact of relay 2507. A circuit is now completed for selecting the first idle marker to which the sender has access. Assuming that the marker shown in the drawing is idle, the corresponding make-busy relay 2508 will be inert. Accordingly a circuit may be traced from battery, through the lower contact of relay 2506, contact of relay 2511, right contact of relay 2508, thence through the contact of relay 2501, normal contact of key 2512, outer left contact of relay 2508, left winding of relay 2509, to ground at the contact of relay 2510. Relay 2509 operates and locks in a circuit from ground, through the winding of relay 2510, inner right front contact and right winding of relay 2509, lower contact of relay 2506, to battery. Relay 2510 operates in this circuit and immediately operates the make-busy relay 2508 to identify the marker as busy. The circuit for relay 2508 may be traced from battery, through its right winding, conductor 2513, to ground at the inner right contact of relay 2510. Ground potential on the conductor 2513 also operates the make-busy relay 2605 at the section 2600 and corresponding relays at other sections to identify the marker as busy to all senders which have access thereto. The multi-contact relay 2504 is now operated in a circuit from battery, through its winding, outer right contact of relay 2509, to ground at the contact of relay 2510. A circuit is also closed for relay 2511 trace-

able from battery, through its winding, outer left contact of relay 2509, to ground at the contact of relay 2510. Relay 2511 prevents the operation of another relay 5 similar to relay 2509, whereas relay 2507 prevents another sender from operating its relay corresponding to relay 2506.

For a more detailed description of the manner in which the sender connector functions, reference is made to Patent No. 10 1,600,399, issued September 21, 1926 to W. W. Carpenter.

With the multi-contact relays 2501 and 2504 operated, a sender is connected to the 15 selected idle outgoing marker.

The office record is now transferred from the sender to the marker.

As soon as the sender is connected to the marker, the ground supply relay 3504 in the 20 marker is operated in a circuit traceable from ground, through the winding of said relay, conductor 3505, through contacts of the connector 2500, and thence over conductor 1416 to battery in the sender as previously traced. Relay 3504 causes the operation of multi-contact relay 3611 in a circuit from battery, through the winding of the latter relay, thence over conductor 2815, inner back contact of relay 2514, to ground 25 at the contact of relay 3504. In order to test the contacts of the sender connector 2500, all of the relays of the registers 2900, 2901 and 2902 are operated. Some of these relays will be operated over front contacts 30 and some of them over back contacts of the corresponding relays of the sender. Since relays 2103, 2104 and 2106 are operated, the corresponding relays 2903, 2904 and 2906 are operated. The circuits for these relays 35 may be traced from battery, through their windings, thence over conductors 2917, through front contacts of relays 2103, 2104 and 2106, to ground. Since relays 2108 and 2111 are operated, corresponding relays 2908 40 and 2911 are energized in circuits from battery, through their windings, thence over conductor 2918, through the connector 2500, to ground at the front contacts of relays 2108 and 2111. Similarly since the relay 50 2116 is operated, corresponding relay 2916 in the marker is energized in a circuit traceable to ground at the front contact of relay 2116. Moreover, the remaining relays 2905, 2909, 2910, 2913, 2914 and 2915 of the marker 55 are temporarily operated in circuits which may be traced from battery, through their windings, thence through sender connector 2500, and thence through the back contacts of the corresponding relays 2105, 2109, 2110, 2113, 2114 and 2115 respectively, to the common conductor 2118, through the sender connector, conductor 2919, to ground at the back contact of relay 3307. Thus all of the 60 marker register relays are operated and a series circuit is completed from ground,

through the lower contact of relay 2906, and thence through back contacts of each of the remaining register relays, to the conductor 2920, winding of relay 3308, to battery. Relay 3308 operates and locks in a circuit from 70 battery, through its winding and right front contacts, back contact of relay 3309, conductor 3310, to ground at the middle right contact of relay 3504. Relay 3308 locks temporarily in a circuit from battery, through its winding and right contact, back contact of relay 3309, to the grounded conductor 3310. Relay 3307 operates in a circuit from 75 battery, through its left winding, contacts of relay 3308, back contact of relay 3309, to the grounded conductor 3310. Relay 3307 at its left contact removes ground from conductor 2919, whereby all operated relays of a group of marker registers corresponding to non-operated relays of the sender registers are released. Relay 3307 locks through its right winding and contact to the grounded conductor 3310. Relay 3307 closes a circuit from battery, through the winding of relay 3309, contacts of relay 3307, to 80 the grounded conductor 3310. Relay 3309 releases the relay 3308.

Operation of the outgoing marker translator.—A translator 3300 is now operated under the control of registers 2900 and 2902 85 and thereafter cooperates with the register 2901 to select a proper one of the code relays 3400, 3401, etc. Since all but the relay 2905 of the register 2900 are operated, the multi-contact relay 3303 of the translator 100 3300 is energized in a circuit from battery, through its winding, conductor 3311, uppermost front contact of relay 2904, upper contact of relay 2906, upper front contact of relay 2903, conductor 2922, left contact of relay 3308, front contact of relay 3309, to the grounded conductor 3310. Since only the relay 2916 of register 2902 is operated, a circuit is completed for energizing the translator relay 3312. This circuit may be traced from battery, through the winding of said latter relay, conductor 3313, upper middle back contact of relay 2914, upper back contact of relay 2915, upper middle contact of relay 2916, uppermost back contact of relay 2913, conductor 2923, windings of relays 3506 and 3507, contact of relay 3508, conductor 3509, to ground at the contact of relay 3504. The relays 3506 and 3507, together with numerous other relays of a similar character occurring throughout the marker, serve in connection with the trouble indicator and alarm circuits, and their purpose will be described more fully 115 in a subsequent part of the specification. With the relays 3303 and 3312 operated, a circuit is closed for the code relay 3500 which may be traced from battery, through the winding of said relay, thence through the distributing frame 3503, conductor 3510, 120 130

contact of relay 3303, contact of relay 3312, conductor 3314, upper back contact of relay 2909, upper contact of relay 2911, upper front contact of relay 2908, to the grounded conductor 2922.

The operated code relay 3500 has a plurality of functions. One of these is to operate a proper one of the class relays 3400, 3401, etc.; another is to operate the proper one of the district group relays 3000, 3001 which represents a group of trunks outgoing from the district selector switch to the incoming selector 800; and still another function is to cause the operation of relays 3511 and 3512 which relate to district selection. The class relay 3400, for instance, is operated in a circuit from battery, through its winding, thence through the contact of relay 3500, to ground. The relays 3511 and 3512 are operated in a circuit from battery through the windings of these relays, thence through the outer right contact of relay 3500, conductor 3511, inner left back contact of relay 3514, to ground at the contact of relay 3504. The trunk group relay 3000 is not operated until after the district frame connector 3600 has functioned.

Before proceeding with the further operation of the outgoing marker, an explanation 30 will be given of the manner in which the class information is re-transferred from the marker back to the sender to enable the sender to adjust itself to control the associated apparatus in accordance with the particular class of call involved.

Transfer of class record from the marker to the sender.—Since a local call is being extended, it will be necessary to transfer information to the sender notifying the class 40 of connection concerned. This is accomplished by the class relay 3400 in the marker. First, a circuit will be traced from ground, through the windings of relays 3403 and 3404, thence through the distributing frame 45 3405, contacts of relay 3400, conductor 3406, through the connector 2500, conductor 2515, winding the sender class relay 1701, to battery. Also the relay 2305 is operated from the marker to indicate to the sender that no 50 stations digit is to be sent by the subscriber. The circuit for this relay may be traced from ground, through windings of relays 3407 and 3408, distributing frame 3405, contact of relay 3400, conductor 3409, through the connector 2500, conductor 2516, winding of the relay 2305, to battery.

Operation of the district frame connector and connection of the outgoing marker to the district selector.—Following the connection 60 of the sender to the marker, a test is made by the relays 2700 to determine the group of district switches and the particular district switch in the group to which the calling line has been extended. Immediately 65 by that the connector 2500 operates, a cir-

cuit is closed for relay 2701 traceable from battery, through the winding of said relay, thence through contacts of the device 2500, to ground. Assume that all trunks leading to the district selector switch 400 are characterized by a battery connected through a resistance connected to the outer left back contact of the relay 310 in the trunk. A test is first made by means of the following circuit: 70 battery, through the windings of relays 2708 and 2707, back contact of relay 2704, back contact of relay 2702, conductor 2709, through the sender connector 2500, conductor 2517, outer right back contact of relay 1402, conductor 1417, through the sender 80 selector 1305, conductor 1338, outer left back contact of relay 307, outer left back contact of relay 310, through the connecting block 300, resistance 311, to battery. Since battery is connected at both ends of this circuit, the 85 relays 2707 and 2708 fail to operate. It may be noted that the test circuit just described is closed immediately that the sender is attached to the marker and while the record is being transferred to the marker for the 90 purpose of sighting the translator 2300.

As soon as the translator 3300 is operated, a circuit is closed as follows for the relay 95 2704: battery, through the winding of said relay, back contact of relay 2703, left contact of relay 2701, conductor 2711, to ground at the contact of relay 3312. The relay 2704 shifts the test circuit and the same may now be traced over conductor 2709, back contact of relay 2702, front contact of relay 2704, 100 through the windings of relays 2705 and 2706, to ground. This time the relay 2706 cooperates but relay 2705 being marginal does not energize in series with the resistance 105 311. A circuit is now closed for selecting one of a number of relays, one of which 3002 is shown, each identifying a particular district selector switch. The circuit for relay 3002 may be traced from ground, through the back contact of marginal relay 2705, contact of relay 2706, thence over conductor 2712, 110 through the winding of relay 3002, to battery. Relay 3002 determines the selection and operation of the frame connector 3600 having access to the group of district selectors 400 and also determines the operation of the frame connector in such a manner as to connect the marker to the particular district frame 400 shown to which the calling line 115 has been extended. For this purpose, the circuit is closed from battery, through the windings of relays 3003 and 3004, thence over the outer right contact of relay 3002, 120 normal contact of key 3005, back contact of relay 3006, conductor 3007, left winding of relay 3602, winding of relay 3603, to ground at the back contact of relay 3611. Relay 3602 operates and locks in a circuit traceable 125 through its right winding and contact, over the back contacts of similar relays pro- 130

vided none of these is energized, to ground through the winding of relay 3611. Relay 3611 operates in this circuit and opens the original circuit to prevent the operation of another relay similar to relay 3602. The multi-contact relay 3604 is now operated in a circuit from battery, through its winding, left contact of relay 3602, to ground at the front contact of relay 3611. Since the relay 3605 is individual to the district selector frame 400 and since relay 3002 is similarly representative of said frame, the latter relay may serve to cause the operation of the relay 3605. The circuit for this purpose may be traced from ground, through the contact of relay 3504, conductor 3515, winding of relay 3009, left contact of relay 3002, conductor 3010, through contacts of relay 3604, conductor 3612, contact of relay 3613 belonging to the alternate frame connector 3609, winding of relay 3605, to battery. Relay 3605 operates and the marker is now connected to the district frame 400. The reason for leading the operating circuit of relay 3605 through a contact of relay 3613 is to prevent the operation of one frame connector while the other frame connector is in an operated condition. The relay 3002 locks to the inner right contact of relay 3009. Relay 3009 operates the relay 2702 to disassociate the frame test relays from the conductor 2709. This circuit may be traced from battery, through the winding of relay 2702, right contact of relay 2701, conductor 2710, to ground at the inner right contact of relay 3009. Thus the relay 2706 becomes deenergized.

The relay 413 at the district selector switch which relates to the vertical row of contacts 401 is now operated in a circuit from ground, through its winding, conductor 420, inner left back contact of relay 310, middle left back contact of relay 307, conductor 312, through the sender selector 1300, conductor 1339, through connector 2500, conductor 2924, back contact of relay 3011, left contact of relay 3009, left front contact of relay 3611, windings of relays 2801 and 2802, outer back contacts of relays 2803, 2804 and 2805, to battery. Relay 413 locks in a circuit from ground, through its winding and inner lower contact, conductor 418, through the frame connector 3600, conductor 3615, contact of relay 3516, to battery.

55 The trunk group relay 3000 is now operated in a circuit from ground, through the outer right contact of relay 3504, inner left back contact of relay 3514, conductor 3511, middle left contact of relay 3500, winding of relay 3000, thence over conductor 3012, through contacts of the frame connector 3600, resistance 3616, to battery. The circuits of the district trunk group relays 3000, etc., are led through the district frame connectors in order to determine the particular

district frame through which the connection is to be extended. This enables a large trunk group to be divided between two or more sets of district frames where one frame will not accommodate all of the trunks. One of the functions of the district trunk group relay 3000 is to select and operate the trunk connector 3700 having access to the group of trunks outgoing from the district selector 400 over which the connector is to be extended. 75

Operation of the trunk connector.—The following circuit is closed by the relay 3000 for operating the relay 3702 which is individual to the particular marker shown at 80 the trunk connector 3700, this trunk connector having access to the proper group of district frames: battery, through the windings of relays 3013 and 3014, outer right contact of relay 3009, conductor 3015, outermost 85 right contact of relay 3611, conductor 3617, inner left contact of relay 3000, conductor 3016, normal contact of key 3103, outermost back contact of relay 3102, left winding of relay 3702, to ground at the back contact of 90 relay 3704. Relay 3702 operates and locks through its right winding and contact, and thence through the back contacts of similar relays, winding of relay 3704, to ground. Relay 3704 operates and opens the operating 95 circuit for other relays similar to relay 3702. The multi-contact relay 3705 is now energized in a circuit from battery, through its winding, outer left contact of relay 3702, winding of relay 3703, to ground at the front 100 contact of relay 3704.

Next the multi-contact relay 3708, individual to the particular group of trunks appearing in the vertical row 403 of the district selector 400, is operated. The circuit 105 for this relay may be traced from battery, through its winding, back contact of relay 3709, conductor 3710, back contact of relay 3102, contact of key 3103, conductor 3104, contacts of relay 3000, conductor 3017, windings of relays 2806 and 2807, conductor 2808, inner left contact of relay 3702, winding of relay 3703, to ground at the front contact of relay 3704. With relays 3705 and 3708 operated, the marker test relays 2800 are associated with the sleeve conductors of the trunks in the group 403 which lead to the incoming selector switches 800. 115

The vertical magnet 409 of the district selector switch is operated in a circuit from battery, through its winding, upper contact of relay 413, conductor 421, through the connector 3600, contact of relay 3611, conductor 3618, conductor 3808, windings of relays 3201 and 3202, conductor 3203, contact of relay 3705, contact of relay 3708, to ground. Magnet 409 rotates the vertical rod 414 to prepare the contacts of the vertical row 401. Also the vertical magnet 411 is energized in a circuit from battery, through its winding, conductor 120 125 130

422, connector 3600, contact of relay 3611, conductor 3619, contact of relay 3000, conductor 3018, windings of relays 3204 and 3205, to ground over conductor 3203. Magnet 411 rotates the vertical bar 423 to prepare the contacts in the vertical row 403.

At the time the relay 3708 operated, relay 2806 was energized in series therewith. Accordingly a circuit is closed for relays 3109 and 3114 traceable from battery, through the windings of said relays, conductor 3112, contact of relay 2806, conductor 3509, to ground as above traced. Since the vertical magnet 411 is also operated, relay 3106 is energized in a circuit from battery, through its winding, inner right front contact of relay 3109, conductor 3113, conductor 3712, contact of relay 3611, connector 3600, conductor 3621, to ground at the lower contact 20 of magnet 411.

Testing the district trunks and horizontal links.—The marker has thus been prepared for testing the trunks of the group appearing in the vertical row 411 of the district selector switch, which trunks lead to incoming selectors, and also for testing the horizontal links of the district switch having access to these trunks. The testing relay set 2800 for performing this test consists of a series of double wound relays 2810, 2811, 2812, 2813, etc., together with a series of single wound relays 2814, 2815, 2816 and 2817. There are 70 of these relays in the series, as explained in connection with Fig. 71, one for each set of contacts in a vertical row in the selector switches. These 70 relays are divided into seven groups of ten each. It may be assumed that relays 2810 and 2811 are two of the relays in the first group of ten which serve to test the first ten trunks and links beginning at the bottom in the district selector switches 400 and also in the office selector switches 600. The left winding of the relay 2810, therefore, serves to test the sleeve conductor of the first trunk counting from the bottom of the switch. The left winding of relay 2811 serves to test the sleeve conductor of the second trunk and similarly eight other relays in the same sub-group of ten serve to test the eight succeeding trunks. The relay 2812, which may be considered the first relay in the second group of ten, serves to test the eleventh trunk from the bottom or the first trunk in the second group trunk. In a similar manner, each of the remaining relays may be employed for testing the respective trunks of the switch. The relays 2814 and 2815 are for testing the corresponding horizontal links in the district selector switches and also in the office selector switches. Relay 2814 is for the purpose of testing the condition of the horizontal link 408 and for the corresponding horizontal links in all other switches. Relay 2815 is for testing the second horizontal link 407.

Considering the selector switch 400, it may be assumed that the links 408 and 407 are two of the links in the first group of ten and that the links 406 and 405 are the first two links in the second group of ten. Accordingly, the test relay 2814 serves to test the link 408 and the relay 2816 serves to test the link 406.

In order that the testing relays 2800 may be assigned to the space in the vertical row 75 of contacts occupied by the selected group of trunks, a space assignment relay 2713 is operated in a circuit from battery, through the winding thereof, conductor 2714, contacts of relay 3000, conductor 3019, contact of relay 80 3106, windings of relays 3107 and 3108, outer right front contact of relay 3109, conductor 3110, conductor 3711, contact of relay 3611, through the connector 3600, conductor 3620, to ground at the lowermost contact of relay 85 409. The space assignment relay 2713 operates the relay 2805 in a circuit from battery, through the winding of the latter relay, contact of relay 2713, windings of relays 2715 and 2716, to ground. The relay 2805 90 determines that the testing operation will commence with the first relay 2810 in the series. If it is assumed that the group is a full group of 70 trunks, then the relay 2713 determines the operation of relay 2828 in a 95 circuit from battery, through the winding of the latter relay, contact of relay 2713, windings of relays 2717 and 2718, to ground. In this case, the test relays 2721 and 2722 may be operated by a circuit connected through 100 the contact of the space assignment relay 2713 to battery as indicated. Also, the relay 2822 is energized in a circuit from battery, through the winding thereof, contact of relay 2713, windings of relays 2719 and 105 2720, to ground.

The test circuit for the first trunk 424 may be traced from battery, through the left winding of relay 2810, outer right back contact of relay 2878, conductor 2831, through 110 the trunk connector 3700, conductor 3714, to the sleeve conductor of the trunk 424. In a similar manner, the test circuit for trunk 425 may be traced through the left winding of the test relay 2811, and the test circuit for 115 the trunk 417 through the left winding of the relay 2812. The test circuit for the horizontal link 408 may be followed from battery, through the winding of relay 2814, inner right back contact of relay 2878, conductor 2823, contact of relay 3611, frame connector 3600, conductor 3622, left winding of the horizontal magnet 427, to the test conductor of the link 408. In a similar manner, the test circuits for the horizontal links 120 407, 406, and 405, etc., may be traced through the windings of relays 2815, 2816, 2817, etc. If the trunk is busy, the corresponding test relay operates through its left winding. If 125 the horizontal link alone is busy, the corre- 130

sponding single wound relay is energized, resulting in the energization of the double wound relay over a circuit as follows, for example: battery, through the right winding 5 of relay 2810, contact of relay 2814, conductor 2832, to ground through the contact of relay 3114. It thus follows that the corresponding one of the double wound test relays is operated whenever the trunk is busy, or 10 the link is busy, or both are busy.

Assume that the first group of ten test relays 2810, 2811 are energized due to the busy condition of their trunks and links in the vertical row 403, and that the trunk 417 15 and its associated link 406 are both idle. Accordingly, the relays 2811 and 2815 may be energized, and as soon as the relay 2805 is operated, as explained, a circuit is completed from ground through the outer contact of relay 2833, inner right contact of relay 2822, windings of relays 2834 and 2835, inner contact of relay 2805, conductor 2836, thence through the left front contacts 20 of relays 2810, 2811, etc., back contact of relay 2825, left back contact of relay 2830, left back contact of the non-operated test relay 2812, winding of relay 2820, to battery. The relay 2834 operates in this circuit and 25 closes a holding circuit for itself through its right contact to the grounded conductor 3509. Relay 2834 also operates the relay 2833 in a circuit from battery, through the right winding of the latter relay, contacts of relay 2834, to the grounded conductor 3509. Relay 2833 locks in a circuit through 30 its left winding and contact, to the grounded conductor 2832.

A test is now made to ascertain whether the horizontal magnet 416 and its circuit 40 are in proper condition. This circuit may be traced from ground, through the right winding of relay 2837, right back contact of relay 2838, inner right front contact of relay 2820, conductor 2840, contact of relay 3611, connector 3600, conductor 3623, through the right winding of magnet 416, to battery. Relay 2837 operates but the magnet 416 does not energize due to the resistance of said relay. Relay 2837 locks 45 in a circuit from battery, through its left winding and left contacts, conductor 2832, to ground at the contact of relay 3114. Another circuit is completed at this time to test the condition of the trunk 417. This 50 trunk normally should have battery connected thereto. The test circuit may be traced from ground, through the right winding of relay 2839, left back contact of relay 2838, outer right front contact of relay 2820, conductor 2841, connector 3700, conductor 3715, thence to the sleeve conductor 430 of 55 trunk 417, through the resistance 500, to battery. Relay 2839 operates and locks through its left winding and contacts, 60 through left contacts of relay 2837, to the

grounded conductor 2832. With relays 2837 and 2839 operated, a circuit is closed as follows for relay 2838: battery, through the winding of the latter relay, thence through left contacts of relays 2839 and 2837, to the 65 grounded conductor 2832.

It having been determined that the horizontal magnet 416 and the trunk 417 are in proper condition, an operating circuit for said magnet is now established to cause the extension of the connection to the district frame 400. This circuit leads from the grounded conductor 3515, contacts of relays 2721, 2719, 2715 and 2717 in series, these relays having operated at the time the space assignment relay 2713 has energized, conductor 2723, inner right contact of relay 3020, conductor 3021, windings of relays 3206 and 3207, inner back contact of relay 3208, conductor 3209, right front contact of relay 2838, inner right front contact of relay 2820, conductor 2840, and thence as traced through the right low resistance winding of the horizontal magnet 416, to battery. The magnet 416 operates in this circuit, rotates the bar 428, and effects connection through the link 406 to the selected trunk 417. As soon as the connection is established through the switch 400, relay 3210 is energized in a circuit from battery, through the winding of said relay, 80 left back contact of relay 3211, conductor 3212, left front contact of relay 2838, outer right front contact of relay 2820, conductor 2841, thence as previously traced through the trunk connector 3700, conductor 3715, 85 through contacts of the switch 400, left high resistance winding of magnet 416, to ground over conductor 3623, as previously traced. Relay 3210 operates and locks in a circuit from battery, through its winding and contact, conductor 3213, to ground over conductor 2832. Relay 3210 closes an obvious circuit for relay 3211. Relay 3211 closes the following circuit: ground, through the windings of relays 3215 and 3214, right contact of relay 3211, conductor 3217, left back contact of relay 3517, conductor 3518, left contact of relay 3020, thence through the frame connector 3600, conductor 3624, inner upper front contact of relay 413, sleeve conductor 115 432 over trunk 219, through contacts of the switch 400, resistance 500, to battery. It will be noted that the relays 3214 and 3215 are shunted by another circuit traceable from battery, through resistance 500, through the switch 400, and thence through the left-hand high resistance winding of magnet 416, to ground as previously explained. Due to the high resistance of the left-hand winding of magnet 416, however, sufficient current flows 120 through the winding of relay 3214 to operate the same. The relay 3215, however, being marginal does not energize. Relay 3214 operates the relay 3519 in a circuit from battery, through the winding of the latter re- 125 130

lay, inner left contact of relay 3511, conductor 3520, contact of relay 3214, left contact of relay 3216, to the grounded conductor 2832. Relay 3519 closes a circuit from battery, through its winding and inner right contact, winding of relay 3521, to the grounded conductor 3310. Relay 3521, however, being shunted does not operate at this time. Relay 3519 in operating closes a circuit as follows from the battery connected to the sleeve conductor 430 of the trunk 417 directly to ground through the resistance 500 in shunt of the circuit previously traced for the operation of relay 3214: battery, through the resistance 500, conductor 430, conductor 3715, trunk connector 3700, conductor 2841, outer right front contact of relay 2820, left front contact of relay 2838, conductor 3212, left front contact of relay 3211, conductor 3218, outer left contact of relay 3519, to the grounded conductor 3310. Relay 3214 thereupon releases and removes the short circuit around the winding of relay 3521 whereby this latter relay operates in series with relay 3519. The apparatus is now in condition to perform a test to ascertain the continuity of the connection extended through the district selector switch 400 to the incoming selector switch 800.

Continuity test of the connection through the district switch to the incoming switch.— The continuity of the talking circuit extended through the district selector switch 400 is tested by means of a polarized relay 3022 located in the marker. The marker makes this test before it releases, and unless the talking connection is complete through the district selector switch, the marker will not be able to release and hence a talking connection will not be established.

Returning to the point where relay 2837 operates, a circuit is closed at this time for relay 3011 traceable from battery, through the winding of relay 3011, conductor 3023, outer left contact of relay 3511, conductor 3522, outer contact of relay 2837, to the grounded conductor 2832. The relay 310 is also energized at the time relay 3519 operates in a circuit traceable from battery, through the winding of relay 310, conductor 316, middle contact of magnet 409, conductor 429, through the frame connector 3600, contact of relay 3611, conductor 3625, outer right contact of relay 3519, to the grounded conductor 3310. As soon, therefore, as connection is extended through the district selector, a test circuit is closed as follows: battery, through the right winding of relay 700 in the trunk 417, left back contact of relay 701, upper left winding of repeating coil 702, upper back contact of relay 703, tip conductor of the trunk 417, through the contacts of the district selector switch 400, conductor 313, inner left front contact of relay 310, middle left back contact of relay 307, conductor 312, thence through the sender selector switch 1300, conductor 1339, through the sender connector 2500, conductor 2924, front contact of relay 3011, winding of the polarized relay 3022, contact of relay 3024, conductor 3025, front contact of relay 2702, conductor 2709, thence through the sender connector 2500, conductor 2517, outer right back contact of relay 1402, conductor 1417, through the sender selector 1300, conductor 1338, outer left back contact of relay 307, outer left front contact of relay 310, conductor 315, ring conductor of the trunk 219, through the district selector 400 over the ring conductor of the trunk 417, inner upper back contact of relay 703, lower left winding of repeating coil 702, right back contact of relay 701, to ground through the left winding of relay 700.

If the test circuit above traced is completed at every contact, current will flow through the winding of the polarized relay 3022 in the proper direction to cause its operation. Relay 3022 closes an obvious circuit for relay 3026. Relay 3026 locks in a circuit from battery, through its winding and right contact, to the grounded conductor 3310. Relay 3026 in turn closes an obvious circuit for relay 3024, this latter relay serving to open the circuit of the polarized relay 3022.

The marker is now ready for release and is about to notify the sender that this operation should proceed. Before the release circuit can be closed, however, it will be necessary that the class test relay shown in Fig. 34 shall have functioned properly. The relays 3407 and 3408, for instance, are included in the circuit with the skip stations relay 2305 in the sender, and if this latter relay operated properly then the relay 3407 will be energized. Again, the relays 3403 and 3404 are included in the circuit for operating the class relay 1701 in the sender, as previously related, and if this class indication has been sent correctly the relays 3403 and 3404 will also energize. Thus for each indication transmitted from the marker to the sender, a separate check is made upon relays similar to those shown in Fig. 34, as many of these relays being provided as is necessary for the particular class of call concerned. In the present instance, it was assumed that the relays 3407, 3403 and 3404 are operated. The release circuit may now be traced from the grounded conductor 3310, outer contact of relay 3521, conductor 3523, contact of relay 3208, conductor 3219, left contact of relay 3026, left contact of relay 3028, left contact of relay 3029, conductor 3030, contact of relay 3007, left contact of relay 3400, conductor 3410, contact of relay 3403, conductor 3411, thence parallel through the winding of relay 3516 and over conductor 2581, through the sender connec-

tor 2500, conductor 2519, winding of the marker release relay 1408, to the sender. Relay 3516 in operating removes battery potential from conductor 3615 and opens 5 the above traced holding circuit for relay 413. Relay 413 opens the circuit of the vertical magnet 409 which restores the vertical rod 414 to normal. Before the magnet 409 releases, however, to open the orginial 10 circuit for relay 310, this relay is locked in a circuit from battery, through its winding and right contact, conductor 317, inner upper contact of relay 304, conductor 318, conductor 433, inner upper back contact of 15 relay 413, conductor 434, to ground at the contact of the holding relay 305.

Release of the outgoing marker.—The outgoing marker has completed its functions in controlling the district selector switch 20 and may now be disconnected both from the sender and from the district selector. This disconnection is initiated by the operation of relay 1408. Relay 1408 in operating opens the circuit of relay 1407, and this latter relay 25 releases. Relay 1407 opens the circuit hereinbefore traced for relays 2506 and 2507. These relays release, causing in turn the release of relays 2501, 2510, 2509, 2508, 2504 and 2511. The release of the multi-contact 30 relays 2501 and 2504 serves to disconnect the sender from the outgoing marker. Before the sender is disconnected, however, the class relay 1701 is locked in a circuit from battery, through its winding and inner 35 right contact, conductor 1702, to ground at the outer left contact of relay 1408. Also the relay 2305 is locked in a circuit from battery, through its right winding and inner contact, outer contact of relay 2306, conductor 2307, conductor 1901, thence over conductor 1702, to ground to the outer left contact of relay 1408. Relay 1408 locks in a 40 circuit from battery, through its winding and middle left contact, to ground over conductor 1410. The disconnection of the marker from the sender results in the release of the operated register relays in the marker together with the translator 3300 and the code and group relays which have been 45 energized due to the setting of the translator. Moreover, the main ground control relay 3504 of the marker is released to remove ground potential from the various holding conductors, causing the release of 50 all energized relays in the marker depending upon these grounded conductors. The release of relay 3009 releases relay 3602, whereupon the multi-contact relays 3604 and 3605 of the district frame connector 3600 55 are released and the marker is disassociated from the district frame 400, resulting in the release of the vertical operating magnet 411. Also the relay 3702 is released to cause the deenergization of the multi-contact 60 relays 3705 and 3708, thereby disconnecting 65

the marker test relays from the sleeve conductors of the selected group of trunks outgoing from the district switch 400.

With the vertical magnets of the district selector deenergized, the connection there-through is now maintained by the continued energization of the horizontal magnet 416, which is locked in a circuit from battery, through both its windings, contact of the switch 400, sleeve conductor 432, conductor 433, and thence as above traced to the above 70 grounded holding conductor 434.

Preparation of the subscriber's sender for the transmission of the numerical record to the incoming sender.—While the foregoing operations of the marker are taking place, the sender is receiving the numerical portion of the record and the timing and controlling sequence switch 1900 is advancing 80 from position to position. Immediately that the sender is seized and the relay 1400 operates, the relay 1803 is energized in a circuit from battery, through the left winding thereof, conductor 1806, left contacts of the sequence switch spring 1902, conductor 1904, 85 left back contact of relay 1804, conductor 1807, upper right contact of sequence switch spring 1905 (1+17), lower left contact of spring 1905 (1), conductor 1906, to ground at the inner right contact of relay 1400. 90 Relay 1803 operates and locks through its right winding and contact, left contacts of sequence switch spring 1903 (1), conductor 1907, to ground at the outer right contact of relay 1803. Relay 1803 closes a circuit 95 as follows for advancing the sequence switch 1900 out of position 1 and into position 2: ground, through the outer right contact of relay 1803, conductor 1907, upper left contact of spring 1903 (1), winding of the sequence switch magnet 1900, to battery. As the sequence switch 1900 moves out of position 100 1, it opens the operating and holding circuits of relay 1803, and this latter relay 105 releases.

If, at the time the sequence switch 1900 reaches position 2, the first digit has been dialed by the subscriber, said sequence switch is immediately advanced into position 6. If the digit has been dialed, relay 1805 110 energizes in a circuit from battery, through its winding, left back contact of relay 1810, outer back contact of relay 1813, conductor 1816, lower left contact of spring 1916 (2+5), conductor 1917, to ground at the 115 outer right contact of relay 2001. Relay 1805 extends the grounded conductor 1816 through its inner left contact, conductor 1915, winding of sequence switch 1900, to battery. Sequence switch 1900 moves 120 through positions 3, 4 and 5 and into position 6, in which position the relay 1805 is released. From positions 6 to 18 the sequence switch counts time to allow the subscriber to dial the remaining digits. In 125 130

position 6, relay 1804 is operated in a circuit from battery, through its left winding, conductor 1808, right contacts of spring 1902 (6), conductor 1908, left back contact of relay 1803, conductor 1807, upper right contact of spring 1905 (1+17), upper left contact of said spring (2+18), conductor 1909, right contact of relay 1809, outer right contact of relay 1810, conductor 1811, right contact of spring 1910 (6+8), to the spring contact of the interrupter 1911. The interrupter 1911 is driven by power and closes its contact at definite time intervals. As soon thereafter as the interrupter 1911 closes its contact, the circuit traced is completed and relay 1804 operates. This relay locks through its right winding and contact, right contacts of spring 1903, to ground at the outer right contact of said relay. Relay 1804 also closes a circuit from ground, through its outer right contact, upper right contact of spring 1903 (6), winding of sequence switch 1900, to battery. Sequence switch 1900 moves out of position 6 and into position 7, releasing relay 1804. Next the relay 1803 is energized in the manner explained and sequence switch 1900 moves into position 8. In this position relay 1804 is again energized, driving the sequence switch into position 9. In position 9 relay 1803 is energized, driving the sequence switch into position 10. In position 10 relay 1804 operates in a circuit from battery, through its left winding, conductor 1808, right contacts of spring 1902, conductor 1908, left back contact of relay 1803, conductor 1807, contacts of spring 1905, conductor 1909, and thence as traced to conductor 1811, through the left contact of spring 1910 (10+14), to the spring contact of interrupter 1918. The interrupter 1918 may be driven at a faster rate than the interrupter 1911, and as soon thereafter as it closes its contact, relay 1804 energizes and drives the sequence switch 1900 into position 11. In this position relay 1803 operates and moves the sequence switch into position 12, out of which position it is driven by relay 1804 and interrupter 1918 into position 13. In this manner the sequence switch advances into position 14 and then into position 15, where it is driven by the interrupter 1911 and the relays 1803 and 1804 into position 18.

If the units digit has been dialed by this time, the relay 2309 is operated and the following circuit is completed for relays 1812 and 1810: battery, through the winding of said relays, right back contact of relay 1813, conductor 1814, lower left contact of spring 1912 (17 $\frac{3}{4}$ +18), lower left contact of spring 1913 (17+18), conductor 1914, to ground at the outer left contact of relay 2309. Relays 1812 and 1810 lock in a circuit leading through the inner right front contact of relay 1810 to the grounded conductor 1906. The relay 1805 is again operated in a circuit from battery, through its winding, left front contact of relay 1810, conductor 1815, lower left contact of spring 1912 (17 $\frac{3}{4}$ +18), conductor 1814, inner right front contact of relay 1810, to the grounded conductor 1906. Relay 1805 extends the grounded conductor through its inner left contact, over conductor 1915, through the winding of sequence switch 1900, to battery. Sequence switch 1900 moves out of position 18 and into position 1. Sequence switch 1900 in moving out of position 18, releases the relay 1805.

The sequence switch 1900 is driven out of position 1 and into position 2 by the relay 1803 as above described. Since no stations digit is required and the relay 2305 has energized, sequence switch 1900 is immediately advanced out of position 2. Relay 1805 is now operated in a circuit from battery, through its winding, left front contact of relay 1810, conductor 1815, lower right contact of spring 1913 (2+5), conductor 2309, conductor 2308, outer contact of relay 2305, to the grounded conductor 1914. Relay 1805 extends the grounded conductor through its inner left contact, conductor 1915, the winding of sequence switch 1900, to battery. Sequence switch 1900 thereupon moves directly into position 6. In position 6 the relay 1805 is energized in a circuit traceable over conductor 1815, lower right contact of spring 1912 (6+9), left back contact of relay 1817, contact of spring 1920 (6+9), conductor 1921, to ground at the outer left contact of relay 1503. The relay 1805 closes a circuit for driving the sequence switch 1900 through position 9 and into position 10.

After dialing has been completed, and the relay 1408 is operated by the marker, and the control sequence switch 1900 has reached position 10 as explained, a circuit is closed for the start relay 1508 traceable from battery, through the winding of said relay, conductor 1509, upper right contact of spring 2201 of the impulse sending sequence switch 2200 closed in positions 20 to 2, conductor 2202, middle left contact of the class relay 1701, conductor 1703, conductor 1704, right contact of relay 1408, conductor 1418, lower left contact of spring 1922 (10+15), conductor 1923, to ground at the outer right contact of relay 1812. The relay 1508 bridges the test relay 1510 across the tip and ring conductors of the circuit extending to the incoming selector switch 800.

Operation of the incoming sender selector to seize an idle incoming sender.—With the connection thus extended to the incoming selector switch and the sender prepared, a circuit is closed including the test relay 1510 and the relay 700. This circuit may be traced from battery, through the right wind-

ing of relay 700, left back contact of relay 701, upper left winding of repeating coil 702, upper back contact of relay 703, thence over the tip of the trunk 417, through the 5 district selector switch 400, conductor 313, inner left front contact of relay 310, middle left back contact of relay 307, conductor 312, thence through the sender selector switch 1300, conductor 1339, inner left contact of 10 relay 1508, outer left back contact of relay 1511, winding of relay 1510, outer right back contact of relay 1511, through the compensating resistance 1512, outer left contact of relay 1508, conductor 1513, conductor 1417, 15 through the sender selector 1300, conductor 1338, outer left back contact of relay 307, outer left front contact of relay 310, conductor 315, through the district selector switch 400, thence over the ring conductor 20 of the trunk 417, inner upper back contact of relay 703, lower left winding of coil 702, right back contact of relay 701, left winding of relay 700, to ground. The relay 700 operates and causes the operation of relay 25 4400. The relay 4400 is individual to the trunk 417 and serves to initiate the operation of the incoming sender selector switch 4500.

Relay 4400 operates the relay 4515 in a 30 circuit from battery, through the winding of the latter relay, conductor 4520, through contacts of relay 4400, to ground at the back contact of relay 4402. Relay 4515 closes an operating circuit for relay 4521 traceable from battery, through the left winding of 35 the latter relay, lower contact of relay 4514, to ground at the contact of relay 4515. The vertical group relay 4513 is also operated in a circuit from ground, through the contact of relay 4404, upper contact of relay 40 4515, upper winding of relay 4513, upper contact of relay 4514, back contacts of relays 4405 and 4406, to battery at the left contact of relay 4407. Relay 4513 locks in a circuit from battery, through the outer contact of 45 slow-operating relay 4408, winding of relay 4405, through the lower contact and winding of relay 4503, and thence to ground as above traced. The relay 4405 also operates in this circuit and closes a locking circuit for relay 50 4521 and an operating circuit for relays 4409 and 4410. The relay 4514 is now operated in a circuit from battery, through its upper winding, lower contact of relay 4513, conductor 4522, to ground at the contact of relay 55 4405. Relay 4514 locks through its lower winding and contact, to ground at the middle right contact of relay 4521. The relay 4516 is also energized in a circuit from battery, through its winding, inner upper contact of relay 4514, lower contact of relay 60 4513, to the grounded conductor 4522. The vertical magnet 4509 is now operated in a circuit from battery, through its winding, upper contact of relay 4513, conductor 4523, inner right contact of relay 4409, to ground

through the winding of relay 4411. Relay 4411 operates in this circuit. The vertical magnet 4509 rotates the vertical rod and prepares the contacts in the row 4505. Magnet 4509 also operates the relay 4412 in a circuit from battery, through the left-hand winding of the latter relay, thence through the right-hand winding of said relay, to ground at the lower contact of magnet 4509. It will be noted that the relay 4411 applies 75 a shunt connection through the right winding of relay 4412. The current flowing through this winding, however, is not sufficient to shunt the left-hand winding to an extent necessary to cause the release of relay 80 4412. Relay 4412 closes an obvious circuit for the slow-release relay 4406.

A vertical magnet 4511, 4512 relating to the first idle sender is now operated. The circuit for this purpose will be traced from 85 ground, through the winding of relay 4413, right contact of relay 4410, middle lower front contact of relay 4513, thence through the upper back contact of relay 4519, assuming the sender illustrated to be idle, winding 90 of the magnet 4512, to battery. Magnet 4512 operates and locks through its winding and contact to ground at the inner left contact of relay 4410. Magnet 4512 prepares the contacts of the vertical row 4504 and 95 closes an obvious circuit for relay 4517. The relay 4413 operates in series with magnet 4512. Relays 4411 and 4413 both apply battery potential in shunt of the left winding of relay 4412. This shunt, however, is 100 still not sufficient to release the latter relay. The relay 4517 causes the operation of relay 4414 and holding relay 4605 in the sender. The circuit for these relays may be traced from ground, through the left winding of relay 4414, conductor 4415, lower front contact of relay 4517, conductor 4524, winding of relay 4605, to battery. Relay 4605 locks to ground at the left contact of slow relay 105 4606. Relay 4605 through its left front contact applies ground potential to the holding conductor 4524 leading back to the sender selector switch. Relay 4414 locks in a circuit from battery, through its right winding and contact, outer right contact of relay 4406, to the grounded conductor 4415. Relay 4407 also operates in a circuit from battery, through its winding, to the contacts of the relay 4414.

The relay 4517 also completes a circuit for 120 relay 4607 traceable from battery, through the winding of the latter relay, to ground through the upper contacts of relay 4517. The relay 4607 serves to connect leads from the frame test relays 4608 and 4609 through 125 to the sender selector switch. The relays 4608 and 4609 serve to determine the group of incoming frames containing the particular incoming frame to which leads the trunk over which the connection has been ex- 130

tended. If there are two groups of incoming frames, the relay 4608 will identify one of these groups and the relay 4609 will identify the other. These relays may be 5 operated from the horizontal group relays 4401, 4416, etc. To this end all trunks such as the trunk 417 incoming to a particular group of incoming frames will appear in certain horizontal groups in the sender 10 selector switch 4500, whereas all trunks incoming to another group of incoming frames will appear in a different group or groups of horizontal links in the sender selector switch 4500. The manner in which 15 the relays 4608 and 4609 are energized will be explained presently.

The horizontal group relay 4401 may be energized at this time in a circuit from battery, through the inner back contact of relay 20 4417, right winding of relay 4401, conductor 4418, inner contact of relay 4516, contacts of relay 4400, to ground at the contact of relay 4402. Relay 4401 locks in a circuit through its left winding and contact, thence 25 through back contacts of other horizontal relays 4416, etc., through the winding of relay 4417, to battery. Relay 4417 operates and opens the original energizing circuit for the horizontal group relays. Relay 4417 30 closes a substitute holding circuit for relay 4405 and relay 4513. Relays 4403 and 4408 are now energized in circuits traceable from battery, through the winding of relay 4403, contacts of relay 4401, and from battery, 35 through the winding of relay 4408, thence through the outer contact of relay 4417, to ground at the contact of relay 4521. Another circuit for holding these relays may be traced through the inner contact of relay 40 4408 to the grounded contact of relay 4410.

The frame test relay 4609 in the sender is now energized in a circuit from battery, through its left winding, outer contact of relay 4607, conductor 4610, contacts of relay 4401, contact of relay 4417, to ground at the contact of relay 4521. Relay 4609 locks through its right winding and contact, conductor 4611, to ground at the contact of relay 4605.

50 With relay 4403 energized, a start circuit for operating the first idle horizontal magnet is closed and may be traced from ground, through the right contact of relay 4407, winding of relay 4419, inner right contact of relay 4406, middle lower contact of relay 4509, conductor 4525, contact of relay 4403, left back contact of relay 4526, assuming the first link 4506 to be idle, left winding of the horizontal magnet 4527, to battery. Magnet 4521 rotates the horizontal bar and establishes connection through to the sender selector. The magnet 4527 closes a circuit from ground, through its left contact, left winding of relay 4526, resistance 55 60 65 4528, to battery. The relay 4526 being

shunted by the circuit from battery, through the resistance 4528, the left contacts of relay 4526, and thence to ground over the operating circuit, does not operate until this short-circuiting ground is removed. The relay 70 4419 operates in the above circuit and applies another circuit for battery potential to the windings of relay 4412. The relay 4412 is now shunted and releases its armatures, opening the circuit of the release relay 4406. 75 Relay 4406 opens the circuit of relay 4414 and relay 4407.

As soon as the sender selector 4500 is operated, a circuit is closed for operating the relay 703 traceable from battery, through 80 the lower winding of said relay, thence through the sender selector, conductor 4524, to ground in the sender as explained. Relay 703 opens the circuit of relay 4400. Relay 4400 in operating releases the relay 4417, 85 which in turn releases the relay 4405. Relay 4405 causes the release of the various energized relays associated with the sender selector 4500. The magnets 4509 and 4502 are also released and the connection is now 90 held by the continued energization of the magnet 4527 in a circuit traceable from battery, through both windings of said relay, contacts of the switch 4500, to the grounded conductor 4524. With the shunt removed 95 from the winding of relay 4526, this relay operates in the circuit above traced. The relay 4518 operates in a circuit from battery, through its upper winding, back contact of relay 4517, to the grounded conductor 4524. 100 Relay 4518 closes an obvious circuit for relay 4519 which extends the start circuit on to the next vertical magnet such as 4511 relating to the next sender.

The relay 703 in the trunk 417 at its upper 105 contacts opens the circuit of relay 700 and connects the tip and ring conductors of the trunk to conductors 705 and 706 leading to the incoming sender. Relay 703 also closes a circuit for the holding relay 707 as follows: battery, through the winding of relay 707, left contacts of relay 708, conductor 709, to ground at the lower front contact of relay 703. Relay 707 locks through the outer left contact of relay 708 to ground at 110 the outer left contact of relay 707.

Transfer of the numerical record from the subscriber's sender to the incoming sender.—At the time relay 1510 operated in the above 115 traced test circuit, it closed an obvious energizing circuit for relay 1514. Relay 1514 operates the relay 1515 in a circuit from battery, through the winding of the latter relay, front contact of relay 1514, to ground at the outer right front contact of relay 1508. Relay 1515 locks in a circuit from battery, through its winding and inner left contact, to ground at the contact of relay 1508. 125

The opening of the test circuit including relay 1510 by the operation of the relay 703 130

permits relay 1510 to release, serving as a signal to the sender that the incoming sender is now ready to receive code impulses representing the numerical designation of the wanted line. Relay 1510 releases relay 1514 and a circuit is closed as follows for relay 1511: battery, through the winding of relay 1511, front contact of relay 1515, back contact of relay 1514, to ground at the contact of relay 1508. The relay 1511 disconnects the tip and ring conductors leading to the incoming sender from the relay 1510 and connects them to the pulsing circuit controlled by the impulse sequence switch 2200. Relay 1511 closes an obvious circuit for relay 1516.

Relay 1517 has been operated in a circuit from battery, through its winding, conductor 1518, inner left contact of the class relay 1701, conductor 1705, middle left contact of relay 1515, conductor 1519, to the grounded conductor 1906. With relays 1517 and 1516 operated, a circuit is closed for initiating the movement of the impulse sequence switch 2200. This circuit will be followed from battery, through the winding of said sequence switch, lower left contact of spring 2203 (18+16), conductor 2204, inner right contact of relay 1517, inner contact of relay 1516, inner right contact of relay 1508, left back contact of relay 1520, to the grounded conductor 1519.

The switch 2200 makes a complete revolution and in doing so its various contact springs are closed and opened in proper sequential order to apply ground and battery potential in various manners to the tip and ring conductors of the trunk circuit leading to the incoming sender to send code impulses representing the digits recorded on the registers 2400, 2401, 2402 and 2403. These code impulses are transmitted over a full metallic circuit comprising both tip and ring sides of the line in series. Impulses may be either positive or negative in polarity depending upon the pole of battery that is connected to a given side of the line circuit. They may also be weak or strong dependent upon whether a high or a low resistance is included in the circuit.

50 The relay 4600 at the distant end of the impulse circuit is polarized in such a way as to respond only when current of positive polarity flows over the ring side of the line. The relay 4601 is polarized in such a manner 55 as to respond to current of the opposite polarity. Both relays 4600 and 4601 respond either to strong or weak impulses provided the polarity is in the proper direction. Relay 4602 responds to strong impulses only 60 of either positive or negative polarity. This relay being marginal does not operate on weak impulses.

The impulse code representing any given digit is made up of four impulse periods 65 following each other in succession and de-

termined by the cuttings on the sequence switch cams or springs. Hence for four digits, the thousands, hundreds, tens and units, a series of sixteen impulse periods is necessary. During these impulse periods 70 either positive or negative impulses may be sent or no impulse at all. The positive impulses for the digits are always weak and occur in the first and third periods, whereas the negative impulses may be either weak or 75 strong and always occur in the second and fourth periods. The connections will now be traced showing how battery and ground are connected to the tip and ring conductors of the line to cause the sending of code impulses representing the digits of the particular number assumed, namely the number 80 2 3 4 5.

The first impulse period is determined by the time required by the sequence switch 85 2200 to pass out of position $1\frac{1}{4}$ following the closure of the impulse circuit. During this interval, ground or positive battery is connected through the outer left front contact of relay 1515, conductor 1521, lower right contact of spring 2205 (20+2), lower left contact of said spring ($20\frac{3}{4}+1\frac{1}{4}$), conductor 2207, outer left front contact of relay 1517, conductor 1522, inner right front contact of relay 1511, resistance 1512, outer left contact of relay 1508, conductor 1513, conductor 1417, and thence as previously traced to the ring side of the line leading through the district selector switch to the incoming selector, thence over the inner upper front contact of relay 703, conductor 706, through the sender selector 4500, conductor 4530, inner right contact of relay 4612, inner right back contact of relay 4613, through the windings of relays 4602, 4601 and 4600, outer right back contacts of relays 4613 and 4612, conductor 4531, through the sender selector 4500, conductor 705, upper front contact of relay 703, and thence to the tip side of the trunk circuit leading back to the subscriber's 100 sender. During this first impulse period, the circuit is completed by connecting battery through a high resistance to the tip side of the line. This circuit may be traced from battery, through the high resistance 1419, 115 inner left contact of relay 1420, conductor 1421, upper right contact of spring 2210 ($20\frac{1}{2}+1\frac{1}{2}$), conductor 2211, conductor 2311, front contact and middle right armature of relay 2406, outer right back contact of 120 relay 2412, conductor 2413, lower right contact of spring 2212 (20+4), conductor 2213, outer left back contact of relay 2310, inner left back contact of relay 2312, conductor 2208, inner left front contact of relay 1517, outer left front contact of relay 1511, inner left contact of relay 1508, conductor 1339, and thence as previously traced to the tip side of the line circuit leading to the incoming sender. Thus during the first period a 130

light positive impulse is transmitted over the ring side of the impulse circuit. As the sequence switch 2200 moves out of position $1\frac{1}{4}$ ground potential is disconnected from the ring conductor, and as the switch moves out of position $1\frac{1}{2}$ battery potential is disconnected from the tip conductor. In position $1\frac{3}{4}$ a second period begins. During this period a light negative impulse is sent by connecting ground to the tip side of the line and battery to the ring side of the line. The ground circuit may be traced over conductor 1521, thence through the right contacts of spring 2205 over conductor 2208 to the tip side of the line. The battery circuit may be traced through the high resistance 2215, upper left contact of spring 2216 ($1\frac{1}{2}+2\frac{1}{2}$), directly to conductor 2207, and thence as traced to the ring side of the line. This second period lasts until the sequence switch 2200 moves out of position $2\frac{1}{4}$, at which time the spring 2205 disconnects ground from the tip of the line. For the digit involved, the next impulse period is a blank, no current being transmitted. Whenever a blank or vacant period follows a negative impulse, ground is connected momentarily during such period to both sides of the line in order to discharge the same. These discharge circuits will now be traced.

First, ground is connected through the upper left contact of spring 2205, lower left contact of said spring ($2\frac{3}{4}+3\frac{1}{4}$), and then over conductor 2207 to the ring side of the line. The circuit leading to the tip side of the line may be traced from ground, through the upper left contact of spring 2205, upper right contact of spring 2217 ($2+2\frac{1}{2}$), conductor 2211, conductor 2311, front contacts and the right armature of the relay 2406, outer right back contact of relay 2412, conductor 2413, contact of spring 2212, conductor 2213, outer left contact of relay 2310, and thence over conductor 2208 to the tip side of the line. It will be noted that this circuit leads through the contacts of the register 2400 in order to determine that for the particular registration no positive impulse is to be transmitted during the third impulse transmitted.

The circuits above traced are for connecting ground to both the tip and ring sides of the line which for discharge purposes last only for a brief duration. The contacts of the sequence switch 2200 are cut in such a manner that they always close a quarter of a position ahead of the position for which they are marked and remain closed for a quarter of a position later than indicated by the marker. Thus the grounded discharge circuit traced to the tip side of the line is closed through the lower left contact of spring 2205 as soon as the switch reaches position $2\frac{1}{2}$, which is a quarter of a position earlier than the marking $2\frac{3}{4}$. Likewise, the

grounded circuit leading to the tip side of the line remains closed until the sequence switch 2200 reaches position $2\frac{3}{4}$ in passing out of the position marked $2\frac{1}{2}$. Thus it will be noted that there is an overlap between these two cuttings of a quarter of a position. This relation will also follow throughout the various positions of the sequence switch wherever it is necessary to discharge the line following a negative impulse. The purpose of discharging the line is to prevent the false operation of the control relays at the other end of the impulse circuit.

Coming now to the last or fourth impulse period for the thousands digit, a weak negative impulse is to be transmitted. As soon as the sequence switch reaches position $2\frac{3}{4}$, ground is connected through the upper right contact of spring 2205 to the tip side of the line over conductor 2208. The ring side of the line has battery connected thereto through the high resistance 2215, contact of spring 2216 ($3\frac{1}{2}+4\frac{1}{2}$), and thence to the conductor 2207 leading to the ring side of the line.

Following the thousands digit, four impulse periods follow for the transmission of the hundreds digit 3. This digit requires a positive impulse in the first period and accordingly ground or positive battery is connected through the lower left contact of spring 2205 ($4\frac{3}{4}+4\frac{1}{4}$), to the ring side of the line. Negative battery is connected through the high resistance 1419, thence over conductor 1421, through the upper right contact of spring 2210 ($4\frac{1}{2}+5\frac{1}{2}$), conductor 2211, and thence as above traced to the tip side of the line. During the next period, a heavy negative impulse is sent over the line and accordingly ground is connected to the upper right contact of spring 2205 ($5\frac{3}{4}+6\frac{1}{2}$), to the tip side of the line. In this case battery is connected through the low resistance 1422, outer left contact of relay 1420, conductor 1423, contact of spring 2218 ($5\frac{1}{2}+6\frac{1}{2}$), conductor 2220, inner left back contact of relay 2414, left front contact of relay 2411, conductor 2430, right contact of spring 2221 ($5+9$), conductor 2222, inner right contact of relay 2310, outer right contact of relay 2312, conductor 2207, to the ring side of the line. Due to the low resistance 1422, the impulse is strong in character. From inspection of the circuits, it will be noted that during the next impulse period no impulse is transmitted over the line.

During the last impulse period for the hundreds digit, a weak negative impulse is transmitted. Ground is connected through the upper right contact of spring 2205 ($7\frac{3}{4}+8\frac{1}{4}$), to the tip side of the line, and battery is connected through the high resistance 2215 and the upper left contact of spring 2216 ($7\frac{1}{2}+8\frac{1}{2}$) to the ring side of the line.

For the tens digit, which is 4, the code consists of no impulse in the first period, a light negative impulse in the second period, a positive impulse in the third, and a light negative impulse in the fourth period. The second period of this digit corresponds to positions $9\frac{3}{4}$ to $10\frac{1}{4}$, and during this period ground is connected through the upper right contact of spring 2205 to the tip side of the line, and battery is connected through the upper left contact of spring 2216 ($9\frac{1}{2}+10\frac{1}{2}$), to the ring side of the line. During the third impulse period, ground is connected through the lower left contact of spring 2205 ($10\frac{3}{4}+11\frac{1}{4}$) to the ring side of the line, and battery through the high resistance 1419 is connected through the lower right contact of spring 2210 ($10\frac{1}{4}+11\frac{1}{2}$) to the tip side of the line. During the last impulse period for the tens digit, ground is connected through the upper right contact of spring 2205 ($11\frac{3}{4}+12\frac{1}{4}$) to the tip side of the line, and battery is connected through the high resistance 2215 and the spring 2216 closed in position $11\frac{1}{2}$ to $12\frac{1}{2}$ to the ring side of the line. For the tens digit, only the register relay 2416 is operated and accordingly no circuit is closed in shunt of the high resistance for applying a strong negative impulse to the line.

The units digit, which is 5, requires that no impulse be sent during the first period, a light negative impulse during the second, no impulse during the third, and a heavy negative impulse during the fourth period. To this end, ground is connected during the second period through the upper right contact of spring 2205 ($13\frac{3}{4}+14\frac{1}{4}$) to the tip side of the line and battery is connected through the high resistance 2215 and the upper contact of spring 2216 ($13\frac{1}{2}+14\frac{1}{2}$) to the ring side of the line. During the last period, ground is connected through the upper right contact of spring 2205 ($15\frac{3}{4}+16\frac{1}{4}$) to the tip side of the line, and battery is connected through the low resistance 1422, conductor 1423, upper contact of spring 2219 ($15\frac{1}{2}+16\frac{1}{2}$), conductor 2223, outer left contact of relay 2421, outer left contact of relay 2419, conductor 2420, lower left contact of spring 2224 ($13+17$), and thence as above traced to the ring side of the line. Thus a heavy negative impulse is transmitted over the line.

At the time the relay 1515 operated, it opened the previously traced circuit for relay 1517. The latter relay, however, is held in a circuit from battery, through its winding, conductor 1518, lower left contact of spring 2225 ($16+10$), conductor 2226, outer right front contact of relay 1517, to the grounded conductor 1519. At the time the impulse sequence switch 2200 leaves position 10, this circuit is opened and relay 1517 releases. It will be recalled that the con-

ductors 2207 and 2208 leading to the line over which the impulses are transmitted extend through front contacts of the relay 1517. When the relay 1517 releases, a substitute path for the impulse circuit is completed. For instance, the conductor 2207 leading to the ring side of the line may now be traced through the lower left contact of spring 2216 ($2+16\frac{1}{2}$), and thence over conductor 1522 to the ring side of the line. The tip conductor 2208 may be traced through the left contact of the spring 2227 ($2+16\frac{1}{2}$), conductor 2228, and thence through the outer left front contact of relay 1511 as hereinbefore traced to the tip side of the line.

Thus the four numerical digits have transferred the code impulses over the impulse circuit to the incoming sender where they are recorded as will be explained presently. From inspection it will be found that any of the various digits may be sent, the codes of impulses determining these digits being selected by the manner in which the sequence switch springs are cut and wired. The following table shows the line conditions during the impulse periods, together with the positions of the pulsing sequence switch for the particular number involved in the connection under consideration. For a more detailed understanding of systems employing this particular method of transferring designations, reference is made to the patent to Lundell and Clark, No. 1,464,084, issued August 7, 1923, and the patent to S. B. Williams, Jr., No. 1,517,331, issued December 2, 1924.

Thousands digit.

Pulse period.	Weak positive.	Weak negative.	No impulse.	Weak negative.
Sequence switch position.....	$1+1\frac{1}{4}$	$1\frac{1}{4}+2\frac{1}{4}$	$2\frac{1}{4}+3\frac{1}{4}$	$3\frac{1}{4}+4\frac{1}{4}$

Hundreds digit.

Pulse period.	Weak positive.	Strong negative.	No impulse.	Weak negative.
Sequence switch position.....	$4\frac{1}{4}+5\frac{1}{4}$	$5\frac{1}{4}+6\frac{1}{4}$	$6\frac{1}{4}+7\frac{1}{4}$	$7\frac{1}{4}+8\frac{1}{4}$

Tens digit.

Pulse period.	No impulse.	Weak negative.	Weak positive.	Weak negative.
Sequence switch position.....	$8\frac{1}{4}+9\frac{1}{4}$	$9\frac{1}{4}+10\frac{1}{4}$	$10\frac{1}{4}+11\frac{1}{4}$	$11\frac{1}{4}+12\frac{1}{4}$

Units digit.

Pulse period.	No impulse.	Weak negative.	No impulse.	Strong negative.
Sequence switch position.....	$12\frac{1}{4}+13\frac{1}{4}$	$13\frac{1}{4}+14\frac{1}{4}$	$14\frac{1}{4}+15\frac{1}{4}$	$15\frac{1}{4}+16\frac{1}{4}$

5 The sender is arranged to send a heavy positive impulse, after all of the numerical digits have been transmitted, to accomplish a switching function at the distant end of the impulse circuit. This impulse is transmitted while the sequence switch is passing through position $17\frac{3}{4}$ to $18\frac{1}{4}$, and the circuit therefor may be traced from battery, through the low resistance 1422, conductor 1424, contacts of spring 2229 ($17\frac{3}{4}+18\frac{1}{4}$), conductor 2230, inner left back contact of relay 1517, thence as above traced to the tip side of the line. Another circuit may be traced from ground, through the upper left contact of spring 2205 ($17\frac{3}{4}+18\frac{1}{4}$), lower right contact of spring 2217 (17+19), conductor 2231, outer left back contact of relay 1517, and thence as above traced to the ring side of the line.

20 *Release of subscriber's sender and sender selector.*—The subscriber's sender having completed its function in transmitting the numerical record to the incoming sender, may now proceed to release. During the period that the impulses are being transmitted, the control sequence switch 1900 continues to advance. At the time the switch 1900 reached position 10, the relay 1804 operated in the manner above explained. 25 The circuit therefor may be traced from battery, through the left winding of said relay, conductor 1808, right contacts of spring 1902 (10), conductor 1908, left back contact of relay 1803, conductor 1807, upper 30 right contact of the spring 1924 (1+14), inner left contact of relay 1812, upper left contact of spring 1925 (10+14), to the interrupter 1911. Relay 1804 drives the sequence switch 1900 into position 11, whereupon relay 1803 drives said sequence switch 35 into position 12. In this manner the switch 1900 advances through positions 13 and 14 and into position 15.

40 As soon as the impulse sequence switch 2200 reaches position $18\frac{3}{4}$, the sender release relay 1402 is operated in a circuit from battery, through its winding, right contact of relay 1501, conductor 1523, middle right back contact of relay 1420, conductor 1425, conductor 1926, contact of spring 2232 (18 $\frac{3}{4}$ +20), conductor 2233, outer right contact of relay 1517, to the grounded conductor 1519. Relay 1402 locks through its inner left contact to the contact of relay 1404. 45 Relay 1402 removes ground from conductor 1401 and conductor 1530, causing the release of relay 1400 and also the release of the sender selector horizontal magnet 1322 and relay 1320. The sender selector switch is thus released to disconnect the sender from the trunk. Relay 1402 at its outer front contact closes a circuit through the lower winding of relay 1321 to maintain this relay operated to render the sender busy to prevent its selection until it has completely re-

50 stored. The impulse relay 1601, relays 1603, 1604, 1605 and 1502 are thus released. Relay 1400 also releases the relay 1404.

55 Relay 1400 opens the holding circuit of relays 1810 and 1812. These relays release. 70 The relay 1805 is now operated in a circuit from battery, through its winding, left back contact of relay 1810, outer left back contact of relay 1813, conductor 1816, upper left contact of spring 1927 (2+18), conductor 1928, 75 outer right back contact of relay 1404, to ground. Relay 1805 extends the grounded conductor through its inner left contact, thence over conductor 1915, to the winding of sequence switch magnet 1900. Sequence 80 switch 1900 is thereupon driven into position 1.

85 It will be noted that the master contact 2234 of the impulse sequence switch 2200 is open in position 5. The sequence switch is moved to its second position in a circuit over the lower left contact of spring 2203, conductor 2404, and thence as previously traced to ground. The impulse sequence switch 2200 is driven out of position 17 in a circuit leading over the lower right contact of spring 2203, conductor 2235, thence through contacts of relay 1516, to ground over conductor 1509. Should the subscriber abandon the call before the impulse sequence switch 2200 95 has reached its normal position, a circuit is closed for driving it to normal in a circuit from battery, over the left contact of spring 2203, thence to ground at the outer right back contact of relay 1400. 100

105 Thus the subscriber's sender has completed its function in controlling the district selector switch through the outgoing marker and in transferring the numerical portion of the record to the incoming sender. 105

110 When the sender selector releases, it causes the release of relays 304 and 305. Relay 304 completes the tip and ring conductors of the calling line through to the left windings of the repeating coil 320. Relay 304 also releases the relay 310. Relay 302 remains locked in a circuit from battery, through its winding and inner upper contact, right contact of relay 301, thence to ground at the inner lower contact of relay 302. The calling supervisory relay 321 is now energized 115 in series with the calling line.

120 *Recording the numerical record in the incoming sender.*—Consulting the table previously given, it will be found that the code 120 representing the first digit 2 consists of a light positive impulse, a light negative impulse, no impulse and a light negative impulse. In response to the first or light positive impulse, relay 4600 operates and closes 125 a circuit from ground, through the outer right contact of relay 4605, conductor 4614, contact of relay 4600, left back contact of relay 4603, conductor 4615, inner back contact of relay 4704, right winding of register relay 130

4705, to battery. Relay 4705 operates and locks through both its windings and left contact, conductor 4706, to ground at the contact of relay 4605.

5 In response to the second or light negative impulse, relay 4601 alone operates and a circuit is closed from the grounded conductor 4614, contact of relay 4601, inner left normal contact of relay 4613, conductor 4616, inner left back contact of relay 4604, winding of relay 4603, left winding of relay 4604, to battery. Relay 4603 operates but relay 4604 being marginal does not attract its armatures. Relay 4603 in operating completes a circuit from battery, through the left winding of relay 4604, winding of relay 4603, right winding of relay 4604, contact of relay 4603, to the grounded conductor 4614. The right winding of relay 4604 is shunted and this relay is not operated. Relay 4603 closes a circuit from the grounded conductor 4614, outer right contact of relay 4603, conductor 4617, right back contact of relay 4707, winding of relay 4704, to battery. Relay 4704 operates and closes a circuit from battery, through its winding, winding of relay 4707, left contact of relay 4704, conductor 4618, to ground at the contact of relay 4605. Relay 4707 being shunted, however, does not operate at this time.

Upon the next interval, during which no current is transmitted, relay 4601 releases and removing the shunt permits relay 4604 to operate in series with relay 4603. Upon the last interval, a light negative impulse is sent and relay 4601 again operates and closes a circuit from ground, through its contact, and thence to conductor 4616, inner left front contact of relay 4604, left winding of said relay, to battery. This direct circuit shunts the relay 4603, which thereupon releases. The shunt for relay 4707 is now maintained over a path traceable as above explained through conductor 4617, right contact of relay 4604, to the grounded conductor 4614. Therefore, relay 4707 still remains inert. At the end of the last impulse, relay 4601 releases and causes the release of relay 4604. The shunt is now removed and relay 4707 energizes in series with relay 4704. Relays 4707 and 4704 extend the operating leads through to the next register 4701.

55 From the foregoing it will be noted that for each digit a negative impulse either light or heavy is sent during the second and fourth intervals. These negative impulses serve to operate the relays 4603 and 4604 in the cycle mentioned once for each digit. These relays in turn serve to operate the switching relays 4707 and 4704, etc., to switch the leads from one register to the next.

65 For the hundreds digit, a code consisting

of a positive impulse, a heavy negative impulse, no impulse, and a light negative impulse is transmitted. The light positive impulse causes the operation of relay 4600 and a circuit is traceable from ground over the 70 left back contact of relay 4603, conductor 4615, inner right front contact of relay 4704, inner right back contact of relay 4709, right winding of relay 4713, to battery. Relay 4713 operates and locks to the grounded conductor 4706. 75

Since the next impulse is negative and heavy, both relays 4601 and 4602 are operated. The relay 4601 causes the operation of relay 4603, while relay 4602 completes a circuit from the grounded conductor 4614, contact of relay 4602, outer left back contact of relay 4604, conductor 4619, inner left front contact of relay 4707, inner left back contact of relay 4708, right winding of relay 4714, to 85 battery. Relay 4714 locks to the conductor 4706.

During the third period, relay 4603 operates and the grounded conductor 4617 is now extended through the right front contact of relay 4707, right back contact of relay 4708, winding of relay 4709, to battery. Relay 4709 operates and prepares a circuit for relay 4708, which, however, does not operate until both relays 4603 and 4604 have 90 released.

At the end of the last or light negative impulse, relay 4604 releases and permits the operation of relay 4708.

For the tens digit 4, a code consisting of 100 no impulse, a light negative impulse, a light positive impulse, and a light negative impulse, is transmitted. The first light negative impulse causes the operation of relay 4603, which in turn causes the operation of relay 4711. The light positive impulse causes the operation of relay 4600, which in turn completes a circuit from the grounded conductor 4614, over the left front contact of relay 4603, conductor 4620, outer right 105 front contacts of relays 4704, 4709 and 4711, outer right back contact of relay 4712, right winding of relay 4715, to battery. Relay 4715 locks to the conductor 4706.

Finally, the last light negative impulse 110 causes the operation of relay 4710 in series with relay 4711.

For the units digit 5, a code consisting of 115 no impulse, a light negative impulse, no impulse, and a heavy negative impulse, is transmitted. The first light negative impulse causes the operation of relay 4603, which extends the conductor 4611 through to the winding of relay 4712. Finally, the heavy negative impulse causes the operation of relays 4601 and 4602. Relay 4601 causes the release of relay 4603, and relay 4602 completes a circuit from the grounded conductor 4614, contact of relay 4602, outer left front contact of relay 4604, conductor 4621, 120

125

130

thence through the outer left front contacts of relays 4707, 4708 and 4710, right winding of relay 4716, to battery. Relay 4716 locks to the grounded conductor 4706. At the end 5 of this last impulse, relay 4604 releases.

It was explained how the subscriber's sender transmitted a final heavy positive impulse after all the numerical coding has been sent. This impulse was transmitted by 10 connection of positive battery to the ring side of the line. In some systems, this heavy impulse is used for switching purposes to give information that the record has been completely sent. In the present system, it 15 serves for no purpose other than preparing the incoming sender for its further operations. The sender, in order to receive this impulse, reverses the direction of the sensitive polarized relay 4601. This is accomplished by the relay 4613, which operates after the final negative impulse relating to 20 the units digit has been sent. The circuit for relay 4613 may be traced from battery, through the winding of relay 4712, thence 25 through the winding of relay 4613, outer left contact of relay 4712, to the grounded conductor 4618. When the shunt is removed and relay 4613 is permitted to operate, it 30 reverses the relay 4601 so that this relay will respond to the final positive impulse. The circuit may be traced from the ring conductor 4530, thence through the inner right contact of relay 4612, inner right front contact of relay 4613, winding of relay 4601, 35 outer right front contact of relay 4613, outer right contact of relay 4612, to the tip conductor 4531. Relays 4602 and 4600 do not operate since they are not included in the circuit. The impulse is made heavy by including the left-hand non-inductive low resistance winding of relay 4622 in parallel 40 with the winding of relay 4601. This parallel circuit may be followed through the outer left contact of relay 4613, left winding 45 of relay 4622, outer right front contact of relay 4613, to the other side of the loop circuit. The relay 4601 in operating completes a circuit from the grounded conductor 4614, contact of relay 4601, inner left front contact of relay 4613, right winding of relay 4622, to battery. Relay 4622 operates and 50 serves to initiate the operation of the sender connector 4900 for connecting the incoming sender to an idle incoming marker. Relay 4622 locks in a circuit from battery, through 55 its right winding, right winding of relay 4612, inner right contact of relay 4622, right normal contact of relay 4623, right normal contact of relay 4624, to the grounded conductor 4614. Relay 4612 operates and locks 60 through its left winding and contact to the grounded conductor 4614.

Connection of the incoming sender to an idle incoming marker.—The relay 4622 closes a circuit for relay 4905 which is indi-

vidual to the sender at the sender connector 4900. This circuit may be traced from battery, through the outer back contacts of relays 4625 and 4626, middle right contact of relay 4622, conductor 4628, upper winding 70 of relay 4905, to ground at the back contact of relay 4606. Relay 4905 operates and locks in a circuit through its lower winding and contact, thence over back contacts of similar relays, through the winding of relay 75 4906, to ground. Relay 4906 operates and opens the original energizing circuit to prevent the operation of other relays similar to relay 4905. The multi-contact relay 4901 operates in a circuit from battery, through 80 its winding, uppermost contact of relay 4905, to ground at the front contact of relay 4906. Relay 4909 is next operated in a circuit from battery, through the lower contact of relay 4905, contact of relay 4907, back 85 contact of relay 4908, lower contact of relay 4901, normal contact of key 4911, outer left contact of relay 4908, left winding of relay 4909, to ground at the contact of relay 4910. Relay 4909 locks in a circuit from ground, 90 through the winding of relay 4910, contact and right winding of relay 4909, lower contact of relay 4905, to battery. Relay 4910 also operates and closes an obvious circuit for the right winding of relay 4908. The 95 multi-contact relay 4904 is operated in a circuit from battery, through its winding, outer right contacts of relays 4909 and 4910, to ground. The relay 4907 is energized in a circuit from battery, through its winding, 100 inner left contact of relay 4909, to ground at the inner right contact of relay 4910. Relay 4907 opens up the original energizing circuit to prevent the operation of other 105 relays similar to relay 4909. With the relays 4901 and 4904 operated, the various leads from the incoming sender are extended through to the idle incoming marker shown in the drawing.

Transfer of the record from the incoming sender to the incoming marker.—As soon as the marker is connected to the sender, the holding ground relay 5100 in the marker is energized in a circuit traceable from battery, over conductor 4628, through the 115 sender connector 4900, conductor 4912, winding of relay 5100, to ground.

The record is now transferred from the registers 4700, 4701, 4702 and 4703 of the sender to the corresponding registers 5300, 5301, 5302 and 5303 of the marker, and during this transfer a test of the contacts in the connector 4900 is made to ascertain whether or not all circuits are properly closed. First, all of the relays of the registers of the marker are energized and then these relays are released to correspond to unenergized relays of the sender registers. Since the relay 4705 of the register 4700 is operated, corresponding relay 5312 is en- 130

ergized in a circuit from battery, through its winding, thence through the connector 4900, right front contact of relay 4705, to ground. Since both relays 4713 and 4714 of the hundreds register 4701 are energized, corresponding relays 5314 and 5321 are energized in circuits from battery, through their windings, thence through the connector 4900 and front contacts of relays 4713 and 4714, to ground. Similarly, since relay 4715 of the tens register and relay 4716 of the units register are operated, corresponding relays 5318 and 5322 are operated. The remaining relays of the marker register are energized in circuits from battery, through their windings, and thence through back contacts of the respective relays of the sender registers, conductor 4717, connector 4900, conductor 5309, to ground at the left contact of relay 5500. When all of the marker register relays are energized, a series circuit is completed from ground, through the back contacts of said relays, conductor 5501, winding of relay 5502, to battery. Relay 5502 operates and locks in a circuit from battery, through its winding and inner contact, right back contact of relay 5503, conductor 5504, conductor 5505, to ground at the left contact of relay 5100. Relay 5502 at its inner contact closes an operating circuit for relay 5500 which locks through its right winding to the grounded conductor 5504. Relay 5500 closes an obvious operating circuit for relay 5503 which opens the locking circuit of relay 5502. As soon as relay 5500 operates, it removes ground from conductor 5309, causing the release of all marker register relays which correspond to unoperated register relays in the sender. The energizing circuit of relay 5502 is thus opened, and this relay releases.

Operation of the incoming marker translator.—With the record registered on the registers of the incoming marker, the translator 5400 is operated to determine the selection of one of the five final choices. The multi-contact relay 5402 is energized in a circuit from battery, through its winding, middle upper front contact of relay 5312, inner upper back contacts of relays 5310, 5311 and 5304, conductor 5313, outer contact of relay 5502, front contact of relay 5503, to the grounded conductor 5504.

Before one of the hundreds relays 5404, 5405, etc., of the translator can be operated, it will be necessary to operate the incoming frame connector 6100 to associate the incoming marker with the incoming frame 800.

Selection and operation of the incoming frame connector.—The test to select and operate an incoming frame connector 6100 having access to the group of incoming switches in which appears the trunk over which the connection has been extended, takes place in much the same manner as for

the district frame connector already described. The frame connector relay 4609 having been operated in the sender, will determine that a particular one of the frame connectors 6100 will be selected for associating the marker with the proper group of incoming frames. In order to connect the marker to the particular incoming frame 800, the characteristic connections at the block 710 are employed. Depending upon whether direct ground or battery, or ground or battery through a resistance is employed, the frame test relays of the marker will be actuated accordingly. Assume in this case that direct ground is connected at the distributing block 710.

Since the relay 4609 is energized, a circuit is closed for operating relay 6102 which determines that the frame connector 6100 is the one to be employed. Had the other test relay 4608 been energized, then the relay 6103 would have been selected to determine the operation of another frame connector 6101. The circuit for relay 6102 may be traced from battery, through its winding, conductor 6104, through the connector 4900, conductor 4913, to ground at the contact of relay 4609.

During the time the record is being transferred to the marker after the sender has been connected thereto, a test is made to ascertain the individual incoming frame. Since this frame is represented by a direct ground connection at the block 710, a test circuit may be traced from ground over conductor 711, thence through the sender selector 4500, conductor 4532, connector 4900, conductor 4914, back contact of relay 5101, winding of relays 5102 and 5103, to battery. Since no resistance is included in this circuit, both the marginal relay 5102 and the sensitive relay 5103 operate. Relay 5102 operates the relay 5104. Had the incoming frame been identified by battery potential connected at the block 710, then neither the relay 5102 nor the relay 5103 would have operated, and a moment later the relay 5101 operates in a circuit closed by the relays 5502 and 5503 and the test conductor 4914 would be shifted to the other set of test relays 5105 and 5106. With relay 5102 operated, a circuit is established for relay 6105 which is individual to the incoming frame 800. The circuit may be traced from the left-hand front contact of relay 5102, conductor 5107, upper contact of relay 6102, winding of relay 6105, to battery.

Relay 6107, individual to the marker shown, is now operated in a circuit traceable from battery, through the windings of relays 5108 and 5109, conductor 5110, inner upper contact of relay 6105, normal contact of key 6109, contact of relay 6108, left-hand winding of relay 6107, to ground at the back contact of relay 6111. Relay 6107 locks

through its right winding and contacts, and the winding of relay 6111, to ground, and the latter relay operates. The multi-contact relay 6112 now energizes in a circuit from 5 battery, through its winding, left contact of relay 6107, winding of relay 6110, to ground at the contact of relay 6111. Another circuit is closed for operating the particular multi-contact relay 6113 which is 10 individual to the incoming frame 800. This circuit may be traced from battery, through the winding of said relay, back contact of relay 6114, contact of relay 6112, upper contact of relay 6105, conductor 6115, winding 15 of relay 5111, conductor 5505, to ground. Relay 6113 opens the operating circuit of relay 6114 of the alternate connector 6101 to prevent the operation of the latter connector while the first one is in use. The various 20 leads have been thus extended through the frame connector 6100 to the incoming frame 800, and the marker is now ready to assume control of the incoming switch.

Selection of a final translator.—The operation of the marker translator 5400 is now completed and serves to determine the selection of one of the five final translators having access to the proper group of 2000 lines. It is assumed that the marker shown prefers on first choice to use the final translator connector 5700, and it will also be assumed that the particular final translator 5900 is the one to be selected.

As soon as relay 5111 operates in the circuit above traced therefor, one of the hundreds relays such as the relay 5404 of the translator 5400 is operated. The circuit may be traced from battery, through the inner left contact of relay 5111, right back contact of relay 5113, windings of relays 5114 and 5115, conductor 5116, inner upper back contacts of relays 5305 and 5306, inner upper front contacts of relays 5321 and 5314, conductor 5316, winding of relay 5404, to ground. Relay 5404 operates and the grounded conductor 5316 is extended through the inner contact of relay 5404, then through a contact of relay 5402, conductor 5407, normal contact of key 5408, back contact of relay 5409, conductor 5410, upper winding of relay 5701, back contact of relay 5702, to ground. Relay 5701 locks through its lower winding and contact and thence through the winding of relay 5702, and this latter relay energizes. The multi-contact relay 5703 is energized next in a circuit through the upper contact of relay 5701, winding of relay 5704, to ground at the front contact of relay 5702. The multi-contact relay 5705, which is individual to the particular group of 2000 called lines containing the desired line, is energized in a circuit from ground, through its winding, conductor 5706, contact of relay 5801, middle lower contact of relay 5701, conductor 5411, to battery on the con-

ductor 5407 as previously traced. With relays 5703 and 5705 energized, the incoming marker is connected to the desired final translator 5900. Since the relays 5705 and 5714, etc., are individual to different final 70 choices, these relays may serve to determine the operation of the trunk vertical magnets 813, 814, etc. There is a group of trunks, such as the group 808, leading from the incoming switches to each final choice and, accordingly, the operation of relay 5705 which pertains to a particular final choice may cause the operation of the magnet 813 controlling the contacts of the trunks which lead to this same final choice. The circuit 75 for magnet 813 may be traced from battery, through its winding, conductor 816, frame connector 6100, conductor 6117, contact of relay 5703, to ground at the contact of relay 5705. Magnet 813 rotates the associated rod 85 and prepares the contacts in vertical row 806.

Setting the final translator.—The final translator 5900 is now positioned from the hundreds and tens designations stored in the incoming marker. First, a circuit is completed for selectively operating one of the tens relays such as the relay 5905 traceable from battery, through the winding of said relay, connector 5700, conductor 5707, back contact of relay 5412, conductor 5413, inner upper front contact of relay 5318, inner upper back contact of relay 5319, conductor 5320, left back contact of relay 5506, conductor 5507, winding of relay 5414, to ground. Relay 5414 also operates in this circuit and closes a circuit for one of the hundreds relays of the final translator such as the relay 5901. This circuit may be traced from ground, through the contact of relay 5414, outer contact of relay 5404, contact of relay 5402, through the connector 5700, winding of relay 5901, to battery.

With the final translator 5900 positioned, a selective circuit is completed for operating the particular one of the vertical magnets 1107, 1108, 1109, etc., on one of the final connector frames 1000 which controls the vertical row of contacts containing the five subscribers' lines in which appears the desired line. Since the line 1100 is the called line, the magnet 1107 is operated. Due to the fact that the units digit of the line 1100 is greater than 4, the register relay 5322 is operated, as explained, and the circuit for the vertical magnet 1107 may accordingly be traced from ground, through the contact of relay 5508, conductor 5509, lowermost front contact of relay 5322, conductor 5324, conductor 5802, through the connector 5700, conductor 5708, inner right contact of relay 5905, contact of relay 5901, conductor 5908, winding of magnet 1107, conductor 1005, connector 5700, conductor 5709, left winding of relay 6302, to battery. The relay 6302, which is individ-

ual to the connector frame 1000, operates in the circuit traced. Another relay 6303 is shown which is individual to a second final connector frame. Relay 6302 locks through 5 its right winding and contact, conductor 6304, to ground at the right back contact of relay 5510. Due to the resistance of the left winding of the relay 6302, the vertical magnet 1107 does not operate at this time. Since, 10 however, the operating circuit is in proper condition, the relay 6302 energizes as above explained to permit the subsequent controlling operation to proceed.

Next, the final frame connector 6300, having access to the final frames in the selected choice and which is the preferred frame connector for the particular marker shown, is operated. The purpose of this frame connector is to associate the control circuits of 20 the marker with the horizontal operating and testing leads of the final switch and with the incoming vertical operating magnets. Inasmuch as there are several final switches in the choice, the particular relay 6305 which 25 is individual to the frame 1000 is selected and operated. The circuit for this relay may be traced from battery, through the winding thereof, conductor 6306, connector 5700, conductor 6202, to ground at the inner left 30 contact of relay 6302. Relay 6307 is now energized in a circuit from battery, through its winding, conductor 6308, connector 5700, conductor 5710, contact of relay 6305, to ground. Relay 6307 shunts the left winding 35 of relay 6302 by means of a path from battery, through the outer right contact of relay 6307, to the conductor 5709. The resistance of the left winding of relay 6302 being shunted, the vertical operating magnet 40 1107 is permitted to operate. Magnet 1107 rotates the vertical rod 1110 to prepare the contacts in the row 1102.

Operation of the final trunk connector.— At this stage of the procedure, the final 45 trunk connector 6200 which is the first preference of the marker shown on the first trial, is operated to associate the marker in the testing equipment with the trunks of the group 808 which lead from the incoming 50 frame 800 to the particular final choice involved. There is a group of trunks similar to the group 808 connecting this incoming selector frame with the final selector frames of each choice. The desired group of trunks 55 may therefore be identified jointly by the incoming frame connector 6100 and the final translator employed. Since the particular final translator 5900 is involved, the multi-contact relay 5705 is energized. Accordingly a circuit may be completed from the frame connector 6100 through a contact of relay 5705 to operate one of the multi-contact relays 6203, 6204, 6205 which relates to the particular group of trunks extending 60 from the incoming frame 800 to the desired 65

final choice. Had another final choice been involved, then another relay similar to the relay 5705 of the connector 5700 would have been operated and the circuit would have selected another of the relays 6203, 6204, etc. 70 In the present instance, the relay 6203 is the one required and its circuit may be traced from battery, through the winding thereof, conductor 6206, contact of relay 5705, contact of relay 5703, conductor 6207, through 75 the connector 6100, to ground.

Testing the called subscriber's line.—Before proceeding further with the operation, it will be necessary to discuss the testing of the called subscriber's line 1100. This operation takes place as soon as the final translator 5900 has been operated. The relay 5113 is the "line busy" test relay and the test circuit may be traced from battery, through the right winding of said relay, conductor 5325, lower back contact of relay 5201, conductor 5202, back contact of relay 5511, back contact of relay 5512, conductor 5513, uppermost back contact of relay 5323, upper front contact of relay 5322, upper 80 back contacts of relays 5326 and 5327, conductor 5328, back contact of relay 5329, conductor 5330, left winding of relay 5331, conductor 5332, connector 5700, conductor 5711, contact of relay 5905, contact of relay 5901, 85 conductor 5909, to the sleeve conductor of the called line 1100. The testing operation is timed by the operation of the relay 6305. As soon as relay 6305 operates as above explained, in case the line is idle and relay 5113 has not energized, it causes the operation of relay 6307 in the circuit traced. Relay 6307 completes a circuit for relay 5511 as follows: battery, through the winding of relay 5511, inner contact of relay 5512, conductor 5514, conductor 5203, to ground at the left contact of relay 6307. Relay 5511 opens 90 the test circuit and connects the relay 5515 to the sleeve conductor of the called line. The following circuit may now be traced: 100 ground, through the winding of relay 5515, front contact of relay 5511, outer back contact of relay 5512, conductor 5513, thence as previously followed to the sleeve conductor of the called line 1100 through the 110 usual cut-off relay to battery. Relays 5515 and 5331 are energized in this circuit. The relay 5515 operates the relay 6309 in a circuit from battery, through the winding of the latter relay, conductor 6310, to ground 115 at the contact of relay 5515. Relay 6309 operates the relay 6315 in a circuit from battery, through the winding of the latter relay, right front contact of relay 6309, conductor 6390, connector 5700, conductor 5713, 120 contact of relay 6305, conductor 6317, to ground at the contact of magnet 1107.

The relay 5331 is controlled by the units register 5303 and serves to operate the particular one of the relays 6311, 6312, etc., 125

which is individual to the horizontal group 1003 at the final switch 1000 in which appears the called line 1100. The relay 6312 is the relay to be operated and the circuit therefor may be traced from battery, through its contact, conductor 6313, connector 5700, conductor 5712, contact of relay 5331, conductor 5333, to ground at the outer right back contact of relay 5510. Relay 6312 connects the bundle of common test leads from the marker through to the test and operating conductors of the horizontal group 1003.

At the time relay 5111 in the marker operates, it also completes a circuit for the relay 712 associated with the trunk 417. This circuit may be traced through the winding of relay 712, conductor 713, through the sender selector 4500, conductor 4533, through the connector 4900, conductor 4915, outer left contact of relay 5111, conductor 5117, windings of relays 5118 and 5119, conductor 5120, to ground at the right back contact of relay 5121. Relay 712 prepares the incoming selector 800 for the operation of the vertical magnet. The vertical magnet 811 of the incoming selector 800 is now energized in a circuit from battery, through its winding, conductor 812, contact of relay 712, conductor 716, frame connector 6100, conductor 6116, to ground at the outer contact of relay 6315. Magnet 811 rotates the associated vertical bar to prepare the contacts in the row 803. The relay 712 is individual to the upper section 801 of the incoming selector switch 800. Similarly, the relay 714 is individual to the lower section 802. Accordingly the relay 712 causes the operation of relay 5204 to associate the test relays 5200 in the marker exclusively with the horizontal link of the section 801, inasmuch as the calling line has been extended over the trunk 417 to this section. The circuit for relay 5204 may be traced from battery, through its winding, conductor 5206, through the frame connector 6100, conductor 810, front contact of relay 712, conductor 715, to ground at the outer left contact of relay 707.

Testing the incoming links, trunks and final links.—A test is now performed by the testing relays 5200 in the marker to determine an idle path through the incoming selector switch 800 over the trunk group 808 and through the final switch 1000 to the called subscriber's line 1100. A three-point test is required to select an available path. Where the connecting trunk group 800 comprises 35 trunks and the horizontal groups in the final switches have only 14 links, it is necessary for the 35 trunks to be terminated in at least three vertical rows in the final switch. This places three trunks of the same group before each horizontal link. Accordingly, if one of the horizontal links

at the final switch is busy in the path, it will be necessary to render the three incoming trunks of the group non-selectable whether they are busy or idle.

The testing relay set 5200 consists of a series of double wound test relays 5207, 5208, 5209, 5210, etc., each serving to test one of the successive trunks of any group such as the group 808 leading from the incoming frames to the final frames. The relay 5207 serves to test the first trunk in each group, such as the trunk 817, in a circuit from battery, through the left winding of said relay, outer right back contact of relay 5219, conductor 5220, connector 5700, conductor 5715, contact of relay 6203, to the test conductor 900 of the trunk 817. The next relay 5208 tests the next trunk by means of a circuit which may be traced similarly through the left winding of said relay to the test conductor 901 of the trunk 818. In like manner, succeeding relays serve to test the successive trunks of the group. If any one of these trunks is busy, the corresponding test relay will energize.

The horizontal links of the incoming switch 800 are tested by means of relays 5211, 5212, etc., by leading one of these relays to each horizontal link in either section 801 or 802. The relay 5211 serves to test the first horizontal link in either section, such as the link 820, by means of a circuit from battery, through the winding of said relay, inner right back contact of relay 5219, conductor 5221, lowermost contact of relay 5204, thence through the frame connector 6100, conductor 821, through the left winding of the horizontal magnet 822, to the test conductor of the link 820. Had the other section 802 of links been involved, then the test circuit for relay 5211 would have been extended through the contact of relay 5205 to the test conductor of the first link of the section 802. In a similar manner, the test circuits for the remaining links of the section 801 may be traced. The test relays 5211, 5212, corresponding to busy markers of these links, will be energized. Finally, the horizontal links of the connector switch 1000 are tested by means of relays 5213, 5215, etc., there being as many of these relays as there are horizontal links in one of the sections 1003. Relay 5213 serves to test the first link in any section, such as the link 1006, by means of a circuit from battery, through the winding of said relay, back contact of relay 5217, back contact of relay 5301, conductor 5222, through the connector 5700, conductor 5716, contact of relay 6312, contact of relay 6205, conductor 1007, left winding of magnet 1008, to the sleeve conductor of the link 1006. In like manner, the other horizontal test relays 5215, etc., serve to test the remaining horizontal links in each final group. Since three of the

trunks of any group incoming to the final frame may appear before a single horizontal link, then relays 5213 and 5215 when energized must cause the energization of three 5 of the double wound test relays 5207, 5208, etc., which correspond to the three particular trunks incoming to the final link involved. These double wound relays are energized by means of obvious circuits which 10 are closed through their right-hand windings.

For a further explanation of the general manner in which testing operations of this kind are performed, reference is made to 15 U. S. Patent No. 1,600,399, issued Sept. 21, 1926, to W. W. Carpenter.

Should any of the elements comprising the first half of the incoming and final switches be busy, then the corresponding 20 test relay or relays may be operated and the remaining available paths are tested until finally an idle path is located. For the purpose of this explanation, however, it will be assumed that the first link 820 of the 25 switch 800, the first trunk 817, and the first link 1006 of the final frame 1000, are all simultaneously idle. Accordingly, relays 5211, 5207 and 5213 remain inert.

The foregoing testing operations are taking place during the interval that the vertical magnets on the incoming frame 800 are energizing. Since these magnets require a considerable interval to operate, this period is sufficiently long to permit the test 30 relays 5200 to become fully adjusted to the busy or idle condition of the associated elements. At the time the relay 5204 operates, it causes the energization of relay 5122 in a circuit from battery, through the winding 35 of the latter relay, conductor 5123, to ground at the inner upper contact of relay 5204.

When, therefore, the vertical magnet 811 subsequently operates, a circuit is completed from ground, through the inner lower 40 contact of said magnet, conductor 823, connector 6100, conductor 6118, left front contact of relay 5122, conductor 5124, left back contact of the deenergized test relay 5207, winding of relay 5219, to battery. Relay 5219 closes an obvious operating circuit for 45 relay 5217. With relay 5219 operated, the circuit of the incoming horizontal magnet 822 is tested over a path from battery, through the right winding of said magnet, conductor 821, thence as traced over conductor 5221, to the inner right front contact of relay 5219, inner right back contact of relay 5224, right winding of relay 5227, to ground. As this circuit is intact, relay 55 5227 operates but the magnet 822 does not become energized. Relay 5227 locks through its right winding and contacts, conductor 5228, to the grounded conductor 6116. The operating circuit of the horizontal magnet 822 is also tested over a path traceable from 60 65

battery, through the right winding of said magnet, conductor 1007, thence as previously traced over conductor 5222, back contact of relay 5201, front contact of relay 5217, left back contact of relay 5224, right winding 70 of relay 5225, to ground. If this operating circuit is completed, the relay 5225 operates but magnet 1008 does not energize due to the high resistance in the circuit.

The next step is to operate the vertical 75 magnet 1010 controlling the row of contacts in which appears the idle trunk 817. The circuit for this magnet may be traced from battery, through its winding, thence through contacts of relay 6305, contacts of relay 6203, conductor 6210, through the connector 5700, conductor 5717, inner left contact of relay 5219, conductor 5223, windings of test relays 5125 and 5126, to ground. The magnet 1010 rotates the associated bars and prepares the 80 contacts in the vertical row 1001.

The relay 5219 in operating closes a circuit for relays 902 and 5226. This circuit may be traced from battery, through the winding of relay 902, outer right back contact of relay 904, conductor 900, and thence as traced to conductor 5220, outer right front contact of relay 5219, conductor 5229, right winding of relay 5226, conductor 5230, left back contact of relay 5127, conductor 5128, 90 to ground at the contact of relay 5100. Relays 902 and 5226 operate in the above circuit. Relay 5226 locks in a circuit through its left winding and contacts, contacts of relay 5227, to ground over conductor 5228. 100 Relay 5225 also locks in a circuit from battery, through its left winding and contacts, left contacts of relays 5226 and 5227, to the grounded conductor 5228. Moreover, the relay 5224 is energized in a circuit from battery, through its winding and then through the contacts of relays 5225, 5226 and 5227 to the grounded conductor 5228.

At the time relay 5122 operates, it also 110 closes a circuit for relay 5129 traceable from battery, through the winding of relay 5129, right front contact of relay 5122, conductor 5130, connector 6100, to ground at the contact of magnet 813. When, therefore, the relay 5224 subsequently operates, indicating 115 that the operating circuits of the horizontal magnets 822 and 1008 are intact, other circuits are prepared for the operation of these magnets. The incoming horizontal magnet 822 is energized in a circuit from battery, through its right winding, thence as above traced to conductor 5221, inner right front contact of relay 5219, inner right front contact of relay 5224, conductor 5231, winding of relay 5131, right contact of relay 5129, right contact of relay 5132, back contact of relay 5133, conductor 5134, inner right contact of relay 6315, left front contact of relay 6309, conductor 6318, to the connector 5700, conductor 6211, contact of relay 6305, 120 125 130

to ground at the contact of magnet 1010. Magnet 822 rotates the horizontal bar and effects connection from the trunk 417 to the link 820 to the idle trunk 817.

- 5 The circuit for the horizontal magnet 1008 may be traced from battery, through its right winding, conductor 1007, thence as above traced to conductor 5222, back contact of relay 5201, front contact of relay 5217, 70 left front contact of relay 5324, conductor 5232, winding of relay 5135, right contact of relay 5129, and thence as above traced to ground at the contact of magnet 1010. The horizontal magnet 1008 rotates the associated 75 bar and effects connection from the trunk 817 to the link 1006 to the called subscriber's line 1100.

A circuit is closed from ground, through the windings of relays 5137 and 5136, conductor 5138, connector 5700, conductor 6212, contact of relay 6203, conductor 906, middle right contact of relay 902, outer right back contact of relay 903, conductor 907, contacts of switch 1000, left winding of magnet 1008, 80 to ground over conductor 1007. Relay 5137 operates in this circuit and closes an obvious energizing circuit for relay 5127. Relay 5127 locks to the conductor 5128.

A test is made of the contacts of the incoming selector switch 800 by means of the 85 relay 5140. The circuit may be traced from ground, through the windings of relays 5141 and 5140, inner left back contact of relay 5142, conductor 5233, connector 6100, conductor 824, front contact of relay 712, conductor 717, contacts of the switch 800, left winding of magnet 822, to ground over conductor 821. Relay 5140 operates and closes an obvious circuit for relay 5121, which locks 90 to the grounded conductor 5128.

Upon completion of the connection to the called line, a test is made of the circuit extended through the incoming and final switches and including the subscriber's telephone line. This circuit may be traced from the source of alternating current 5143, lamp 5144, winding of relay 5145, conductor 5146, contacts of frame connector 600, conductor 825, contact of relay 712, thence over the tip conductor of the trunk 417 to the incoming and final switches through the subscriber's subset, and returning over the ring conductor to the contact of relay 712, conductor 826, connector 600, to ground. If the connection is complete, the relay 5145 operates and closes a circuit for relay 5147. Relay 5147 locks to the conductor 5128. The apparatus is now ready to bring about the release of the incoming sender.

60 *Release of the incoming sender and sender selector.*—The release of the sender is initiated by the marker which causes the operation of relay 4624. The circuit for this relay may be traced from battery, through its 125 winding, conductor 4630, contacts of sender 65 connector 4900, conductor 4917, outer contact of relay 5147, right front contacts of relays 5127 and 5121, to ground. Relay 4624 closes an obvious circuit for the sender release relay 4606, which operates and opens the 70 holding circuit of the ground relay 4605, removing ground potential from conductor 4524. The removal of this ground potential causes the release of the sender selector switch 4500 and also the release of relay 75 703 in the trunk circuit.

70 *Release of the incoming marker.*—The operation of the marker release relay 4624 opens the holding circuit of the ground control relay 5100 in the marker. Relay 5100 80 removes ground potential from the various holding conductors whereupon the energized relays in the marker become released. The sender connector 4900 is also released by the removal of battery potential from conductor 4628. The incoming frame connector 6100, marker translator 5400, connector 5700, final translator 5900, the trunk connector 6200, and the final frame connector 6300 85 are also released at this time. The energizing circuits of the vertical magnets 811, 813, 90 1010, and 1107 having been opened, these magnets deenergize and restore the associated vertical rods to normal.

90 Connection is held through the final 95 switches by the maintained energization of the horizontal magnets 822 and 1008. The circuit for the magnet 822 may be traced from battery, through both windings thereof, contacts of switch 800, conductor 717, 100 through the make-before-break back contact of relay 712, this relay having deenergized, to the grounded holding conductor 715. The horizontal magnet 1008 is held temporarily in 105 a circuit from battery, through both its windings, contacts of switch 1000, conductor 907, outer right back contact of relay 903, middle right front contact of relay 902, to the grounded conductor 906. As ground is removed from conductor 900, which occurs before the energizing circuit of magnet 1008 110 is opened, relay 902 releases and relay 904 is now operated. The circuit for relay 904 may be traced from battery, through its winding, outer left contact of relay 902, conductor 910, contacts of the switch 800, to ground at conductor 717. Relay 904 closes an operating circuit as follows for relay 903: battery, through the winding of relay 903, inner left front contact of relay 904, to ground at the back contact of relay 905. Relay 903 closes a permanent holding circuit 115 for magnet 1008 traceable over conductor 907 to ground at the outer right front contact of relay 903. Another holding circuit 120 for the magnet 1008 may be traced from the conductor 907, through the outer right back contact of relay 902, conductor 900, to ground at the outer right front contact of 125 relay 904.

Ringing the called subscriber's line.—At the time relay 703 releases following the operation of the incoming and final switches, relay 700 is energized in a circuit from battery, through its right winding, thence as previously traced over the ring side of the trunk through the district selector switch 400, lower right winding of repeating coil 320, winding of the polarized supervisory relay 322, upper right winding of the coil 320, upper contact of relay 323, upper front contact of relay 302, upper back contact of relay 305, and thence over the tip side of the trunk and through the left winding of relay 700, to ground. The relay 700 operates but the direction of the flow of current is such that the relay 322 remains inert.

Should the circuit at the district be open at the time relay 703 releases, relay 700 remains inert. Accordingly, a circuit is closed for relay 708 as soon as the interrupter 718 closes its bottom terminal. This circuit may be traced from ground, through the lower back contact of relay 703, back contact of relay 700, innermost contact of relay 707, right winding and contact of relay 708, lower contact of interrupter 718, to battery. Relay 708 locks through its inner right contact, and upon the closure of the upper contact of interrupter 718 a circuit is closed from battery, through the outer right contact of relay 708, upper winding of relay 703, to ground. Upon the operation of relay 708, the locking circuit through the left back contact of said relay and winding of relay 707 is opened. Relay 707, however, is held in a circuit through the lower inner contact of relay 703 to ground at the outer left contact of relay 707. Immediately that relay 703 operates upon the closure of the upper contact of interrupter 718, relay 707 releases and removes holding ground from the incoming and final switches.

Assuming, however, that the connection has not been released at the district switch, relay 700 operates as explained and prepares the ringing circuit. First, relay 721 is energized by means of a circuit from ground, through the lower back contact of relay 703, front contact of relay 700, middle front contact of relay 707, inner left contact of relay 723, back contact of relay 722, inner lower armature and back contact of relay 720, left winding of relay 721, to battery. Another branch of this circuit extends through the winding of relay 720 and the right winding of relay 721 to battery. Relay 720, however, being shunted, does not operate at this time. Relay 721 completes the ringing circuit from the source 724, winding of relay 722, left contact of relay 721, lowermost back contact of relay 720, thence over the ring side of the subscriber's line, and returning over the tip side of the line to the uppermost back contact of relay 720, to ground at the front contact of

relay 721. When the subscriber answers, the resistance is reduced and relay 722 operates to remove the shunt and permit relay 720 to operate in series with relay 721. The called subscriber's line is thus extended through the right windings of repeating coil 702, the circuit including a supervisory relay 725. Relay 725 operates the slow-release relay 701 which reverses the direction of flow of current of the windings of relay 700 through the polarized supervisory relay 322 in the district trunk. Relay 720 in operating opens the circuit through the left-hand energizing winding of relay 721, and since the right-hand winding of relay 721 is non-conductive the relay 721 releases, in turn causing the release of relay 722. Relay 720 is now held in a circuit from battery, through the right winding of relay 721, winding of relay 720, contact of relay 722, front contact of relay 720, conductor 713, to ground at the contact of relay 707.

As soon following the operation of relay 322 as the interrupter 326 closes its lower contact, relay 325 is energized. This circuit may be traced from battery, through the lower contact of interrupter 326, normal contact and right winding of relay 325, inner left contact of relay 327, to ground at the front contact of relay 322. Relay 325 locks through its right winding and front contact to battery. As soon as the interrupter closes its back contact, a circuit is closed from battery therethrough, outer right contact of relay 325, left winding of relay 327, to ground. Relay 327 operates, releases relay 325, and locks itself in the following circuit: battery, through the right winding and contact of relay 327, outer right back contact of relay 328, conductor 229, left contact of relay 301, to the grounded conductor 309.

The connection is now in condition for conversation.

Release of the connection.—When the subscribers have completed conversation, they replace their receivers. The calling supervisory relay 321 releases and operates the message register relay 328, assuming the calling subscriber's message register is to be operated. The circuit may be traced from ground, through the inner lower back contacts of relays 304 and 329, back contact of relay 321, middle lower contact of relay 302, left winding of relay 328, to the upper contact of interrupter 330, as soon as this contact is closed, to battery. Relay 328 locks through its inner left front contact to battery. When later the interrupter closes its other contact, a circuit is closed from battery, through the inner right contact of relay 328, thence through the right winding of said relay, and also over conductor 331, inner left back contact of relay 325, right winding of relay 301, to ground. Relay 301 releases the holding relay 302 which in turn closes

a circuit from battery, through the resistance 332, outer left contact of relay 328, lower contact of relay 302, outer left contact of relay 327, through the line switch 200, to ground through the called subscriber's meter 128. Ground is maintained on the conductor 229 and on the winding of relay 327 to prevent this relay from releasing and also to prevent the line switch from releasing. This holding circuit may be traced from ground, through the outer right contact of relay 328, conductor 229, and also over the outer right back contact of relay 334, through the right contact and winding of relay 327, to battery. The district horizontal magnet 416 is also held after the release of relay 302 in a circuit from battery, through its windings, contact of switch 400, thence as previously traced to conductor 434, inner upper back contact of relay 329, connector 309, outer left contact of relay 325, to the grounded conductor 229.

After the charging operation has taken place and the interrupter 330 opens its lower contact, relays 301 and 328 release. Relay 328 removes the holding ground to permit the district selector and the line switch to restore to normal.

The release of the district selector causes the deenergization of relay 700, which closes a circuit from ground, through the lower contact of relay 703, back contact of relay 700, inner contact of relay 707, right winding of relay 708, and thence to battery when the lower contact of interrupter 718 is closed. Relay 708 operates and brings about the release of relay 707 in the manner above described. The removal of ground potential from conductor 717 releases the incoming selector switch 800 and also the relay 904 in the trunk 817. Relay 904 opens the above traced holding circuit for relay 903. Relay 903, however, remains energized in the other holding circuit traced therefor. Relay 902 is now operated in a circuit from battery, through its winding, contact of relay 904, to ground at the contact of relay 903. Relay 902 opens the final holding circuit of relay 903 and this latter relay releases provided the called subscriber has hung up his receiver. Relay 903 in turn releases the relay 904.

Called line tests busy.—Assume now that the called subscriber's line 1100 had been busy at the time the same was tested. Since the line is busy, ground potential exists on the sleeve conductor thereof and the above traced test circuit through the right winding of relay 5113 is completed to cause the operation of said relay. Relay 5113 closes an obvious circuit for relay 5142. The relay 5113 in operating locks through its left winding and contact, to ground at the outer right contact of relay 5100. Relay 5113 at its right back contact opens the circuit

previously traced for relay 5701. Relay 5701 releases the multi-contact relay 5703, whereupon the final translator 5900 is released, thus disconnecting the marker from the final connector switch. Following this, a circuit is closed for the vertical magnet 815 controlling the vertical row of contacts 827 in which appears the busy tone device 828. Also the horizontal links in the section 801 are tested to determine an idle one for connecting the trunk 417 through to the busy tone device 828. The vertical magnet 815 is operated by means of a circuit from battery, through its winding, frame connector 6100, conductor 6120, inner right contact of relay 5142, to ground at the contact of relay 5100. Magnet 815 rotates the associated vertical rod to prepare the contacts in the row 827. When magnet 815 operates, it closes a circuit as hereinbefore traced for the energization of relay 5129.

Since the final translator connector 5700 has been released, the test circuits for the trunks extending between the incoming and final switches and the test circuits for the horizontal links and the final switches are open, and accordingly the condition of these trunks and links have no effect upon the test relays 5200. The horizontal links in the group 801, however, are tested by the relays 5211, 5212, etc. Assuming that the first link 820 is idle, the test relay 5211 will remain deenergized as above explained. The relay 5207 remains inert since it cannot be operated by any of the trunks, which may be busy at this time. An appreciable interval is allowable for allowing the relays to assume their operated or their unoperated condition before the operation of the vertical magnet 811 of the incoming switch 800. The circuit for this magnet is closed by the relay 5142 and may be traced from battery, through the winding of said magnet, and thence as previously followed through the frame connector switch 6100 to conductor 6116, thence over conductor 5228 to the middle right contact of relay 5142, to ground at the contact of relay 5100. Upon the complete operation of magnet 811, a circuit is closed from ground, through the contact of said magnet, and thence as previously traced over conductor 823, through the frame connector 6100, thence over conductor 6118, through the left front contact of relay 5122, conductor 5124, left back contact of relay 5207, winding of relay 5219, to battery. Relay 5219 operates, whereupon a circuit is closed for testing the horizontal magnet 822. This circuit may be traced from battery, through the right winding of said magnet, conductor 821, and thence as previously traced to ground through the right winding of relay 5227. Relay 5227 locks through its left winding and contacts, conductor 5228, middle right contact of relay 5142, to ground

at the contact of relay 5100. The magnet 822, however, does not operate in this circuit. Relay 5227 closes a circuit for relay 5224 traceable from battery, through the 5 winding of the latter relay, outer right contact of relay 5142, contacts of relay 5227, to the grounded conductor 5228. An operating circuit is thereupon closed for the magnet 822 traceable from battery, through 10 its right winding and thence as previously followed through the connector 6100, through the inner right front contact of relay 5224, conductor 5231, winding of relay 5131, right front contact of relay 5129, 15 right contact of relay 5132, contact of relay 5133, to ground at the outer left contact of relay 5142. The magnet 822 operates in this circuit and extends the trunk 417 through to the busy tone device 828. A circuit 20 may thereupon be traced from ground, through the right winding of the tone coil 828, contact of switch 800, over the ring side of the trunk 417, lowermost back contact of relay 700, thence through the winding 25 of relay 725 and the lower right winding of coil 702, to battery and ground. Current flowing in this circuit causes an induced current in the left windings of the coil 702 which flows over the calling line and 30 produces a characteristic sound in the calling subscriber's receiver, notifying him that the called line is busy.

The calling subscriber on hearing the busy tone places his receiver on the switchhook, bringing about a release of the switch in the manner hereinbefore fully described in detail.

Establishment of an outgoing connection.—We have shown how the central 40 office equipment functions when a full mechanical connection is to be established between two subscribers' lines in the same office. To further illustrate the grouping of this system, it will next be considered 45 that a connection is to be established from a subscriber's line in the local office over a trunk outgoing to a distant office. It is not believed to be necessary to illustrate the switching apparatus at the distant office. 50 This may be of any of the well known types, such as incoming selector switches and call indicators at the operators' positions. For a complete understanding of the manner in which the apparatus at the distant office 55 functions, reference is made to U. S. Patent No. 1,543,967, issued June 30, 1925, to S. B. Williams and E. S. Gibson, and to the Williams Patent No. 1,517,331, granted December 2, 1924.

60 For this particular type of call, both a district switch 400 and office switch 600 are employed. These switches are both controlled by the outgoing marker in much the same manner as already explained in connection with the district selector 400. The

principal difference is that the marker, after having tested the district horizontal links and trunks, instead of releasing forthwith thereupon performs a similar test of the office selector links and outgoing trunks in 70 the desired group. Following the determination of an idle path for the office selector, this switch is operated and then the outgoing marker is given the signal to release.

The operation of the system, including the 75 functioning of the line switch 200, sender selector 1300, the registration of the designation of the subscriber's sender, and the association of the sender with an idle outgoing marker, all take place in substantially 80 the same manner as hereinbefore described. The designation, however, being different for an outgoing or inter-office call than the one for a local connection, the code registers 2100, 2101 and 2102 of the sender will, of course, be operated in a different combination. 85

Let it be assumed that the designation of the called subscriber's line is such as to cause the operation of relays 2904 and 2903 90 of register 2900, relay 2908 of register 2901, and relays 2916 and 2915 of register 2902 in the marker. Accordingly, the multi-contact relay 3302 is energized in a circuit from battery, through its winding, conductor 3315, lower front contacts of relays 2903 and 2904, lower back contacts of relays 2905 and 2906, and thence to ground over conductor 2922 as previously explained. Also the relay 3316 is energized in a circuit from battery, through its winding, conductor 3317, front contacts of relays 2915 and 2916, upper back contact of relay 2913, conductor 2923, and thence to ground as above traced. With the translator 3300 positioned, the code relay 3501 is energized in a circuit from battery, through its winding, conductor 3524, contacts of relays 3302 and 3316, conductor 3318, front contact of relay 2908, back contact of relay 2909, back contacts of relays 95 2910 and 2911, thence to ground over conductor 2922. 100

In a manner similar to that previously explained, code relay 3501 serves to determine the operation of a district trunk group relay 115 3001 and one of the space assignment relays 2713, together with a class relay 3401. In this case, since there is an office selection involved, the relay 3501 will also prepare for the subsequent operation of an office 120 trunk group relay 3101 in a manner to be explained hereinafter.

Also in the manner fully explained, the class relay 3401 may connect ground potential to the proper ones of various leads which affect certain class relays in the sender to prepare the sender for subsequently controlling the apparatus in accordance with the particular class of call concerned.

Following the operation of the district 130

frame connector 3600, a circuit is closed in the manner explained hereinbefore over conductor 3031, winding of the district trunk group relay 3001, contact of the relay 3501, 5 conductor 3511, contact of relay 3514, to ground at the contact of relay 3504. The relay 3525 has already been operated in a circuit from battery, through its winding, contact of relay 3501, and thence to ground 10 over conductor 3511 as traced.

The relay 3001 causes the operation of the trunk connector 3700 by energizing the relay 3702 in the following circuit: battery, through the windings of relays 3013 and 15 3014, outer right contact of relay 3009, conductor 3015, contact of relay 3611, conductor 3617, inner left contact of relay 3001, conductor 3032, conductor 3016, and thence as previously traced through the winding of 20 relay 3702. In this case, a group of district trunks will be employed such as the group appearing in the vertical row 404 leading to the office selector switches 600. Accordingly, the multi-contact relay 3716 of the 25 trunk connector is energized in a circuit from battery, through its winding, contact of relay 3717, thence over conductor 3718, back contact of relay 3102, contact of key 3103, conductor 3115, contact of relay 3001, 30 thence over conductor 3017, windings of relays 2806 and 2807, conductor 2808, to ground through the contact of relay 3704. Relay 3716 associates the marker testing equipment with the group of trunks leading 35 from the district selector switch to the office selector switches 600.

The vertical operating magnet 412 which controls the contacts in the row 404 is energized in a circuit from battery, through 40 its winding, thence through the frame connector 3600, contact of relay 3611, conductor 3626, contact of relay 3101, conductor 3018, and thence to ground as hereinbefore traced.

The control relays 3109 and 3114 in this instance are operated in circuits from battery, through their windings, thence over conductor 3112, contact of relay 2806, conductor 3509, outer contact of relay 3525, to 50 the grounded conductor 3310.

The selection of an idle trunk 501, an idle horizontal link 406, and the operation of the horizontal magnet 416, take place in the manner already fully described hereinbefore. As soon as the district selector is operated, relays 3210 and 3211 are energized as explained. A circuit is now closed from ground, through the windings of relays 3215 and 3214, front contact of relay 3211, 55 conductor 3217, left back contact of relay 3517, conductor 3518, left contact of relay 3020, connector 3600, conductor 3624, contact of relay 413, conductor 433, thence through the contacts of the district switch 60

400, inner back contact of relay 502, resistance 503, to battery. Relay 3214 operates in this circuit and closes an operating circuit for relay 3514 as follows: battery, through the winding of relay 3514, inner contact of relay 3525, conductor 3520, contact of relay 3214, back contact of relay 3216, to ground on conductor 3213. Relay 3514 closes a circuit from battery, through its winding and right contact, winding of relay 3517, to the grounded conductor 3310. 75 Relay 3517 being shunted at this time, however, does not operate. Relay 3514 in operating releases relay 3611. This relay disconnects the marker test relays from the 80 district frame, but the frame connector 3600 remains operated in order that the marker may retain control over the district switch. Relay 3514 also causes the release of relay 3225 and the district group relay 3001. The release of relay 3001 causes the 85 release of the trunk connector 3700 and all operated test relays 2800 are also released. Moreover, the trunk vertical magnets of the 90 district selector frame are deenergized. The release of relay 3525 removes the shunt around the winding of relay 3517 and this latter relay now operates in series with relay 3514. Relay 3517 closes an operating 95 circuit as follows for relays 3512 and 3511: battery, through the windings of relays 3512 and 3511, right front contact of relay 3517, to the grounded conductor 3310.

An office trunk group relay 3101 is next selected and operated. The circuit for this purpose may be traced from battery, 100 through the winding of relay 3101, outer left contact of the code relay 3501, right front contact of relay 3517, to the grounded conductor 3310. The functions of the group 105 relay 3101 are similar to those of the district group relay 3001.

Operation of the office frame connector.—The office frame connector 3800 is selected under the control of the test relays 2800 and the district trunk group relay 3001. 110 Relay 3501 is able to determine the particular group of trunks which the district selector may seize. Since these trunks may be distributed to a number of office frames, the particular trunk seized must be determined by the cross-point test relays 3200. 115 Therefore, during district selection, one of the office frame test relays 3200 is operated and locked. It may be assumed that the relay 3220 identifies the office frame connector 3800 having access to the desired group of office frames. Accordingly this relay will be operated in a circuit from battery, through the middle right contact of relay 3501, conductor 3528, conductor 3221, right 120 winding of relay 3220, conductor 3222, left contact of test relay 2820, conductor 2815, inner left back contact of relay 3514, to 125

ground at the contact of relay 3504. Relay 3220 locks through its left winding and contact to the grounded conductor 3515.

When, later, the district selection has been completed and relay 3511 operates, the office frame connector 3800 is operated for energizing the relay 3802. The circuit for this purpose may be traced from battery, through the right contact of relay 3511, conductor 3527, windings of relays 3033 and 3034, conductor 3035, inner right contact of relay 3220, contact of key 3233, back contact of relay 3224, left winding of relay 3802, to ground at the back contact of relay 3803. Relay 3802 operates and, in the manner fully explained hereinbefore, causes the operation of multi-contact relay 3805. Relay 3806 also operates in a circuit from battery, through its winding, contact of relay 3809, contact of relay 3805, conductor 3807, outer right contact of relay 3220, conductor 3116, winding of relay 3117, to ground.

Operation of the trunk connector.—The trunk connector 3700 is again operated to associate the marker test relays with the group of trunks outgoing from office selector switch 600. The operation of the trunk connector this time is involved by the trunk group relays and its selection is determined by the office trunk group relay 3101. The circuit for the relay 3702 may be traced through the left winding of this relay, thence through the contact of relay 3102, contact of key 3103, conductor 3016, inner left contact of relay 3101, conductor 3118, conductor 3617, right contact of relay 3117, windings of relays 3014 and 3013, to battery. The operation of the trunk connector 3700 takes place as described hereinbefore.

The marker has thus been connected to the office frame 600 and relay 613 is energized in a circuit from ground, through its winding, conductor 640, outer back contact of relay 502, thence over the tip side of the trunk through the district selector 400, conductor 313, thence as traced through the sender selector to the sender and the sender connector 2500 to the conductor 2924, back contact of relay 3011, conductor 3036, left contact of relay 3117, conductor 3119, back contact of relay 3611, windings of relays 2801 and 2802, back contacts of relays 2803, 2804, and 2805 to battery. Relay 614 operates and locks through its winding and lower inner contact, thence through the connector 3800, conductor 3811, conductor 3812, inner back contact of relay 3519, to battery.

The vertical magnet 609 of the office selector is operated in a circuit from battery, through its winding, contact of relay 613, through the frame connector 3800, conductor 3808, windings of relays 3201 and 3202, conductor 3203, and thence as traced to ground

through the contacts of the trunk connector 3700. The vertical magnet 612 controlling the row of contacts 604 is also energized in a circuit from battery, through its winding, connector 3800, conductor 3813, contact of relay 3101, conductor 3120, conductor 3018, windings of relays 3204 and 3205, and thence to ground over conductor 3203. Next an idle horizontal magnet such as the magnet 641 is operated. The circuit for this magnet may be traced from battery, through its right winding, connector 3800, and thence over conductor 2840, inner right front contact of relay 2820, to ground through the right winding of relay 2837 as above described.

Following the operation of the district selector, the relays 3210 and 3211 will release owing to the release of relays 3114 and 3109 at the time relay 3525 opened its outer contact. Relays 3210 and 3211 are operated again, however, in connection with office selection. The circuit for relay 3210 may be traced from battery, through its winding back contact of relay 3211, thence over conductor 3212, through the contact of relay 2820, thence to grounded conductor 4815. Relay 3210 locks to the conductor 3213 which has in the meantime been grounded by relay 3114. The new operating circuit for relay 3114 is completed by the contact of relay 3512. Relay 3210 causes the operation of relay 3211 as above explained. Relay 3214 is now operated by means of a circuit from battery, on the sleeve of the trunk 642, thence through the office switch 600, conductor 643, contact of relay 613, connector 3800, conductor 3226, outer right contact of relay 3020, conductor 3037, left contact of relay 3517, conductor 3217, left contact of relay 3211, windings of relays 3214 and 3215. Relay 3214 closes the above traced circuit for relay 3515, which operates and prepares a circuit for relay 3521. The relay 3519 at its outer left contact shunts the relay 3214, which thereupon releases, and in so doing removes the shunt to permit relay 3521 to operate in series with relay 3519. Relay 3519 also opens the holding circuit of relay 613 and this latter relay releases. Following the release of relay 613 and before the operating circuit of the horizontal magnet 641 has opened, a circuit is closed for operating relay 502. This circuit may be traced from battery, through the winding of relay 502, lower back contacts of relay 613, conductor 643, contacts of switch 600, left winding of magnet 641, to ground over the operating circuit of the magnet 641. Relay 502 operates and locks in a circuit from battery, through its winding, thence through the lower contact of relay 613, conductor 644, inner front contact of relay 502, thence to ground on the sleeve conductor of trunk 219. A locking circuit is now established

for the magnet 641 traceable from battery, through both its windings, contacts of the switch 600, to ground over conductor 613 as traced.

5 Following the operation of relay 3521, the controlling apparatus including the marker is released in the manner hereinbefore fully described. The subscriber's sender may now proceed to transmit code impulses over the 10 trunk 642 to the distant office, there to control switching or indicating mechanism for the further completion of the call.

Release of the connection.—After the conversation has been completed and the 15 subscribers replace their receivers on the switch-hooks, the district selector 400, the office selector 600, and the line switch undergo release as hereinbefore explained.

Second trial feature and trouble indicator 20 operation.—A description will now be given of the manner in which a second marker may be called into use for the establishment of a connection in case the connection is not successfully completed under the control of 25 the first marker. This provision is made both in connection with the outgoing marker and the incoming marker. Also, a description will be given of the operation of the trouble indicators which are associable with 30 the markers for recording the nature of the trouble encountered and the reason why the connection could not be successfully established.

At the time the outgoing marker is seized 35 by the sender connector 2500, the time measuring device 4301 is set in operation to measure an interval of time which is ordinarily sufficient for the completion of the marker's functions. In case, however, the 40 marker encounters trouble or for any reason ceases to proceed with its operation, the time measuring device 4301 actuates the connector 4000 which serves to connect the trouble indicator, shown in Figs. 41 and 42, with the 45 particular marker in trouble. Also at this time an indication is sent back to the sender notifying it that something irregular has occurred and recording the nature of the marker that is being used. The sender 50 thereupon immediately releases the marker and proceeds to seize a second marker. The information recorded in the sender following the encounter of trouble is now transferred to the new marker and is used by it 55 to determine which frame and trunk connector should be employed. In any event, the second marker will always employ a different frame and trunk connector than the one used by the first marker.

60 At the time the relay 2510 operates, it places ground potential upon conductors 2513 and 2520. These conductors lead through the windings of relay 3904 and accordingly this relay operates, lighting the 65 lamp 3905. Relay 3906 is also energized in

an obvious circuit, causing in turn the operation of lamp 3907. The lamp 3907 is a common signal.

As soon after relay 3906 operates as the 70 interrupter 4308 closes its contact, a circuit is completed for operating the counting relays 4309 and 3910. This circuit may be traced from ground, through the left contact of relay 3906, conductor 4323, interrupter 4308, left contact of relay 4315, right 75 back contact of relay 4309, winding of relay 4310, to battery. Relay 4310 operates and prepares a circuit from battery, through its winding and the left winding of relay 4309, contact of relay 4310, contacts of relays 80 4312 and 4314, to ground on conductor 4323. Relay 4309, however, being shunted, does not operate at this time. When the interrupter 4308 opens its contact, relay 4309 85 operates in series with relay 4310. On the next closure of the interrupter, a circuit is closed from the grounded conductor 4323, through the right front contact and right winding of relay 4309, and in parallel through the right back contact of relay 4311, 90 to battery through the winding of relay 4312. Relay 4310 is shunted and releases, and relay 4312 operates. When the interrupter again opens its circuit, relay 4309 releases and relay 4313 operates in series 95 with relay 4312. On the next closure of the interrupter the relay 4310 is again operated, and upon the following opening of the interrupter relay 4309 operates. When 100 the interrupter again closes, the grounded conductor 4323 is extended over the front contacts of relays 4309 and 4311, and the back contact of relay 4313, through the winding of relay 4314, to battery. On the 105 following opening of the interrupter, relay 4313 operates and relays 4311 and 4309 are released. By suitably connecting the contacts of the counting relays to the conductor 4324, the device may be arranged to 110 measure any desired interval of time. Assume that the operation of the relay 4313 measures the end of the desired interval. In this case, the conductor 4324 is connected as shown and when relay 4313 operates a circuit is closed as follows for operating relay 4315: battery, through the winding of relay 4315, conductor 4324, thence through the middle left contact of relay 4313, to the 115 grounded conductor 4323. Relay 4315 operates to prevent the further operation of the counting relays 4301 and also closes a circuit for relay 4317. This latter circuit may be traced from battery, through the winding of relay 4317, left contact of relay 4316, left 120 contact of relay 4320, right contact of relay 4315, to the grounded conductor 4323. Relay 4317 closes an obvious circuit for the slow relay 4318, which in turn closes a circuit for relay 4319. Relay 4319 closes a 125 circuit for relay 4320, which in turn closes 130

a circuit for relay 4316. Relay 4316 locks through the right contact of relay 4315 to the grounded conductor 4323. Relay 4316 opens the circuit of relay 4317, which in turn 5 opens the circuit of relay 4318. Relay 4318 opens the circuit of relay 4319, which in turn opens the circuit of relay 4320.

As soon as relay 4319 operates, the connector 4000 is set in operation to connect 10 the trouble indicator to the marker. Relay 4319 in operating completes a circuit from battery, through its left contact, left contact of relay 4321, key 4322, conductor 4325, upper winding of relay 4003, upper contact of 15 relay 4004, conductor 4105, key 4203, to ground at the device 4201. Relay 4003 operates and locks through its lower winding and contact, back contact of relay 4006, winding of relay 4004, to ground. The relay 4004 20 operates and closes an obvious circuit for the multi-contact relay 4001. Relay 4001 being individual to the particular marker shown, serves to connect this marker to the trouble indicator. Relay 4001 closes an obvious 25 circuit for relay 4005 which locks to the conductor 4105. Relay 4005 is slow to operate to prevent the premature operation of relay 4321. From the time the trouble indicator is connected to the marker until the 30 slow relay 4319 releases, a considerable interval expires during which the trouble indicator takes a complete record of the condition of the marker. When, subsequently, the relay 4319 releases, it removes battery 35 potential from conductor 4325, causing the release of relays 4003, 4005 and 4001 to disconnect the marker from the trouble indicator.

Should a second marker attempt to seize 40 the trouble indicator while the first marker is associated therewith, the attempt will be rendered unsuccessful by the relay 4005. When the relay 4317 of the timing device of 45 the second marker operates, a circuit is closed from battery, through the right contact of said relay, left winding of the relay similar to relay 4321, thence over a common conductor 4106, to ground at the contact of relay 4005. Relay 4321 operates and 50 opens the start circuit 4325 to prevent the second marker from interfering with the connector 4000 while the first marker is associating with the trouble indicator. The relay 4005, being slow to operate, provides 55 an interval following the application of ground potential to the conductor 4325 and before it applies ground potential to the conductor 4106. During this interval, the relay 4317 has become released so that when 60 ground potential is applied to conductor 4106, the relay 4321 of the first marker sees that the trouble indicator is not prematurely operated.

The manner in which the trouble indicator 65 takes a record of the progress made by the

marker will be described at a later place in the specification. A description will now proceed to explain the different functions on a retrial.

When ground is applied to conductor 70 4106, the relay 4107 commences to operate. This relay is slow to attract its armature to provide a sufficient time for the record to be taken by the trouble indicator before the sender is notified that it should release the 75 first marker and summon a new marker. When relay 4107 finally operates, it closes a circuit for relay 1415 in the sender. This circuit may be traced from battery, through the winding of relay 1415, inner left back 80 contact of relay 1412, conductor 1430, connector 2500, conductor 2521, thence over conductor 2925, through the connector 4000, to ground at the contact of relay 4107. Relay 1415 operates and locks in a circuit from battery, through its winding and inner left contact, winding of relay 1412, outer right contact of relay 1415, to ground at the inner 85 left front contact of relay 1407. Relay 1412 being shunted does not operate until the 90 marker is released. As soon as relay 1415 operates, it opens the previously traced circuit for relay 2506. Relay 2506 in releasing releases the sender connector 2500, thereby disconnecting the marker from the 95 sender. The sender connector 2500 in releasing opens the shunt around the winding of relay 1412, which operates in series with relay 1415. The start circuit for the sender connector 2500 is now closed in a circuit 100 from battery, through the resistance 1411, outer right contact of relay 1412, front contact of relay 1407, thence over conductor 1416 as traced through the winding of relay 2506. The sender connector 2500 functions 105 and seizes the first idle marker, whether this marker is one of the same or of a different group from the first marker employed. If the record of the trouble existing at the first marker has already been taken, the marker 110 is restored to its normal condition and is available to the sender when said sender prepares to seize a certain marker for a new trial. Therefore, the second trial marker may, in fact, be the same marker employed 115 for the first trial dependent upon the busy and idle condition of the various markers and its position in the preferential order of seizure. For the sake of illustration, assume 120 that the second marker belongs to the same group and is in all respects identical to the marker shown in the drawing. Accordingly the marker shown will now be treated as though it were the second marker to be treated by the sender. The first marker in the meantime has been associated with the trouble indicator and a record of the trouble taken therein.

Upon the connection of the sender to the 125 second marker, information is given to the 130

marker whereby it will be able to choose a frame connector and a trunk connector in the groups other than the group containing the frame connector 3600 and the trunk connector 3700. If an interoffice call is involved, it will also employ this information to select an office frame connector in the group other than the group containing the frame connector 3800. Thus the second marker will 5 employ entirely different connecting apparatus for associating itself with the district and office switches and with the district and office trunks. For this purpose, the relays 3040 and 3041 are energized. The circuit 10 for these relays may be traced from battery, through their windings, conductor 3042, connector 2500, conductor 2522, outer left contact of relay 1415, to ground at the inner right contact of relay 1412. Inasmuch as 15 this circuit contains no appreciable resistance, both the sensitive relay 3040 and the marginal relay 3041 operate. Relay 3040 closes an obvious circuit for relay 3043. Moreover, the multi-contact relay 3006 is operated 20 in a circuit from battery, through its winding, contact of key 3005, to ground through the contacts of relays 3041 and 3040. The relay 3006 shifts all of the leads, connections and contacts of relays such as the 25 relay 3002 from its back contacts to its front contacts, respectively. Accordingly, when the start circuit is closed for the district frame connector, instead of leading to the relay 3602 of the frame connector 3600 as 30 previously traced, it will now be closed through the outer right front contacts of relay 3002, contact of key 3005, front contact of relay 3006, conductor 3044, winding of relay 3627, to ground at the contact of 35 relay 3628. Thus the alternate frame connector 3601 is selected and operated to associate the outgoing marker with the district selector switch 400 in order that the new marker may proceed to establish the connection 40 which the first marker failed to complete. By this means, a possible source of trouble in the frame connector 3600 will be avoided the second time by employing the frame connector 3601.

50 Relay 3102 is also energized in a circuit from battery, through its winding, thence to ground through the contacts of relays 3041 and 3040. Relay 3102 in a manner similar to relay 3006 shifts the start leads from its back and front contacts so that the trunk connector 3701 is employed instead of the trunk connector 3700. This avoids the possibility of a repeated case of trouble due to the fault of the trunk connector 3700 which 55 is first used.

Again, the relay 3224 is energized by the relays 3041 and 3040, and this relay determines that the office frame connector 3801 will be used instead of the connector 3800 60 first employed.

Assume that the first trial marker was of the kind opposite to the one shown in the drawing and therefore belonging in the other group. When such a marker encounters trouble, the trouble indicator applies 5 ground potential upon conductor 2926 due to the fact that this conductor is strapped to the conductor 2925, instead of placing the potential upon conductor 2521. With ground potential on conductor 2926, an obvious circuit is traceable for the relay 1414 in the sender. Relay 1414 operates and prepares a circuit for relay 1412. In a manner similar to that discussed for relay 1415, the relay 1414 causes the first marker to release, 10 permitting the relay 1412 to operate whereupon the sender is associated with a second marker. Assuming that the second marker is the one shown in the drawing, it will accordingly be necessary for this marker to 15 employ its first choice connectors 3600, 3700 and 3800 inasmuch as the first marker employed the connectors 3601, 3701 and 3801. Accordingly the circuit through relays 3040 and 3041 may be traced over conductor 3042, 20 thence as previously traced to conductor 2522, outer left contact of relay 1414, resistance 1426, to ground at the inner right contact of relay 1412. Due to the high resistance 1426, the relay 3040 operates but 25 the marginal relay 3041 remains inert. Accordingly relays 3006, 3102 and 3224 are not operated and therefore the marker selects its regular choice connectors 3600, 3700 and 3800.

30 In an analogous manner, should the first trial marker be the one shown in the drawing and should the second trial marker be one of the opposite character, then the second trial marker will employ its second 35 choice frame and trunk connectors.

In case the second trial marker fails to complete the connection, the time measure device 4301 completes the counting of the predetermined interval and ground potential is applied as above explained to conductor 2925 in a circuit which may be traced through the sender connector 2500 to the conductor 1430, thence through the inner left front contact of relay 1412, winding of the 40 relay 1409, to battery. Relay 1409 operates the sender release relay 1402 in a circuit from battery, through the winding of relay 1402, right contact of relay 1501, conductor 1523, outer left contact of relay 1431, 45 left contact of relay 1409, conductor 1432, lower contact of sequence switch spring 1929 (2+15), conductor 1923, to ground at the contact of relay 1812. In the manner fully described hereinbefore, the sender releases.

The ground potential on conductor 2925 also results in the closing of the circuit traceable over conductor 2523, winding of relay 3020, to battery, and in parallel through the contact of relay 3043, thence over conductor 50

3046, through the connector 3600, contact of relay 413, winding of relay 334, to battery. Relay 334 operates and causes the application of the busy tone potential to the calling subscriber's line. The circuit may be traced from the busy tone source 335, through the inner left contact of relay 334, conductor 315, to the ring side of the link circuit, and from ground, through the inner right contact of relay 334 to the tip side of the circuit. The subscriber hearing the tone induced in his line, realizes that the connection cannot be obtained and accordingly releases.

Second trial by the incoming marker.—It will next be assumed that the incoming marker shown in the drawing is unsuccessful on its first attempt to control the incoming and final selector switches due to one reason or another. When the incoming sender is first connected to the marker, relay 4910 operates as explained and closes circuits from ground, through its contacts, over conductors 5334 and 5335, windings of relay 6402, to battery. Relay 6402 operates the relay 6403. Relay 6403 applies ground potential to conductor 6404. The interrupter 6502 causes the counting relays 6501 to function in the manner explained in connection with the timing device for the outgoing marker. As soon as relay 6503 operates, a circuit is closed from battery, through the left contact of said relay, left contact of relay 6504, key 6505, conductor 6506, upper winding of relay 6603, contacts of relays 6604 and 6605, conductor 6706, key 6801, to ground at the device 6802. Relay 6603 operates and locks in series with relay 6604. The multi-contact relay 6601 and the slow-operating relay 6605 are now energized. Relay 6605 applies ground potential to conductor 6707, causing the operation of relay 6504 which in turn releases the relays 6603 and 6604, causing the disconnection of the trouble indicator from the marker after the expiration of an interval of time.

As soon as relay 6605 operates, a circuit is closed for the slow-operating relay 6606. After an interval relay 6606 operates and a circuit is closed from ground, through the contact of said relay, contact of relay 6601, conductor 6607, contact of the connector 4900, conductor 4919, middle right back contact of relay 4627, winding of relay 4626, to battery. Relay 4626 operates and prepares a circuit from battery, through its winding and inner right contact, winding of relay 4627, outer left contact of relay 4626, to the grounded conductor 4614. Relay 4627, however, being shunted does not operate at this time. Relay 4626 opens the circuit of relay 4905, causing the disconnection of the sender connector 4900 to disassociate the sender from the marker.

It will be understood that the timing device 6501 provides an interval of time for the

trouble indicator to take a record of the condition of the incoming marker, and at the end of such interval the trouble indicator is released.

As soon as the sender connector 4900 releases, the shunt is removed and relay 4627 operates in series with relay 4626. Relay 4627 again closes the operating circuit for relay 4905 and the sender connector 4900 is reoperated to connect the sender either to the same or to another idle marker in order to make a second trial.

Assume that the new marker belongs to the same group as the first one, and accordingly it may be considered that the marker shown in the drawing is the new marker selected. As soon as the marker is attached, a circuit is closed from battery, through the windings of relays 5148 and 5149, conductor 5150, connector 4900, conductor 4918, inner left contact of relay 4626, inner right contact of relay 4627, to ground. Since no appreciable resistance is included in this circuit, both the marginal relay 5148 and the sensitive relay 5149 are energized. Relay 5149 closes an obvious circuit for relay 5151. The relays 6108 and 5409 are also energized in a circuit which may be traced from battery, through the winding of relay 5409, and parallel to battery through the winding of relay 6108, conductor 6121, contacts of relays 5148 and 5149, to ground. The multi-contact relay 6108 operates and shifts its armatures from the back contacts to the front contacts. When, therefore, the start circuit is again closed for the incoming frame connector, it will now lead through the armature and front contact of relay 6108 to the winding of the relay 6119. Accordingly the alternate frame connector 6101 is appropriated for associating the marker with the incoming frame, the connector 6100 having been used on the first trial.

The multi-contact relay 5409 also shifts its armatures to the front contacts and therefore determines that the alternate translator connector 5800 will be used instead of the translator connector 5700. To this end the start circuit closed through the translator 5400 may now be traced over conductor 5407, contact of key 5408, conductor 5415, lower winding of relay 5803, to ground at the back contact of relay 5804. The connector 5800, as hereinbefore explained, operates to connect the incoming marker to the alternate final translator 6000. In a manner analogous to that hereinbefore described, translator 6000 determines the selection of a vertical magnet on the final switch, the final trunk connector 6201 is selected and operated, and the final frame connector 6301 is selected and thus, due to the fact that the second trial marker has caused the operation of relay 5409, an alternate translator and connecting devices have been used to associate the

marker and translator with the final switch and trunks.

It will be obvious, of course, that the incoming markers are arranged in groups, an even and an odd group, similar to the arrangement of the outgoing markers, and that a second trial marker whether the same or different from the first trial marker will also employ connecting devices and a final translator different from the ones employed on the first trial.

The keys 3005, 3103, 3223, 5408 and 6109 are provided so that one set of connectors and translators may be thrown out of service, permitting the other alternate set to be employed by the markers.

Operation of the outgoing marker trouble indicator.—During the time the trouble indicator shown in Figs. 41 and 42 is associated with the outgoing marker through the connector 4000, various ones of the leads 4007 will be grounded in the marker depending upon the progress which has been made. These grounded leads cause the operation of corresponding ones of the relays in the trouble indicator which energize to light lamps and which also close circuits for governing the operation of a printer 4201. The lamps give a visual indication temporarily of the progress that has been made showing the point at which the trouble occurred or a point at which the marker failed to continue further in the control of the switches. The printer 4201 automatically prints in a well known manner a record on a tape or a medium giving the history of the performance in permanent form. For a more detailed description of the manner in which the trouble indicator and the printer operate, reference is made to U. S. Patent No. 1,594,003, issued July 27, 1926, to W. W. Carpenter, and to the application of E. B. Craft and L. Keller, Serial No. 747,174, filed November 1, 1924.

More specifically, the trouble indicator consists of three sets of relays 4102, 4101 and 4100 which have circuits leading to the corresponding operating conductors of the hundreds, tens and units registers 2900, 2901 and 2902. Accordingly, these relays in the trouble indicator take a record showing the digits which were dialed and recorded in the marker.

The relays 4109 are individual to the various markers and are operated from contacts of the individual relays 4001, 4002, etc. Whenever one of these relays operates, it designates the particular marker to which the trouble indicator has been connected.

Moreover, there is provided a set of relays 4200 which have circuits leading to the testing relays 2800 in the marker. These relays are each individual to one of the horizontal links and serve to indicate the particular

horizontal link that was used in the attempted connection.

The relays 4204 designate the senders and are operated in circuits which may be traced through contacts of the individual sender relays 2501, 2502, etc., and thence to ground 70 through the connector 4000.

The relays 4205, 4206, etc., are operated in circuits which lead through the contacts of relays such as 413 and thus individualize the trunks incoming from the district frame. 75 Relays 4207, 4208, etc., are operated in circuits leading through contacts of relays 3605, 3607, etc., and thus individualize the particular district frame.

Similarly, relays 4209, 4210, etc., are individual to the office selector trunks while relays 4211 and 4212 relate to the office frames. The relays shown in Fig. 42 are equipped with indicating lamps which are operated from contacts of the relays. For instance, the set of lamps 4224 is provided for the group of relays 4200 and these lamps may be numbered serially, each representing a different horizontal link. By variously connecting the contacts of the relays, each relay may serve to illuminate the proper one of the several lamps. If desirable, part of the lamps may serve as tens lamps and the others as units lamps, thus requiring only twenty lamps for a large number of horizontal links. Each relay would then operate two lamps to designate the tens and units digit of the particular horizontal link. Similarly, the remaining lamps shown in Fig. 42 may be wired to the respective relays.

It is not believed necessary to assume a specific instance of trouble in the marker and show which of the lamps are lighted in such case. This has already been done in detail in the previously mentioned Carpenter Patent No. 1,594,003.

The printer 4201, which normally provides ground on the conductor 4105, may be arranged to remove this ground as soon as it has received the record, thus permitting the relay 4105 to release making it possible for the trouble indicator to be seized a second time.

In addition to the relays and lamps already specified, a trouble indicator is provided with a series of progress relays 4103 and a series of trouble relays 4104. A large number of relays in each of these sets may be provided, although only a few have been 120 illustrated. The leads from the progress relays extend and terminate in the bracketed leads 2927. Similarly, the leads from the trouble relays 4104 extend and terminate in the bracket 2928. The purpose of the progress relays is to show each of the sequential operations which have taken place in the marker up to the point where the marker

ceases to operate. Throughout the marker there will be found, as hereinbefore explained, a number of pairs of test relays occurring in the various operating circuits.

- 6 For instance, the relays 3207 and 3206 constitute one such pair. In these cases one of these relays is sensitive and the other relay is marginal. In the normal operation of the system, only enough current flows through the circuit to operate the sensitive relay. For example, when the horizontal magnet of the selector switch is energized, if the circuit is functioning normally, the relay 3206 alone operates. This relay applies ground potential to the conductor 3227, which leads to the bracket 2927 and thence over one of the leads to the trouble indicator and to the operating winding of the corresponding relay in the group 4103. The energization of this relay in the trouble indicator will indicate that the horizontal magnet was operated properly. The same is true of the remaining sensitive test relays throughout the marker.

- 25 The trouble relays 4104 are for the purpose of indicating that certain conductors in the marker have become crossed with each other, resulting in an excessive potential. The manner in which such a trouble is detected will now be explained.

- Whenever certain of the conductors become crossed with each other, resulting in an excessive potential upon one of these conductors, the marginal relay in the marker such as the relay 3207 will operate in addition to the sensitive relay. Relay 3207 in operating closes a circuit from ground, through its front contact, conductor 3228, through the left winding of the relay 3923, to battery. Whenever one of the relays 3901 operates in response to the existence of such a condition, it is desired to immediately hold the progress of the marker and to summon a trouble indicator without waiting for the counting of a time interval. Accordingly, a circuit is completed from ground, through the left contact of one of the relays 3901, conductor 3924, winding of relay 3028, to battery. Another circuit is closed from conductor 3924, thence over conductor 3230, winding of relay 3208, to battery. The relay 3028 opens the releasing lead to prevent the marker from giving the sender a signal, whereas relay 3208 opens the operating circuit of the horizontal magnet to prevent this magnet from being operated. The operated relay 3923 also closes a circuit from ground, through its inner right contact, conductor 3925, thence over conductor 4325, to operate the connector 4000 to attach the trouble indicator immediately.

- It will be noted that in the normal operation the marginal relay such as the relay 3207 does not operate, and accordingly a circuit is closed from ground, through its

back contact, thence over conductor 3231, through the bracket 2928, and thence through the connector 4000, to operate the corresponding one of the trouble relays 4104. When, however, the relay 3207 operates, ground is removed from its back contact and accordingly the corresponding relay 4104 in the trouble indicator remains deenergized. The failure of this relay to energize serves as an indication that a crossed condition of the conductors exists and also shows exactly what conductors have encountered the trouble.

Another function of the relays 3901 is to close an operating circuit for an alarm such as a gong 3903.

A further check is made upon the circuits of the marker by means of the relays 3900. The windings of these relays are connected to various conductors in the marker which are of importance, and whenever one of these conductors becomes grounded a corresponding relay will operate. The operation of the relay starts the time measuring device 4300 to function, and if the grounded condition remains longer than it should the device 4300 immediately functions and a circuit is closed for operating a gong or other alarm 3902 to notify an attendant. In this instance, however, the trouble indicator is not summoned.

Inasmuch as the incoming marker is provided with the same indicating device as above explained, it is not thought necessary to go into a detailed description thereof.

Private branch exchange operation.—The system is arranged to accommodate P. B. X. trunk groups of varying sizes. Where a group contains more than ten trunks, it is divided into subgroups of ten each for the purposes of testing. The testing equipment shown in Fig. 56 is arranged to test the subgroups of ten, one at a time in succession until a subgroup is found containing an idle trunk.

Each P. B. X. trunk group is identified at the final frame by a call member corresponding to which a call circuit occupies the position similar to a subscriber's line. These identifying call circuits may be located anywhere on the frame, in the same vertical rows with direct subscribers' lines if desirable. If a P. B. X. trunk group contains an even ten trunks, five of these will appear in a vertical row on one final frame and the other five in a vertical row on a second final frame in the same terminal choice. If a group contains twenty trunks, five of the first subgroup of ten will occupy a full vertical row on one final frame, the second five of the first group will occupy a vertical row on the second frame, and correspondingly the first and second halves of the second group of ten will occupy vertical rows on the first and second mentioned final frames.

In a similar manner where a group contains any even multiple of ten, each subgroup of ten is divided and half of them are arranged on one final frame and the other half on a different final frame. It may occur, however, that the number of trunks in a group is not an even multiple of ten. If the number is greater than ten, as many full subgroups of ten as there are may be arranged as explained. If the fractional group is greater or less than five, it will be necessary to have a number of the trunks less than five appearing on some final frame and thus not occupying a full vertical row, there being as heretofore explained five horizontal groups of links in each final frame. To be specific, if a group of sixteen trunks is assumed, the first ten of these will be disposed five on one frame and five on another. The remaining group of six will be arranged with the first five on one frame and the remaining one on another frame. It may be desirable to have the odd trunk constitute the first trunk in the entire group or the last trunk, in which case the testing operation may begin with the odd trunk or terminate with the odd trunk. In any event, the odd trunk or trunks where more than one occurs may be located at any desired point in the final frame, and the testing equipment is arranged to take into account the variable location of such trunks. This will be better understood from a description of the testing equipment shown in Fig. 56.

This testing equipment consists of a series of ten testing relays 5600, one for each trunk in a full subgroup. It also includes a series of ten relays 5602 each of which identifies the ten points at the final frames occupied by a full group of ten trunks. If the testing operation is to begin at some point other than the first point in the final frame, then the particular relay 5602 representing the starting point will be operated. This operated relay will determine the starting point of the testing operation. After this first fractional subgroup of ten is tested, then the operated relay 5602 is released so that on testing a subsequent full subgroup of ten, all of the testing relays 5600 will be employed.

Moreover, there is provided a series of relays 5604 each of which represents the end of a P. B. X. trunk group. For instance, the first relay may pertain to groups having only one subgroup of ten; the second relay pertaining to a group having two subgroups of ten, and so on. When, therefore, the last subgroup of ten is being tested, the proper one of these relays having been operated will serve to determine the testing operation.

Where it is desired to have the fractional portion of a group at the end of the total P. B. X. trunk group, the relays 5608 serve to determine which one is the last trunk in

the group and to give a busy signal in case all of these trunks are busy.

Assume that a call is made to a private branch exchange having a group of eighteen trunks appearing in the vertical rows 1104 and 1105 of the final switch 1000 and in two similar vertical rows of another final switch in the same final group. It may also be assumed that the call circuit constitutes the first trunk in the group. The operation proceeds in the manner hereinbefore explained to the point where the final translator 5900 is operated. Since a P. B. X. trunk group is being called, it will be assumed that the relay 5905 and relay 5902 of the translator 5900 are operated, and that the start circuit leads over conductor 5708 as previously traced, through contacts of relays 5905 and 5902, thence through the winding of the P. B. X. trunk group relay 5910, to battery. Relay 5910 identifies the called group of trunks and causes the operation of relay 5510 in a circuit from battery, through the winding of the latter relay, conductor 5522, thence through the connector 5700, inner right contact of relay 5910, to ground over the operating circuit for relay 5910. Relay 5510 operates the relays 5508 and 5512 in an obvious circuit. The operation of relay 5510 causes the release of relay 5312, also the release of the line vertical magnet of the final switch, and causes the operation of transfer relays 5329 and 5412. The operation of these latter relays may be traced in a circuit from battery, through their windings, thence to ground at the left front contact of relay 5510. The translator relay 5905 is now held in a circuit from battery, through its winding, thence through the connector 5700, conductor 5707, outer left front contact of relay 5412, conductor 5417, right back contact of counting relay 5610, thence over conductor 5416, to ground on conductor 5413 as previously traced. The counting relays 5603 are for counting the subgroups of ten trunks as they are tested in succession. The counting relay 5611 is energized at this time in a circuit from battery, through its winding, left back contact of relay 5610, to ground on conductor 5416. Relay 5611 prepares a circuit from battery, through its winding and contact, winding of relay 5610, conductor 5504, to ground. Relay 5610 being shunted, however, does not operate at this time.

If it be assumed that the first trunk in the group is located in the final frame at a position corresponding to the second test relay 5615, then the first relay 5618 will be operated to nullify the effect of relay 5614. The circuit for this relay may be traced from battery, through the winding of said relay 5618, conductor 5620, connector 5700, thence through the contact of relay 5910,

and returning through the connector 5700, conductor 5805, to ground at the contact of relay 5519.

Since the assumed group of trunks has two subgroups, the relay 5621 is operated in a circuit from battery, through its winding, conductor 5622, contacts of connector 5700, conductor 5720, to ground at the contact of relay 5910. Relay 5621 closes an obvious circuit for relay 5606. The relay 5621 will determine the testing operation after the last subgroup of trunks has been tested.

The test circuit for the first trunk, which is the called line, may be followed from battery, through the left winding of relay 5614, right back contact of relay 5625, inner right front contact of relay 5618, conductor 5626, thence through the connector 5700, conductor 5721, outer right contact of relay 5910, conductor 5911, to the sleeve conductor of the first trunk 1111, for instance.

The test circuit for the second trunk in the subgroup may be traced from battery, through the left winding of relay 5615, right back contact of relay 5623, inner right back contact of relay 5619, conductor 5624, front contact of relay 5329, conductor 5330, left winding of relay 5331, conductor 5332, connector 5700, conductor 5711, contacts of relay 5905, contacts of relay 5902, and thence to the sleeve conductor of the second trunk in the group. Similarly, test circuits for the remaining trunks in the first subgroup lead through the windings of respective test relays 5616, 5617, etc., through the contacts of relay 5329, through the connector 5700 and the translator 5900 to the test conductor of these trunks. If all of the trunks in the first subgroup are busy, the test relays are all operated indicating that a repetition of the test should be made with respect to the second subgroup.

When relay 5329 operates it closes a circuit for the slow-operating timing relay 5520 traceable from battery, through the winding of the latter relay, thence through the right contact of relay 5329, conductor 5320, left back contact of relay 5506, conductor 5507, to ground. Relay 5520 after an interval closes an obvious circuit for the slow-operating relay 5521. These relays provide a sufficient interval for the testing relays to adjust themselves. When relay 5521 operates, relay 5506 is energized in a circuit from battery, through the winding of the latter relay, left contact of relay 5605, left front contact of relay 5617, left back contact of relay 5627, left front contact of relay 5616, and in a similar manner through the front contacts of all operated relays in the series 5600 and through the back contacts of relays in the series 5608, finally through the left front contact of relay 5614, conductor 5630, left contact of relay 5618, to

ground at the contact of relay 5521. Relay 5506 opens the locking circuit of the test relays 5600, releases the time measure relays 5520 and 5521, releases the final translator relay 5905, and operates relay 5519. Relay 5519 locks through its inner right contact to ground on conductor 5505. Relay 5519 releases the relay 5618 for the reason that the test circuit of the corresponding trunk in the remaining subgroups will lead directly to the sleeve conductor of these trunks rather than through the contacts of the relay 5910. The release of the final translator relay 5905 disconnects the ten test relays 5600 from the terminals of the first subgroup of ten lines. The shunt around the winding of the counting relay 5610 is opened at this time and this relay operates in series with relay 5611. As soon as the test relay is released, the relay 5506 also releases.

A new tens relay in the translator 5900 is now operated to associate the test relays 5600 with the second subgroup of P. B. X. trunks. This circuit may be traced from the grounded conductor 5507, through the left back contact of relay 5506, conductor 5320, thence through the register 5302, conductor 5413, conductor 5416, right front contact of relay 5610, conductor 5631, right back contact of relay 5632, contact of relay 5412, conductor 5418, through the winding of relay 5906, to battery. The testing relays are thus connected to the second subgroup of P. B. X. trunks. Since the relay 5621 is energized, indicating that this is the last subgroup to be tested, ground over conductor 5416 is extended through the left front contact of relay 5610, left contact of relay 5621, winding of relay 5605, to battery. One of the relays 5608 is operated next to define the position of the last trunk in the subgroup. The circuit for this purpose may be traced from ground, through the right front contact of relay 5605, conductor 5634, connector 5700, inner left contact of relay 5910, thence returning through the connector 5700, conductor 5722, winding of relay 5627, to battery.

If all of the trunks in this subgroup are busy when the timing relays 5520 and 5521 operate, a circuit is closed from ground, through the contact of relay 5521, outer contact of relay 5519, conductor 5630, thence through the front contacts of the operated test relays, armature and front contact of relay 5627, through the winding of relay 5518, to battery. In the manner similar to that hereinbefore described, relay 5518 causes the marker to control the incoming selector to connect the calling subscriber's line to a busy tone trunk.

If, during the testing operation, an idle P. B. X. trunk is found, the associated test relay remains unoperated. When, therefore, the timing relay 5521 operates, the grounded

circuit over conductor 5630 leads through the left back contact of the unoperated test relay, such as the relay 5614, to operate the associated relay 5625. Relay 5625 completes a circuit from ground, through its left contact, thence over conductor 5635, through the connector 5700, through the translator 5900, winding of the proper vertical operating magnet 1109 at the final switch. Moreover the relay 5625 operates one of the relays 5336 in a circuit traceable from the grounded conductor 5523, right front contact of relay 5625, inner right back contact of relay 5618, thence through the front contact of relay 5329, left winding of relay 5336, to the connector 5700, through the translator 5900, to battery on the sleeve conductor of the selected idle P. B. X. trunk. The relay 5336 causes the operation, in the manner hereinbefore explained, of the proper one of the relays 6311, 6312, etc. This operated relay associates the test relays 5200 in the marker with the proper group of horizontal links in the final switch 1000. A test of these links is made and an idle one chosen and the switch is operated to seize the idle P. B. X. trunk in a manner similar to that already explained for a direct subscriber's line.

What is claimed is:

30 1. The combination in a telephone system of a selective switch, a controlling mechanism, a plurality of connectors for successively connecting said mechanism to and disconnecting the same from said switch to selectively operate the switch to extend a connection, means for using a particular one of said connectors whenever the mechanism is connected to said switch the first time for extending a connection, and means effective whenever the mechanism is to be connected to said switch a second time during the extension of the same connection to use a different one of said connectors.

45 2. The combination in a telephone system of a selective switch, a controlling mechanism, a plurality of connectors, means for operating a particular one of said connectors to connect said mechanism to the switch, said mechanism serving to selectively operate the switch to establish a connection, means effective in case said connection is not established to cause the disconnection of the mechanism from said switch, and means for thereupon selecting and operating another of said connectors to again connect said controlling mechanism to the switch to control the establishment of said connection.

60 3. The combination in a telephone system of a selective switch for establishing connections, a controlling mechanism arranged to make a plurality of separate attempts to selectively control said switch to extend a connection therethrough, a plurality of connectors, means for employing a particular one of said connectors to connect the mecha-

nism to said switch for the first attempt, and means if a second attempt is required to select and use a different connector for reconnecting the controlling mechanism to said switch.

70 4. The combination in a telephone system of an automatic switch for extending telephone connections, a controlling device for selectively operating said switch, a number of connectors, means for operating one of said connectors to connect said device to the switch, means effective if said device fails to operate the switch for disconnecting the same therefrom without releasing the connection, and means for selecting and operating a different one of said connectors to connect said device to the switch in a second attempt to operate said switch.

75 5. The combination in a telephone system of an automatic switch for extending telephone connections, a controlling device for controlling the selective operation of said switch, a number of connectors, means for using a particular one of said connectors to connect said device to the switch, means effective if said device encounters trouble for disconnecting the same from the switch, means for thereupon selecting and operating a different one of said connectors to reconnect the controlling device to the switch 80 for a second trial, a recording mechanism for recording the progress made by said device, and means for associating said recording mechanism with the controlling device 85 whenever the latter encounters trouble.

90 6. The combination in a telephone system of a group of trunks, a selective switch having access to said trunks, means for extending a telephone connection to said switch, a testing and controlling mechanism, a number of connectors, means for employing a particular one of said connectors for connecting the testing mechanism to said trunks to determine an idle one thereof in a first trial to extend said telephone connection 95 through said switch, means for causing the disconnection of said mechanism from said trunks without disturbing the extended telephone connection, and means for selecting and operating another of said connectors to connect the testing mechanism to said trunks to determine an idle one in a second trial 100 to extend said telephone connection.

105 7. The combination in a telephone system of a group of trunks, a selective switch having access to said trunks, means for extending a telephone connection to said switch, a controlling and testing device, a number of connectors, means for taking in use a certain pair of said connectors, one for connecting said device to the switch to selectively control the same in a first trial to further extend said telephone connection through said switch over one of said trunks and the other connector of said pair for connecting 110 115 120 125 130

- said device to the trunks to determine an idle one thereof, means for causing the disconnection of the device from said switch and from said trunks without disturbing 5 said telephone connection, and means for taking into use a different pair of said connectors to reconnect said device to the switch and to said trunks in a second trial to extend the telephone connection.
10. 8. The combination in a telephone system of an automatic selective switch, a plurality of controlling mechanisms, means for taking one of said mechanisms into use to selectively control the operation of said switch to extend a telephone connection, a number of connectors, means for employing a particular one of said connectors to connect the controlling mechanism to said switch, means for causing the disconnection of said mechanism 15 from the switch without disturbing the telephone connection, means for thereupon taking into use any one of said mechanisms for a second trial to selectively control said switch, and means for selecting and operating 20 a different one of said connectors to connect said second trial mechanism to the switch.
9. The combination in a telephone system of a group of trunks, a selective switch having access to said trunks, means for extending a telephone connection to said switch, a plurality of markers, a number of connectors, means for seizing any one of said markers to test said trunks for an idle one 25 and to control the operation of said switch to further extend the telephone connection over one of said trunks, means for employing a certain pair of said connectors, one for connecting the seized marker to said switch and the other for connecting the marker to said trunks, means for releasing said 30 marker without disturbing said telephone connection, means for thereupon seizing any one of said markers in a second attempt to 35 extend the telephone connection through said switch, and means for selecting and using a different pair of said connectors for connecting the second trial marker to said switch and trunks.
40. 10. In a telephone system, a plurality of selective switches in series, means for extending a telephone connection toward said switches, a plurality of markers, a number of connectors, means for seizing an idle one of 45 said markers to control the selective operation of said switches to further extend said connection, means for using a certain set of said connectors, each for connecting said marker to a respective one of said switches, 50 means for releasing the marker from said switches if the latter are not completely operated without disturbing the extended telephone connection, means for thereupon seizing an idle one of said markers for a second trial to operate said switches, and 55

means for using a different set of connectors for connecting the second trial marker to said switches.

11. In a telephone system, a selective switch, means for extending a telephone connection to said switch, two markers, two connectors, means for seizing either one of said markers for controlling the selective operation of said switch to further extend said connection, means dependent upon the 70 marker seized for using a particular one of said connectors to connect the seized marker to said switch, means for releasing the seized marker without interfering with the extended telephone connection, means for thereupon seizing either one of said markers for a second trial to control said switch, and means for selecting the other of said connectors for connecting the second trial marker to the switch regardless of which 75 marker is used for said second trial.

12. In a telephone system, an automatic switch, means for extending a connection to said switch, two markers, a first connector normally preferred by one of said markers, 80 a second connector normally preferred by the other marker, means for seizing either marker for controlling the selective operation of said switch to further extend said connection, means for using the connector 85 normally preferred by the seized marker for connecting such marker to the switch, means for releasing the seized marker and connector in case said switch is not properly operated without releasing the extended connection, means for seizing either one of said markers for a second attempt to control the switch, and means for selecting and using the connector not employed in the first trial 90 for connecting the second trial marker to 100 said switch.

13. In a telephone system, a selector switch, a first group of markers, a connector normally preferred by said group, a second group of markers, a second connector normally preferred by said second group, means for seizing any marker in either group for controlling the selective operation of said switch, means for selecting and operating the connector normally preferred by the seized 110 marker to connect such marker to said switch, means effective if the seized marker is unsuccessful in controlling the switch for releasing such marker, means for thereupon seizing any marker in either group for a second trial to control said switch, and means for selecting and operating the connector not used by the marker first seized 115 to connect the second trial marker to the switch regardless of whether the second trial marker belongs to the first or second group.

14. In a telephone system, a selective switch, two groups of markers, two connectors, each normally preferred respectively by one of said groups of markers, means for 120

125

130

seizing any marker to control the selective operation of said switch, the seized marker having means for selecting for use the connector preferred by such marker to connect 5 said seized marker to the switch, means effective if the seized marker is unsuccessful in controlling said switch for releasing the marker, means for thereupon seizing any one of said markers for a second trial to control 10 said switch, and means for informing the second trial marker as to which group contained the marker first seized, said second marker having means effective in accordance with the information received to cause the 15 selection and operation of the connector not used for the first trial to connect said second trial marker to the switch.

16. In a telephone system, automatic switches arranged in groups, two groups of 20 markers, a first group of connectors normally preferred by one group of markers, a second group of connectors normally preferred by the other group of markers, the several connectors in each group serving to connect the 25 markers to respectively different groups of switches, means for seizing any marker in either group for controlling the operation of any particular switch, means for selecting and operating the connector in the group 30 preferred by the seized marker which has access to the group of switches containing said particular switch for connecting the seized marker to said switch, means effective if the seized marker fails to control the operation 35 of said switch for releasing said marker, means for then seizing any marker in either group in a second trial to control the switch, and means for selecting and operating the connector in the group other than the group 40 containing the connector first used for connecting the second trial marker to said particular switch.

17. The combination in a telephone system of a selective switch, means for extending a 45 connection thereto, a sender for registering designations, a plurality of markers, a pair of connectors, one serving as first choice to part of said markers and the other as first choice to other of said markers, means for causing said sender to seize any one of said markers to control the operation of said switch, means to select and operate the connector serving as first choice to the seized marker for connecting such marker to the 55 switch, means effective if the seized marker does not proceed regularly to release the same both from the sender and switch, means for causing the sender to reseize any one of said markers for a second trial, and means for selecting and operating the connector other than the one first used to connect said second trial marker to the switch.

18. The combination in a telephone system of a selective switch, a sender for registering 60 designations, two groups of markers, a first

choice connecting device for each group of markers, means for causing the sender to seize any one of said markers to control the operation of said switch, means for causing the operation of the connecting device which 70 is first choice to the seized marker for connecting such marker to the switch, means effective if the seized marker does not proceed regularly to establish in the sender a record identifying the group containing the seized marker and for causing the release of such marker both from the sender and from the switch, said sender then acting to reseize any one of said markers for a second trial, said second trial marker being governed by 75 the identifying record in the sender to select and operate the connecting device other than the one first used to connect said second trial marker to the switch.

19. The combination in a telephone system of a plurality of switches and trunk groups for the extension of telephone connections, markers, switch connectors and trunk connectors, each connector being first choice to some markers and second choice to others, means for using any marker for testing said trunks and controlling the switches in a first trial to extend a connection, means for operating the switch and trunk connectors which are first choice to the marker in use for connecting such marker to the switches and trunks, means effective if the first trial is not successful for releasing the marker and connectors, means for taking any marker in use for a second trial, and means for operating switch and trunk connectors other than the ones first used for connecting the second trial marker to the switches and trunks whether such other connectors are first or second choice to the second trial marker.

20. In a telephone system, a group of switches, two translators for governing the operation of any one of said switches, two markers arranged to cooperate with said translators, means for seizing either one of said markers in a first trial to extend a connection through one of said switches, means for connecting the seized marker to a preferred one of said translators, means effective if the first trial is unsuccessful to release the marker and translator, means for causing the reseizure of either marker for a second trial, and means for connecting the second trial marker to the translator not used for the first trial whether or not such translator be the preferred one for said second trial marker.

21. In a telephone system, a plurality of groups of switches, two translators for each group for controlling any switch therein, two groups of markers arranged to cooperate with said translators, means for seizing any marker in a first trial to extend a connection through a particular switch, means for connecting the seized marker to the pre-

ferred one of the two translators associated with the group containing said particular switch, means effective if the first trial encounters trouble for releasing the marker and translator, means for causing the reseizure of a marker in either group in a second trial, and means for connecting the second trial marker to the second translator of the pair associated with the group containing the particular switch whether or not such second translator is preferred by said second trial marker.

21. In a telephone system, a selective switch, two translators for controlling the operation of said switch, two groups of markers for cooperation with said translators, said translators being respectively first choice each to a different group of markers and second choice to the other group, two connectors for connecting the markers to the translators, means for seizing any marker in a first trial to extend a connection through said switch, means for operating the first one of said connectors to connect the seized marker to its first choice translator, means for causing the release of the marker and translator if the first attempt fails, means for reseizing any of said markers for a second trial, and means for operating the second one of said connectors to connect the second trial marker to the translator other than the one used in the first trial.

22. In a telephone system, a selective switch, two groups of markers, two connectors, each serving as first choice to a different one of said groups of markers, means for seizing any marker in a first trial to selectively control the operation of said switch, means for operating the first choice connector to connect said marker to the switch, means effective if the marker encounters trouble to release the same, means for seizing any one of said markers for a second trial, means for operating the connector not used in the first trial for connecting the second trial marker to said switch, a trouble device common to all markers and serving to indicate the performance of a marker that has encountered trouble, and means for temporarily connecting said device to the first trial marker at the time said marker is released.

23. In a telephone system, selective switches, a plurality of controlling mechanisms for governing the selective operation of said switches, an indicating device common to said mechanisms for indicating progress made by said mechanisms, timing means effective after a given interval following the seizure of one of said mechanisms for connecting said device to such mechanism, and means responsive to certain conditions in any one of said mechanisms for connecting said device thereto immediately.

24. In a telephone system, selective switches, a plurality of markers for control-

ling said switches, a trouble indicating device common to said markers, means for seizing a marker for use and connecting it to one of said switches, means effective at the end of an interval following the seizure of a marker for connecting the indicating device to such marker, means controlled by said device for releasing the marker, and means responsive to the presence of certain conditions in a marker for immediately connecting said device to such marker.

25. In a telephone system, an automatic switch having selectively operable contacts, a controlling mechanism for controlling the selective operation of said switch to extend a telephone connection therethrough, means for seizing said mechanism for use, a test circuit including a polarized relay in said mechanism for testing the continuity of the telephone connection extending through said switch, a source of current for said test circuit, said relay operating upon the closure of the test circuit if the current from said source is in the proper direction, and release means for said mechanism dependent upon the operation of said relay.

26. In a telephone system, a number of automatic switches having selectively operable contacts, a marker for controlling the selective operation of said switches to extend a telephone connection through the contacts of said switches in series, means for seizing said marker for use, a circuit for testing the continuity of the telephone connection extended through the contacts of said switches, said circuit including a source of current and a polarized relay, said relay operating upon the closure of the test circuit if the current flows in the proper direction, and means for releasing said marker dependent upon said polarized relay.

27. In a telephone system, a plurality of groups of trunks of different sizes, selective switches having series of contact points in which said trunks appear, said groups so arranged that the first trunk of each group appears in a point in one series not corresponding to the point in other series of contacts in which appears the first trunk of other groups, a common device for testing said trunks and including a plurality of relays, one for defining each of the separate points in said series of contacts in which the first trunk of a group may appear, and means effective when it is desired to test a particular group of trunks for operating the proper relay to determine the point in which appears the first trunk of such group.

28. In a telephone system, a selective switch having series of contact points, trunks divided into groups of different sizes and so arranged that the trunks of each group begin at a number of different arbitrary points in said series of contacts, continue consecutively and terminate in a number of different

arbitrary contact points in said series, a common device having a series of trunk testing relays corresponding to said series of switch contacts, and means effective when it is desired to test the trunks of a particular group to start the testing operation with the particular relay in said series corresponding to the location of the first trunk in said group and for terminating the testing operation with the relay corresponding to the location of the last trunk in said group.

29. In a telephone system, a selective switch having series of contact points, trunks divided into groups of different sizes and so arranged that the trunks of any group may begin at any one of a number of different arbitrary points in said series of contracts and terminate in any one of a number of contract points, the points of beginning and ending for the several groups being non-corresponding, a series of trunk test relays common to all groups and having as many relays as there are contact points in a single series, means for using exclusively any portion of said series of relays corresponding to the location in a series of contacts of a group of trunks to be tested, and means for starting the testing operation at different points within the portion of relays employed in the testing operation.

30. In a telephone system, a group of trunks divided into subgroups, a number of switches for extending connections over said trunks, a series of test relays for testing the trunks of a subgroup simultaneously and arranged to be applied to said subgroups in succession until an idle trunk is found, a series of relays each for determining a dif-

ferent starting point for the testing operation in the first subgroup, and a series of relays each for determining a different terminating point in the testing operation in the last subgroup.

31. In a telephone system, a plurality of groups of trunks each divided into subgroups, a number of switches for extending connections over said trunks, a series of test relays common to all groups for testing the trunks of a subgroup simultaneously and arranged to be applied to said subgroups in succession until an idle trunk is found, a series of relays each for determining a different starting point for the testing operation in the first subgroup of any group, and a series of relays each for determining a different terminating point in the testing operation in the last subgroup of any group.

32. In a telephone system, a plurality of groups of trunks each divided into subgroups, a number of switches for extending connections over said trunks, a series of test relays common to all groups for testing the trunks of a subgroup simultaneously and arranged to be applied to said subgroups in succession until an idle trunk is found, a series of relays each for determining a different starting point for the testing operation in the first subgroup of any group, a series of relays each for determining a different terminating point in the testing operation in the last subgroup of any group, and a set of counting relays for counting the number of subgroups to be tested.

In witness whereof, I hereunto subscribe my name this 13th day of July, A. D., 1925.

WARREN W. CARPENTER.
